Detailed description of the circuit diagram:

The diagram illustrates a complex electrical circuit, likely a filter or oscillator, with the following key components and connections:

- Power Input:** A vertical line on the left is labeled **D2** at the top and **116** at the bottom.
- Resistor Network:** A large rectangular block on the left contains resistors labeled **620**, **621**, **622**, **623**, **624**, **625**, **630**, **631**, **632**, **633**, and **634**.
- Capacitor Network:** A large rectangular block on the right contains capacitors labeled **640**, **641**, **642**, **643**, **644**, **645**, **652**, **653**, **654**, **655**, **656**, **657**, **663**, **664**, **665**, **666**, **667**, **668**, **669**, **670**, **671**, **672**, **673**, **674**, **675**, **676**, **677**, **678**, and **679**.
- Inductor Network:** Inductors are represented by vertical lines with arrowheads pointing upwards. They are labeled **601**, **602**, **603**, **604**, **605**, **611**, **612**, **613**, **614**, **615**, **616**, **617**, **618**, **619**, **620**, **621**, **622**, **623**, **624**, **625**, **630**, **631**, **632**, **633**, **634**, **640**, **641**, **642**, **643**, **644**, **645**, **652**, **653**, **654**, **655**, **656**, **657**, **663**, **664**, **665**, **666**, **667**, **668**, **669**, **670**, **671**, **672**, **673**, **674**, **675**, **676**, **677**, **678**, and **679**.
- Switches:** Several vertical lines with arrowheads pointing upwards represent switches, labeled **628**, **629**, **636**, **637**, and **638**.
- Ground:** A horizontal line at the bottom is labeled **118** at the top and **119** at the bottom.

UNITED STATES PATENT OFFICE

JOHN WICKS, OF OAK PARK, ILLINOIS, ASSIGNOR TO RESERVE HOLDING COMPANY, OF KANSAS CITY, MISSOURI, A CORPORATION OF DELAWARE

AUTOMATIC TELEPHONE SYSTEM

Application filed August 6, 1928, Serial No. 297,610, and in Great Britain August 8, 1927. Renewed December 15, 1930.

The present invention relates to improvements in or relating to an automatic or semi-automatic telephone system, and while it more particularly concerns means for enabling step-by-step exchanges to work in conjunction with revertive control exchanges and vice versa, it also contains improvements applicable to both types of systems, and possibly to automatic telephony generally.

10 The system disclosed herein may be considered an improvement on the systems disclosed in the co-pending applications of Arthur J. Ray, Serial No. 589,985, filed September 23, 1922, and Serial No. 599,022, filed 15 November 4, 1922.

As is well known, in step-by-step exchanges the switches respond directly to impulses generated by a calling subscriber, or if they do not respond directly, they respond to impulses generated in a similar manner either by an operator or by a register controller. The revertive control exchange on the other hand includes switches which are power driven, the extent and movement of which is 20 controlled by a register controller, the register of which is set by the calling subscriber or by an operator, as the case may be, and the control is effected by counting the number of impulses received back from the power 25 driven switches over what is known as a fundamental circuit. Usually the revertive impulses are the complement of the impulses generated by the calling subscriber.

One of the features of the present invention 30 is the provision of repeater translators whereby on the one hand the controlling impulses received from the step-by-step exchange are caused to control the operation of switches in the revertive control exchange in exactly the 35 same manner as if the switches were controlled from a local register and whereby on the other hand the control exerted by a register from the revertive control office is caused to effect transmission of impulses to the step- 40 by-step switches in an exactly similar manner to the manner in which the impulses are transmitted from a local subscriber's dial. By this means it is possible to arrange for the step-by-step exchange to interwork with 45 a revertive control exchange and the revertive

control exchange to interwork with a step-by-step exchange by the addition of separate units which can be located in either one exchange or the other.

Another feature of the invention is a particular layout of the step-by-step exchange so that it can conform with the layout of the revertive control exchange. The advantage of such a layout is that it enables the register translator between the revertive control exchange and the step-by-step exchange to be reduced in size as it can transmit a series of impulses immediately it has been set without necessitating a provisional means for storing the whole of the number. The register translators may either be individual to the trunk lines or may be provided in common to a group of trunk lines, preferably the translators between the step-by-step exchange and the revertive control exchange would be provided in common, whereas the register translators between the revertive control exchanges and the step-by-step exchanges may be individual as their size is not so great. Of course if desired they could be provided in common to a group of lines and whether this would be advantageous or not can be determined for any particular case.

These and other features of the invention, which have been developed to meet the various conditions which arise when actually working out the interworking between exchanges of known types, will be better understood by referring to the accompanying claims and the drawings, in which Figs. 1-9 and 23 taken in conjunction represent the switches and other circuit details incidental to understanding the setting up of a connection between a subscriber in a step-by-step exchange to a subscriber in a revertive control exchange; Figs. 1, 3, 4, 7, 12, 13, 14 and 15, taken in conjunction show an alternative arrangement for working to another type of revertive control exchange; Figs. 1, 16, 17 and 18 show an arrangement for setting up special calls from the step-by-step exchange to an operator in the revertive control exchange; Figs. 19, 20, 20a, 21 and 22 illustrate an arrangement for setting up a connection between a subscriber in a revertive control ex- 100

change to a subscriber in a step-by-step exchange, Figs. 24, 24a, 21 and 22, taken into conjunction, illustrate the setting up of a connection between a subscriber in a different type of revertive control exchange and a subscriber in a step-by-step exchange; Fig. 11 is a table to show which of the relays 211—215 are operated for the different number of impulses in a series; Fig. 10 shows how the various Figures 1 to 9 and 23 should be arranged for understanding the setting up of the first type of connection; Figure 26 illustrates how the Figures 1, 3, 4, 7, 12, 13, 14 and 15 should be arranged for setting up a second type of connection; Fig. 29 illustrates how Figures 1, 16, 17 and 18 should be arranged for setting up the third type of connection; Fig. 27 illustrates how the figures should be arranged for setting up the fourth type of connection; Fig. 28 shows how the figures should be arranged for setting up the fifth type of connection; Fig. 25 illustrates a general arrangement showing how the step-by-step exchange interworks in a network including a revertive control exchange and a manual exchange fitted with call indicators and operator control key sets. It will be understood however that the arrangements herein set forth are given by way of example only, and that various modifications may be made to provide for different circumstances by those skilled in the art without departing from the spirit of the invention.

A description will first be given of the arrangement shown in Fig. 25 so that the switching layout to which the invention applies may be understood. On the left-hand side of Fig. 25 is shown a revertive control exchange RCX, on the right-hand side is shown a step-by-step exchange SSX, while in the upper part of the middle of the figure is shown a manual exchange MX. The manual exchange MX is fitted with operator key sets OKS and with call indicator positions CIP. The apparatus in the revertive control exchange RCX and in the manual exchange MX is of known type as well as the interworking arrangements between these exchanges. Associated with the revertive control exchange RCX is shown in suitable rectangles the various apparatus required to set up a connection, a subscriber's instrument SI, having associated therewith at the exchange a line circuit LC. On making a call a primary finder PF, and a secondary finder SF operate to connect the calling line with a primary selector PS, having a register selector RS associated therewith. The register RS operates to find an idle register RG. The impulses dialled by the calling party are registered on the register RG while revertive control impulses for the primary selector PS, the second selector SR, the third selector R3 and the final selector R4 are sent back and the operation of these switches is controlled in

known manner to connect with a called subscriber's line, such as the line of substation B. In this way a connection is set up between one subscriber and another in the revertive control exchange RCX. For outgoing calls to the manual exchange MX particular levels of the primary selector PS lead to call indicator positions CIP, which can be readily traced, apparatus at the call indicator position being adapted to send back revertive impulses in a similar manner to the switches SR, R3 and R4 and its operation being controlled so as to display the number of the called party.

On another level of the primary selector PS, trunk lines lead to the step-by-step exchange SSX. These trunk lines are fitted with repeater translators RT which are represented in two parts, the upper part consisting of trunk relay equipment and the lower part consisting of the translating equipment which may be permanently associated with a particular trunk line, or may be provided in a group common to a group of trunk lines. On the other side of the repeater translator is an incoming second selector S2 of the standard type used in step-by-step exchanges having vertical and rotary motion. The repeater translator operates to send revertive impulses back to the register RG so that it functions in the same way as for a call over revertive control switches, and for each series of impulses received it sends out series of impulses corresponding exactly to the appropriate digits dialled by the calling party. The impulses cause the operation of selectors S2 and S3 and connector S4. Connector S4, however, is of special construction having two sets of wipers, one set of wipers being taken into use if the hundreds digit is odd, and the other set of wipers being taken into use if the hundreds digit is even, this arrangement of layout being employed so as to correspond to the revertive control register RG in which the hundreds digit according as to whether it is odd or even causes the final register to be operated in response to a number of steps less than ten, the number corresponding to the units digit, or a number of steps greater than ten, the number corresponding to the units digit with ten added.

A local call in a step-by-step exchange SSX is set up from a calling line, such as the line of substation A, over a line switch LS, a first selector SL1, a second selector SL2, a third selector SL3, and then either over a hundred line connector SL4 if the hundreds digit is even, or over a connector such as S4 if the hundreds digit is odd. The connector S4 in this case utilizes only one set of wipers.

For outgoing calls from a subscriber in the step-by-step exchange SSX to a subscriber in the revertive control exchange

RCX a connection is set up as follows: subscriber's instrument, line switch LS, selector SL1 and thence on a particular level (in this case the second level) through a trunk relay group D, having associated therewith a register controller RC to a trunk line leading to an incoming second selector R2 at the reverting control exchange RCX. The function of RC is to respond to step-by-step impulses and also to receive reverting control impulses from the switches successively taken into use by the reverting control exchange RCX and to effect the necessary translation according as to whether the hundreds digit is odd or even, and other modifications which will be understood hereinafter. The register controller having to register all the impulses consists of a considerable amount of equipment and would usually be arranged in a separate group common to a number of trunk lines. The call proceeds over the second selector R2, third selector R3 and final selector R4 to substation B.

In the case of calls to the manual exchange MX the trunk relay group DM and a register controller RCM are taken into use, both of which are identical in constructional details with the repeater D, and the register controller RC. By this means the call indicator equipment at the manual exchange MX may be made the same as for the call indicator equipment used for receiving calls from a reverting control exchange RCX. There is therefore no necessity for describing their operation in greater detail. Just as there are in the call indicator exchange reverting control impulses sent back for operating the register RG, so when a connection is set up to a call indicator position from a step-by-step exchange similar reverting control impulses will be sent back which would be identical with the reverting control impulses sent back from the reverting control switches R2, R3, R4.

In the case of special service calls a special level is allotted on the selector SL1 so that the calls are set up from a subscriber through his line switch LS, selector SL1, trunk relay group D2 with associated register controller trunk line leading to special second selector R7, which when operated connects with an operator's position OP. In the following description two different types of reverting control exchanges will be described. These reverting control exchanges differ more particularly in the releasing arrangements although they also differ in circuit details, so that it has been found necessary to show their circuit in considerable detail. It should however be understood that all the apparatus shown in a reverting control exchange is of known type. In a manual exchange the "B" board employing key senders is arranged with register control equipment for operating reverting control switches only, and

consequently in the trunk line leading from the manual exchange to the step-by-step exchange a repeater translator such as RT is provided. Here again exactly the same equipment can be used, in fact in general it may be taken that as regards inter-operation with the step-by-step exchange the manual exchange is similar to a reverting control exchange.

It will be appreciated that when employing switches responsive to a non-decimal control, such as final selector switches having a capacity of 200 lines some form of translation is necessary. Assuming a final selector bank provided with ten horizontal rows of twenty contacts each it will be readily seen that by employing an impulse sender capable of generating twenty impulses it would be possible by a vertical and rotary selection to operate the switch under the direct control of the impulse sender to connect with any one of such contacts.

If, however, use is to be made of an impulse sender generating a maximum of ten impulses, additional control is necessary to perform the units selection and this has been obtained when using reverting impulse control by arranging that the number dialled is recorded on a register. The numerical setting of the switches is controlled by impulses which are sent back to the register from the switch being controlled and the selection is terminated when the number of reverting impulses corresponds in number to the complement with respect to 11 of the number registered. When connection is required with a subscriber connected to the second half of the bank, additional impulses are arranged to be sent back before the control circuit is opened, this correction is determined by the value of some previous digit prior to the tens digit.

In order to facilitate the description a specific example of a numbering scheme will be given and this will be taken as a telephone network of between 20,000 and 100,000 lines in which connections are set up by the dialling of five-digit numbers.

It will be assumed that the subscribers are provided with impulse senders of the dial type capable of generating up to ten impulses, the number of impulses generated being equal to the number of the digit dialled by the subscriber. To set a connection three selector switches each having access to ten groups of 20 lines leading to the next rank of switches and a final selector (having access to 200 lines) will be required. The numbers dialled will range from 00,000 to 99,999; and only the odd levels of the first selectors are equipped, and in the case of incoming second selectors, such as R2, also the odd levels only are equipped. In the example considered, it is assumed that a call has been set up from a subscriber in one reverting control exchange

to subscriber B in exchange RCX, Fig. 25, having a number 26248. The connection can be traced in Fig. 6, the bank wiring of the first selector at the distant exchange and the 5 selectors R2 and R3 being numerically illustrated and the arrangement of the bank contacts of the final selector R4 is also numerically illustrated.

Revertive impulses, as is well known, are sent back from the selector switches by the 10 rotary movement of a spindle which determines which of a number of brushes is to be tripped, such spindle generally being referred to as a trip spindle, and in the example given the number of impulses sent back is equal to the number of the level (LN, Fig. 6) over which the set of brushes to be released by the trip spindle will sweep.

In the case of the final selector switch, 20 two sets of impulses are sent back, the first set corresponds to the level selected as in the case of the selector switches and consists of up to ten impulses, while the second set, which is sent back by the rotation of the 25 brush carriage, corresponds to the units digit and may consist of up to twenty impulses. The first set of impulses sent back by the final selector switch to select the proper level of contacts requires no modification for it is 30 obvious that if all the subscribers having the same tens digit in the 200 group selected, lie in the same level, then that particular level must be selected to connect with subscribers having that tens digit regardless of the other 35 digits of the number.

In the example given, the level of any tens digit is the complement of that digit with respect to 11 e. g. numbers having a tens digit of 7 will be found in the fourth level 40 of the final selector switch. The general operation of the switch is to send back to the register impulses, the number of which is the complement to 11 of the number of the digit in question registered thereon, whereupon 45 the control circuit is opened and the switch movement is stopped. Consequently, in the case of the tens digit being 7, seven impulses are transmitted by the subscriber and registered on the register, the trip spindle of the 50 final selector switch will require to send back four impulses before the control circuit is opened and to do this it will take four steps and select the fourth level of contacts in which numbers having a tens digit of 55 seven will be found.

In the case of the units digit the same reasoning applies to the example given, in which the brushes move from left to right over the units digit 0, 9, 8 . . . 2, 1, in succession. The 60 numbers in the even hundred are shown on the left and in this case the revertive impulses are the same as for the tens digit, for numbers in the odd hundred however, the brushes must in each case take ten extra steps 65 and in order that they may be allowed to do

so arrangements are made in the register so that ten extra revertive impulses are required to be sent back before the control circuit is opened.

The number of revertive impulses required for each digit is given in the following 70 table:

Number of impulses returned by switch

Number dialled	10,000 digit	2nd sel.		3rd sel.		Final selector		75
		1,000 digit		100 digit		Units digit		
		10,000 digit even	10,000 digit odd, or incoming 2nd sel.	1,000 digit even	1,000 digit odd	Tens digit	100 digit even	100 digit odd
1	9	10	9	10	9	10	10	20
2	7	8	7	8	7	9	9	19
3	7	8	7	8	7	8	8	18
4	5	6	5	6	5	7	7	17
5	5	6	5	6	5	6	6	16
6	3	4	3	4	3	5	5	15
7	3	4	3	4	3	4	4	14
8	1	2	1	2	1	3	3	13
9	1	2	1	2	1	2	2	12
0	9	10	9	10	9	1	1	11

The arrangement for selector switches is somewhat different since the hunting movement takes place over twenty contacts so that any given selector switch may have access from its banks to two hundred switches and in this connection it will be easier first to consider the first selector switch. If the system is equipped for 100,000 lines each of such switches could have access to subscribers with numbers ranging from 00,000 to 99,999 the odd levels only of the first selectors being equipped. In the example shown, the calling subscriber in connecting with subscriber No. 26248 has connected with the seventh level which has access to subscribers 20,000-39,999. In the case of local calls this group of subscribers is divided into ten groups, one for each level, but may be considered as being first divided into five groups depending on the thousands digit viz. 0000-1999, levels 10 and 9: 2000-3999, levels 8 and 7: 4000-5999, levels 6 and 5: 6000-7999: levels 4 and 3: 8000-9999, levels 2 and 1: and these groups are then each divided into two sub-groups depending upon whether the ten thousands digit is odd or even e. g. the group 26,000-27,999 is allotted to the even level (4) and the group 36,000-37,999 is allotted to the odd level (3). In general, the digit preceding the one by which the selector is named, if even, determines that its sub-group shall be allotted to the even level and, if odd, determine that its sub-group shall be allotted to the odd level.

In the example shown, however, the dialling of 2 as the first digit determines an inter-exchange connection, the inter-exchange trunks then terminates at an incoming second selector such as R2 in which only the odd levels are equipped, the revertive impulses

from this selector do not then follow the above rule but since the even ten thousand have been placed in the odd levels, the revertive impulses correspond to those given 5 in the table for an odd ten thousands digit.

The dialling of the second digit (6) then effects the selection of the third level of the switch R2.

The dialling of the third digit (2) is required to effect the selection of the eighth level of the switch R3 whereas if the thousands digit has been odd the dialling of the third digit (2) would require the selection of the seventh level. From a consideration of 10 Fig. 6, it will be seen that if the ten-thousands digit is even, the thousands digit 0 and 1 require the 9th level to be selected; digits 2 and 3 the seventh level, digits 4 and 5 the fifth level; digits 6 and 7, the third level; and 15 digits 8 and 9 the first level: the number of revertive impulses being numerically equal to the level selected; and that if the ten-thousands digit is even an extra revertive impulse is required in each case.

20 It will be noted in the case of selector R3 that the sum of the number of impulses generated by the calling subscriber and the number generated by the switch may be either 9, 10 or 11 and it will be shown subsequently 25 how this is dealt with. If the thousands digit is even and the hundreds digit is even, the sum is 10, if the thousands digit is odd and the hundreds digit is odd, the sum is also 10; if the thousands digit is odd and the hundreds 30 digit is even, the sum is 9 and if the thousands digit is even and the hundreds is odd the sum is 11.

A description will now be given of the detailed operation of the system with respect to 40 the setting up of a call between a subscriber at sub-station A in the step-by-step exchange and a subscriber at sub-station B in the revertive control exchange whose number we will assume to be 26248. The subscriber A initiates the call by lifting his receiver off the 45 switch hook whereby a loop is closed across the line conductors 111 and 112, and a circuit is completed for line relay 101 of the plunger type line-switch C as follows: earth, contact 128, conductor 111, subscriber's instrument at 50 sub-station A, conductor 112, contact 127, relay 101, to battery. Relay 101 operates, and at contact 122 completes a circuit as follows: earth, contact 122, upper winding of plunger 55 magnet 102, open main conductor 610, contact 608, to battery. When the upper or pull-down winding of the plunger magnet energizes it attracts its bridge cut-off armature 131, which disconnects the line relay from the 60 line, this relay, however, is slow to release and holds the circuit of the pull-down winding closed at contact 122 for a short period. Following the operation of the quick acting bridge cut-off armature the pull-down winding 65 more slowly attracts the plunger arm 130

to connect together the pairs of bank springs opposite which it is aligned when the call is initiated such as the pairs of bank springs 123, 124, 125 and 624. Connection is thereby established with an idle trunk line such as 70 the one comprising conductors 153, 154 and 155 connected to the step-by-step selector S1.

By the closure of bank springs 123 and 125, line conductors 111 and 112 are connected with conductors 155 and 153 respectively, and by the closure of bank springs 124 the private 75 normal conductor 129 extending to the banks of the connector switches is connected to conductor 154 of the first selector S1.

The line relay 103 then operates in the following circuit: battery, upper winding of 80 relay 103, contact 144, conductor 153, bank springs 123, subscriber's loop, bank springs 125, conductor 155, contact 151, lower winding of relay 103 to earth. Relay 103 operates 85 and at contact 133 closes a circuit for the release relay 104 as follows: earth, contact 149, contact 133, relay 104 to battery. Relay 104 energizes and places earth on the release trunk conductor 154 at contact 135, this earth serves 90 to maintain magnet 102 operated over its lower or bridge cut-off winding after relay 101 falls back. Relay 104 also closes contact 136 to prepare a circuit for relay 105 and the vertical magnet 108 in series.

95 By the closure of bank springs 624 earth is placed upon conductor 611 which is connected to contact 623 of the master switch bank upon which wiper 604 is resting and which corresponds to the tenth trunk accessible to the master switch M. A circuit is thereby closed for lock magnet 602 which thereupon operates to withdraw the lock lever 615 and to close contact 607. At contact 607 a 100 circuit is closed for open main relay 603 which operates and at contact 608 removes battery from the open main conductor 610. The removal of battery from conductor 610 prevents the operation at this time of any of the line switches controlled by the master switch M. 110 By the operation of lock lever 615, the roller 617 is removed from the notch in the sector 614, in which it is resting, thereby allowing the sector 614 to rotate together with the guide shaft 619 which controls the idle plungers, under the control of the U-shaped spring 618 and the governor 616. The plungers of the associated idle line switches are thereby moved opposite the next set of contacts, wiper 604 being also moved simultaneously onto the next contact 620 of the master switch bank. If earth is encountered on contact 620, the 115 circuit of lock magnet 602 remains closed, and the rotation of the guide shaft 619 continues. When wiper 604 reaches a contact which is not earthed the circuit of magnet 602 is opened, lock lever 615 is released and roller 617 immediately falls into a notch in the sector and the idle plungers are held 120 aligned opposite the idle trunk corresponding 125 130

to the contact selected by wiper 604. The circuit of open main relay 603 is opened at contact 607 and battery is again connected to the open main conductor 610 and any one of the associated idle line switches may then be operated to seize the selected trunk.

If the idle plungers have been aligned opposite the contacts corresponding to the first trunk, wiper 604 will be resting on contact 621 of the master switch bank, and finger 612 will be in contact with spring 624 but contact 609 will not be closed. If this trunk is then taken into use magnet 602 operates as before and allows the spring 618 to rotate the guide shaft still further, sufficient to allow the finger 612 to close contact 609 and thereby complete a circuit for relay 609. Relay 601 then operates, and closes contacts 605 and 606; spring 622 is caught by the latch on spring 624 and contacts 605 and 606 are held closed; contact 605 closes a holding circuit for trip relay 601 as follows: earth, contact 605, contact 609, relay 601 to battery. At contact 606 a circuit is closed for the solenoid magnet 600, which is then energized and attracts its plunger and by means of the arm 623 rotates the guide shaft until it is aligned opposite the first trunk and wiper 604 is again resting on contact 623. During the return motion idle plungers which have been released since the guide shaft last passed the position in which they were taken into use are gathered up and aligned opposite the set of contacts corresponding to the tenth trunk. Relay 602 is held operated during the return motion of the sector 614, by earth connected over contact 605 and in turn maintains the open main relay 603 operated at contact 607. When the plungers have been aligned opposite the set of contacts corresponding to the tenth trunk, finger 613 comes into contact with spring 624 to open contact 609 and unlatch spring 622, the circuit of relay 601 is thereby opened and this relay releases and opens contacts 605 and 606. Lock magnet 602 and open main relay 603 thereupon restore to normal, and the line switches controlled by the master switch M are again in readiness to be operated by calling subscribers.

The subscriber then operates his impulse sender to send out a number of impulses corresponding to the first digit (2) of the wanted subscriber's number, relay 103 falls back on each interruption of the loop circuit and closes a circuit as follows: earth, contact 149, contact 134, contact 136, winding of relay 105, winding of vertical magnet 108 to battery. Vertical magnet 108 operates to raise the wipers 156, 157 and 158 opposite the second level of bank contacts; relay 105 operates on the first impulse to close contact 139 and since it is slow to release holds this contact closed during the rest of the impulse series. On the first step of the vertical mag-

net the off-normal contacts 138 and 148 are closed, contact 138 prepares the circuit of the release magnet 109 and contact 148 closes a circuit for relay 106 as follows:—earth, contact 135, contact 139, off-normal contact 148, interrupter contact 143, winding of relay 106 to battery. Relay 106 operates and at contact 141 short-circuits relay 107 by connecting earth to the lower terminal of its winding, at contact 142 a circuit is prepared for the rotary magnet 110 and at the end of the series of impulses, when relay 105 falls back to close contact 140, this circuit is completed as follows: earth, contact 135, contact 140, contact 142, winding of magnet 110 to battery.

Rotary magnet 110 operates and opens its interrupter contact 143 thus opening the circuit of relay 106, which releases and at contact 142 opens the circuit of the rotary magnet which then releases and steps the wipers 156, 157 and 158 onto the first set of contacts in the selected level. If the first set of contacts are connected to a busy trunk line, wiper 157 will encounter earth and relay 106 will operate in the following circuit: earth, wiper 157, contact 146, off-normal contact 148, interrupter contact 143, winding of relay 106 to battery, when relay 106 operates it again closes the circuit of the rotary magnet at contact 142. The rotary magnet thereupon operates to open the circuit of relay 106 and then releases to step the wipers 156, 157 and 158 onto the next set of contacts as previously described. The interaction between relay 106 and magnet 110 continues in this manner until wiper 157 encounters an unearthing contact whereupon the short circuit is removed from relay 107 and this relay operates in series with relay 106 in a circuit extending as follows:—earth, contact 135, relay 107, off-normal contact 148, contact 143, winding of relay 106 to battery. Relay 106 however owing to its relatively low resistance does not operate in this circuit. Relay 107 opens contacts 144 and 151 thereby disconnecting the line relay 103 and at contact 149 holds open a point in the circuit of the release magnet 109. Relay 103 releases and opens the circuit of relay 104 which also releases after a short interval. Relay 107 also opens contact 146, and relay 106 is thereby disconnected from the test wiper 157, and at contact 147 the release trunk conductor 114 of the seized line is connected to that of selector S1; earth is received back from the succeeding switch before relay 104 releases, so as to maintain relay 107 operated. At contacts 145 and 150 the subscriber's loop is extended forwards to the seized trunk line which will be assumed to be that comprising conductors 113, 114 and 115 and leading to repeater D shown in Fig. 2. The line relay 162 in the repeater D operates in the following circuit:—battery, upper winding of relay 162, contact 173, conductor 113, wiper 150

156, contact 145, subscriber's loop, contact 150, wiper 158, conductor 115, contact 175, lower winding of relay 162 to earth; and at contact 178 closes a circuit for relay 163 which operates and closes contacts 180, 181 and 182. At contact 180 earth is fed back to the preceding switches over the release trunk conductor 114 to hold relay 107 and the bridge cut-off winding of magnet 102 energized, at contact 181 the impulse lead 199 over which the series of impulses dialled by the calling subscriber are to be sent to the register is connected to contact 179 and at contact 182 a circuit is completed for the pull-down winding of plunger magnet 204 of the plunger type line switch E, Fig. 3, as follows:—earth, contact 180, low resistance upper winding of relay 165, contact 182, contact 187, contact 196, conductor 171, pull-down winding of magnet 204, contact 152, open main conductor, contact 126 to battery. The current through the low resistance upper winding of relay 165 is insufficient to cause its operation. Magnet 204 immediately attracts its bridge cut-off armature and the circuit of magnet 204 then extends from conductor 171, pull-down winding of magnet 204, contact 200, bridge cut-off winding of magnet 204 to battery. Magnet 204 is held operated over this circuit independently of the potential applied to the open main conductor. Magnet 204 then attracts its plunger arm and closes the corresponding pairs of bank springs opposite which it is aligned, such as the pairs of bank springs 250, 251, 252 and 253; conductors 170, 171, 172 and 199 are thereby extended to an idle register which will be assumed to be the register shown in Figs. 3, 4 and 5. The remainder of the circuit of the plunger type line switch is similar to that shown in Fig. 1, and includes the master switch wiper 254 and its associated bank contacts, the open main relay 203, the lock magnet 202 which releases the guide shaft to permit the idle plungers to be placed opposite the next idle trunk, and the trip relay 201 which is operated when the plungers are moved past the first set of contacts and when operated closes a circuit for the solenoid magnet which aligns the idle plungers opposite the tenth set of contacts. Earth on conductor 171 extends into the register controller over bank springs 253 and causes relay 209 to operate. When relay 209 operates it closes contact 282 over which contact certain relays are subsequently locked energized as will be described later. At contact 281, conductor 231 is connected to a time pulse lead, that is, a lead to which earth is momentarily connected at regular periods, say 30 seconds.

The subscriber then operates his impulse sender to send out a number of impulses (six) corresponding to the second digit of the number of the wanted subscriber. On each in-

terruption of the subscriber's loop, relay 162 falls back and at contact 179 sends an impulse to the register over the following circuit:—earth, contact 179, contact 181, conductor 199, bank springs 252, contact 260, winding of relay 218 to battery. Relay 218 operates on the first impulse and at contact 273 closes a circuit for relay 219. Relay 219 operates and is maintained energized during the series of impulses owing to its slow-to-release feature. Relay 219 in turn closes a circuit at contact 276 for relay 220 which also remains energized during the series of impulses and connects earth at contact 279 to conductor 235 to control the operation of the input control relays 401, 402, 403 and 404 the circuit now extending over contacts 442, 436, 427 and 417 to the upper winding of relay 401 which operates partially to close contact 419 only, thereby connecting its lower winding to earth over conductor 232 and contact 282. This winding is however short circuited as long as earth is connected to its upper terminal over conductor 235.

At contact 272, relay 218 connects earth to conductor 234 and an impulsing circuit to the counting relay sets is closed which now extends to the first relay of the first counting set, i. e. the counting set for the thousands digit, as follows:—battery, upper winding of relay 211, contact 288, contact 293, contact 298, contact 303, contact 310, conductor 242, contact 421, contact 431, contact 440, contact 444 conductor 234 to the impulsing contact 272. Relay 211 operates partially to close contact 290 only.

The complete operation of the thousands register comprising the chain of counting relays 211-215, inclusive, will now be considered. On the first impulse relay 211 operates partially to close contact 290, only, thus short-circuiting its lower winding, and at the end of the impulse the short circuit is removed from its lower winding and the relay operates fully over the following circuit: battery, upper and lower windings of relay 211 in series, contact 290, contact 315, contact 297, contact 309, contact 301, contact 307, contact 314, holding conductor 244, contact 367, conductor 240, contact 450, conductor 232, contact 282 to earth. Relay 211 thereupon closes contact 289 and the impulse conductor 242 is extended to the upper winding of relay 212.

On the second impulse a circuit is closed for the upper winding of relay 212 which operates partially to close contact 296 only. At the end of the impulse, relay 212 operates fully, and closes a locking circuit for itself as follows:—battery, upper and lower windings of relay 212 in series, contact 296, contact 309, contact 301, contact 307, contact 314, holding conductor 244 and thence to earth, over the circuit previously described. Relay 212, upon operating, opens the locking cir-

cuit of relay 211 at contact 297, so that relay 211 de-energizes and closes contact 294, impulse conductor is extended to the upper winding of relay 213.

5. On the third impulse relay 213 operates partially to close contact 300 only and at the end of the third impulse operates fully in the following circuit: battery, upper and lower windings of relay 213 in series, contact 300, 70 contact 307, contact 314, holding conductor 244, to earth. Upon operating, relay 213 opens contact 301, thereby opening the locking circuit of relay 212, which de-energizes and also connects the impulse conductor to 75 contact 299.
10. On the fourth impulse, relay 214 operates partially to close contact 305 only, and at the end of the impulse operates fully in the 80 following circuit: battery, upper and lower windings of relay 214 in series, contact 305, contact 314, holding conductor 244 to earth. At contact 307, relay 214 opens the locking circuit of relay 213 which de-energizes and 85 contact 304 connects the impulse conductor to the upper winding of relay 215.

20. On the fifth impulse, relay 215 operates partially to close contact 312 only, and at the end of the impulse operates completely 90 and locks directly on to conductor 244. At contact 314, relay 215 opens the locking circuit of relay 214 which de-energizes, and at contact 311 connects the impulse lead to the upper winding of relay 211. Relay 215 also 95 closes contact 313 to provide a direct locking circuit for relay 211 when that relay is again operated.

30. On the sixth impulse, relay 211 operates partially to close contact 290 only, and at the end of the impulse it operates fully and remains locked to conductor 244, relay 211 100 also closes contact 289 and connects the impulse conductor to the upper winding of relay 212.

40. On the seventh impulse, relay 212 operates partially to close contact 296 only and at the end of the impulse operates fully over a circuit extending as follows: battery, upper and lower windings of relay 212 in series, 105 contact 296, contact 309, contact 301, contact 307, contact 291; at contact 294 relay 212 extends the impulse lead to the upper winding of relay 213.

50. On the eighth impulse, relay 213 operates partially to close contact 300 only, and at the end of the impulse operates fully in the following circuit: battery, upper and lower windings of relay 213 in series, contact 300, contact 307, contact 291, holding conductor 110 244 to earth. Relay 213 opens contact 301 thereby opening the locking circuit of relay 212 which de-energizes and closes contact 299 thereby extending the impulse conductor to the upper winding of relay 214.
60. On the ninth impulse, relay 214 operates 115

partially to close contact 305 only and at the end of the impulse operates fully over a circuit extending as follows:—battery, upper and lower windings of relay 214 in series, contact 305, contact 291, holding conductor 244 to earth. At contact 307, relay 214 opens the locking circuit of relay 213, which de-energizes and at contact 298 connects the impulse conductor to the upper winding of relay 212.

70. On the tenth impulse, relay 212 operates partially to close contact 296 only, and at the end of the impulse operates fully over a circuit which extends as follows:—battery, upper and lower windings of relay 212 in series, contact 296, contact 308, holding conductor 244 to earth. Relay 212 closes contact 294 and extends the impulse conductor to the upper winding of relay 213 in readiness for the eleventh impulse, this will be received back from the switch controlled by this register but will be described now in order to complete the description of the operation of the register.

75. On the eleventh impulse, relay 213 operates partially to close contact 300 only, and at the end of the impulse operates fully over the following circuit: battery, upper and lower windings of relay 213 in series, contact 300, contact 295, contact 306, contact 291, holding conductor 244 to earth. The operation of the counting relays is shown diagrammatically in Fig. 11 which shows which relays are locked operated at the end of each impulse. In the example being described the second digit is six and consequently at the end of the sixth impulse relays 211 and 215 will be locked operated.

80. Shortly after the end of the series of impulses relay 219 releases and contacts 275, 277 and 278 close. At contact 276 relay 219 opens the circuit of relay 220 which after a 105 contacts 279 and 280. When relay 220 opens short intervals also releases and opens contact 279, earth is removed from conductor 235 and relay 401, which partially operated at the beginning of the series of impulses, operates completely in the following circuit:—battery, upper and lower windings of relay 401 in series, contact 419, conductor 232, contact 282, to earth. At contact 418, relay 401 110 transfers conductor 235 to the upper winding of relay 402 in readiness for the next series of impulses.

85. The trunk line comprising conductors 168 and 169 and terminating at the retractive control exchange in an incoming second selector such as the selector R2 shown in Fig. 7 was taken into use by the operation of the selector S1. When the register controller was seized 120 by the line switch E the trunk line was extended to the register controller over bank contacts 250 and 251 but remains ineffective until the thousands digit has been registered and relay 401 has operated to close contact 125 130

415. Relay 401, upon operating, completes a circuit extending to the incoming second selector R2, (Fig. 7) as follows:—earth, contacts N3 and N2 in position 1 of sequence switch SS2, winding of retard 502, high resistance upper winding of relay 503, in series with its low resistance lower winding, contacts J3 and J2 in position 1 of sequence switch SS2, conductor 169, contact 198, conductor 170, bank springs 251, contact 265, conductor 222, contact 485, conductor 223, contact 263, conductor 227, contact 416, conductor 225, winding of relay 206, bank springs 250, conductor 172, contact 190, conductor 168, contacts M1 and M2 in position 1 of sequence switch SS2, relay 505 to battery.

Relay 503 of the selector R2 alone operates in this circuit, relays 505 and 206 being of comparatively low resistance do not operate; 20 relay 503 closes contact 517 which completes a circuit as follows: earth, contact 517, contacts C1 and C2 in position 1 of sequence switch SS2, winding of magnet 510 to battery. Magnet 510 energizes and the sequence switch SS2 advances into position 2.

When the sequence switch moves out of position 1 the circuit of relay 503 is opened at contacts M2 and M3 and relay 503 de-energizes. When sequence switch SS2 reaches position 2 the fundamental circuit is closed as follows:—earth, contacts L2 and L1 in position 2 of sequence switch SS2, conductor 168, contact 190, conductor 172, bank springs 250, relay 206, conductor 225, contact 416, conductor 227, contact 263, conductor 223, contact 485, conductor 222, contact 265, bank springs 251, conductor 170, contact 198, conductor 169, contacts J2 and J1 in position 2 of sequence switch SS2, winding of relay 505 to battery. Relays 206 and 505 operate in this circuit and at contact 519 a circuit is completed for magnet 508 as follows: battery, winding of magnet 508, contacts G1 and G2 in position 2 of sequence switch SS2, contact 519 to earth. Magnet 508 energizes and causes the trip spindle to rotate, and cause the interrupter 513 to close off-normal contact 525 and contact 524 intermittently to send back impulses to the register controller.

Returning now to the operation of relay 206 in the register controller, when this relay operates a circuit is completed as follows:—earth, contact 257, conductor 224, contact 460, contact 454, contact 446, conductor 242 to the thousands register comprising relays 211-215 inclusive. Now it will be recollected that these relays have responded to six impulses dialled by the calling subscriber so that relays 211 and 215 remain energized. Therefore, a circuit is now completed for the upper winding of relay 212 as follows:—earth on conductor 242, contact 311, contact 298, contact 293, contact 289, upper winding of relay 212 to battery. Relay 212 operates partially

to close contact 296 only, thereby short circuiting its lower winding.

Referring now to Fig. 7, contact 524 is closed on each step taken by the trip spindle and earth is connected up intermittently in the following circuit:—earth, contact 525, contact 524, contacts H1 and H3 in position 2 of sequence switch SS2, contacts J1 and J2 in position 2 of sequence switch SS2, conductor 169, and thence over the previously traced circuit over conductors 222 and 225 to the lower terminal of relay 206; relay 206 is intermittently short circuited and relay 505 is held energized. Relay 206 therefore releases on each step taken by the trip spindle. At the end of the first impulse, relay 212 operates fully and the operation of the thousands register continues as previously described until relays 211, 214 and 215 are operated, whereupon a circuit is completed as follows:—battery, winding of relay 208, conductor 229, contact 451, lower winding of relay 405, contact 423, contact 422, conductor 239, contact 283, contact 287, contact 302, contact 316, conductor 240, contact 450, conductor 232, contact 282 to earth. Relay 208 operates and opens the fundamental circuit at contact 263. Referring to the impulse table it will be seen that since the thousands digit dialled was 6, three revertive impulses must be returned by the selector R2, in order that the correct row of bank contacts may be selected, hence relay 206 must release three times before the rotation of the trip spindle is arrested. Referring to Fig. 11 it will be seen that after six impulses have been registered by the calling subscriber and a further three have been registered by the operation of selector R2, relays 211, 214 and 215 will be operated which is the condition required for the operation of relay 207 and the consequential opening of the fundamental circuit.

After the fundamental circuit has been opened by the operation of relay 208, relay 206 remains de-energized and relay 505 in the selector R2 releases and at contact 520 a circuit is completed as follows:—earth, contact 520, contacts B1, B2 in position 2 of sequence switch SS2, winding of magnet 510 to battery. Magnet 510 energizes and sequence switch SS2 advances into position 3. In this position, relay 505 is operated in the following circuit: battery, winding of relay 505, contacts H1 and H2 in position 3 of sequence switch SS2, off-normal contact 525 to earth; and opens contact 520 to allow the sequence switch SS2 to stop in position 3. In position 3 of sequence switch SS2 a circuit is closed for the brush carriage magnet 509 as follows: battery, winding of magnet 509, contacts D3 and D2 in position 3 of sequence switch SS2, contact 523 to earth. The brush carriage is thereby set in motion, and the set of brushes corresponding to the

level selected are released and moved over their associated bank contacts. The brushes continue rotating until a trunk line leading to an idle third selector is encountered, such as that comprising conductors 528, 531 and 534 and leading to selector R3.

When this happens a circuit is completed as follows:—earth, high resistance lower winding of relay 506, contacts F3 and F2 in

10 position 3 of sequence switch SS2, brush 532, bank contact 533, conductor 534, contacts L4 and L3 in position 1 of sequence switch SS3, contacts K2 and K3 in position 1 of sequence switch SS3, winding of relay 702 to battery.

15 Relay 702 operates in this circuit and closes contact 711 to make itself independent of contacts L4 and L3. Relay 506 also operates and closes contact 521 thereby completing a circuit for relay 507 as follows: earth, winding of

20 low resistance relay 507, contact 521, low resistance upper winding of relay 506, wiper 532, bank contact 533, conductor 534, contact 711, contacts K2 and K3 in position 1 of sequence switch SS3, winding of relay 702

25 to battery. Relay 506 is however short-circuited by earth connected to brush 513 over a tooth of the rack 512 until the brushes are properly aligned with respect to the selected bank contacts. When the brushes are cor-

30 rectly aligned the short circuit is removed and relays 506 and 507 operate. Relay 507 operates and opens the circuit of the brush carriage magnet 509 at contact 523, and at contact 502 completes a circuit for the hold-

35 ing magnet 511 as follows:—earth, contact 522, contacts C3 and C2 in position 3 of sequence switch SS2, contacts E3 and E2 in position 3 of sequence switch SS2, winding of magnet 511 to battery; magnet 511 en-

40 ergizes and brings the brush carriage to rest. A parallel circuit is also closed over contacts C3 and C2 for magnet 510, magnet 510 en-

45 ergizes and the sequence switch SS2 leaves position 3. It will be noted that from the time that sequence switch SS2 passes into position 3 conductors 168, 169 are bridged by retard 502 and relay 503 in the following circuit:—conductor 168, contacts N1 and N2 in positions 3 to 5½, of sequence switch SS2,

50 winding of retard 502, high resistance upper winding and low resistance lower winding of relay 503 in series, contacts J3 and J2 in positions 3 to 5½ of sequence switch SS2, to conductor 169.

55 Referring back to the operation of relay 208, it will be noted that immediately after contact 263 was opened, sequence switch SS3 passed into position 3, and accordingly retard 502 and relay 503 were at once bridged

60 across the conductors 169 and 168 so that a circuit was completed for relay 205 as follows:—earth, winding of relay 205, contact 258, bank springs 250, conductor 172, contact 190, conductor 168, contacts N1 and N2 in

65 position 3 of sequence switch SS2, winding

of retard 502, upper and lower windings of relay 503 in series, contacts J3 and J2 in position 3 of sequence switch SS2, conductor 169, contact 198, conductor 170, bank springs 251, contact 265, conductor 222, contact 485, conductor 223, contact 262, resistance 255 to battery. Relay 205 energizes in this circuit sufficiently quickly to hold relay 208 operated over contacts 256 and 264 before the original energizing circuit of relay 208 has been opened by the energization of relay 405.

70 It will be recollect that relay 405 was energized through its lower winding in circuit with relay 208 but in this circuit relay 405 energizes only partially and closes contact 448, thereby completing a circuit for its upper winding over conductor 232, contact 282 to earth, which causes it to operate fully. Relay 405 upon completely operating disconnects earth from the holding conductor 244 at contact 450 and relays 211, 214 and 215 de-energize.

75 As the energization of relay 205 takes place rapidly, and relay 405 is arranged to be slow to pull up, relay 405 will not open contact 451 in the initial energizing circuit of relay 208 until after contact 256 of relay 205 is closed. When relay 405 has completely operated, a second locking circuit for relay 208 is closed as follows:—battery, winding of relay 208, contact 264, conductor 230, contact 432, contact 449, conductor 232, contact 282 to earth. This locking circuit is effective only if the circuit of relay 205 is opened due to an idle selector such as R3 being found before relay 402 has energized due to the reception of the third series of impulses. This is to prevent the selector R3 starting to send back reverte impulses until the series of impulses from the calling subscriber which should control 100 its operation has been registered.

80 The previously described circuit for magnet 510 is maintained over contacts C2 and C3 of sequence switch SS2 until the sequence switch leaves position 5, magnet 510 is then maintained energized over contacts A1 and A2 of sequence switch SS2 until position 6 is reached, and in this position the sequence switch stops. In this position the speaking 105 conductors 168 and 169 are extended to selector R3, conductor 168 being connected over contacts O1 and O2 in position 6 of sequence switch SS2, brush 526, bank contact 527 to conductor 528, and conductor 169 being connected over contacts K3 and K2 in position 110

6 of sequence switch SS2, brush 529, bank contact 530 to conductor 531; while at the same time the bridge including retard 502 and relay 503 is opened. Relay 205 in the 115 register controller is now short-circuited by earth connected to its upper terminal over the following circuit: earth, contacts M1 and M2 in position 1 of sequence switch SS3, conductor 528, bank contact 527, brush 526, contacts O2 and O1 in position 6 of sequence 120

125 conductors 168 and 169 being connected over contacts K3 and K2 in position 6 of sequence switch SS2, brush 529, bank contact 530 to conductor 531; while at the same time the bridge including retard 502 and relay 503 is opened. Relay 205 in the 130 register controller is now short-circuited by earth connected to its upper terminal over the following circuit: earth, contacts M1 and M2 in position 1 of sequence switch SS3, conductor 528, bank contact 527, brush 526, contacts O2 and O1 in position 6 of sequence

switch SS2, conductor 168, contact 190, conductor 172, bank springs 250, contact 258, to the upper terminal of relay 205. This relay accordingly de-energizes and opens contact 256, thereby opening one of the locking circuits of relay 208.

Relay 208 however is maintained operated until the third series of impulses has been received by the hundreds register. The 10 third series of impulses corresponding to the hundreds digit, the transmission of which may take place concurrently with the above described operation of selector R2, are repeated in the same way as the thousands 15 series of impulses, namely, by contact 179 of line relay 162 and contact 272 of relay 218. The impulse circuit over conductor 234 now extends as follows: earth, contact 272, conductor 234, contact 444, contact 440, contact 20 431, contact 420, conductor 352 to relays 321-325 inclusive. The holding conductor for these relays is conductor 353 which extends to earth over the following circuit:—conductor 25 353, contact 491, contact 458, conductor 232, conductor 282, to earth. These relays are arranged in a similar manner to relays 211-215 inclusive, and the circuit description given in connection with the operation of 30 relays 211 to 215 inclusive may be applied, with the necessary alterations.

As the third series consists of two impulses relay 322 will be held energized at the end of the series of impulses. The locking circuit for this set of relays may be traced to earth 35 as follows:—conductor 353, contact 491, contact 458, conductor 232, contact 282 to earth. Hence, if before the hundreds digit has been registered, relay 413 is energized (which occurs due to the subscriber delaying to dial for 40 an undue length of time) it becomes impossible for the subscriber to register the hundreds digit.

At the beginning of the series of impulses, when relay 220 operates a circuit is completed 45 as follows:—earth, contact 279, conductor 235, contact 442, contact 436, contact 427, contact 418, upper winding of relay 402 to battery. Relay 402 operates partially to close contact 429 only, and at the end of the series 50 of impulses when relay 220 releases, relay 402 operates completely in the following circuit: battery, upper and lower windings of relay 402 in series, contact 429, conductor 232, contact 282 to earth. Relay 402 upon operating 55 extends the impulse conductor 234 at contact 430 to conductor 358 which is connected to the tens register comprising relays 331-335 inclusive and also extends conductor 235 to relay 403 at contact 428. Relay 402 at the same 60 time closes contact 434 so as to render the holding circuit of relays 321-325, inclusive, independent of contact 491.

It will be remembered that relay 208 had a locking circuit extending as follows:—battery, winding of relay 208, contact 264, con-

ductor 230, contact 432, contact 449, conductor 232, contact 282 to earth. When relay 402 operates, the locking circuit of relay 208 is opened at contact 432, and this relay releases provided that the locking circuit extending over contact 256 has been removed by the release of relay 205, which takes place as previously described when an idle trunk has been found by the selector R2.

When both these conditions, namely, the 75 reception of the hundreds digit and the finding of an idle trunk by selector R2 are satisfied, relay 208 is released thus again closing the fundamental circuit which now extends as follows:—earth, contacts M1 and M2 in position 1 of sequence switch SS3, conductor 528, bank contact 527, brush 526, contacts O2 and O1 in position 6 of sequence switch SS2, conductor 168, contact 190, conductor 172, bank springs 250, winding of relay 206, conductor 225, contact 416, conductor 227, contact 263, conductor 223, contact 485, conductor 222, contact 265, bank springs 251, conductor 170, contact 198, conductor 169, contacts K3 and K2 of sequence switch SS2 in position 6, 80 brush 529, bank contact 530, conductor 531, contacts H1 and H4 of sequence switch SS3 in position 1, winding of relay 704 to battery.

Relay 704 operates and closes a circuit as 95 follows:—earth, contact 715, contacts B4 and B5 in position 1 of sequence switch SS3, winding of magnet 707 to battery. Magnet 707 energizes and the sequence switch SS3 advances into position 2. In position 2, a circuit is completed for the trip spindle magnet 100 705 as follows:—battery, winding of magnet 705, contacts C4 and C1 in position 2 of sequence switch SS3, contact 715 to earth.

The trip spindle and its interrupter 708 begin to rotate, when the interrupter moves 105 off-normal, contact 718 is closed and for every step taken by the trip spindle, contact 717 is also closed, and earth is thereby intermittently connected to conductor 531 by connecting earth to its lower terminal to short circuit 110 relay 206, as follows:—earth, contact 718, contact 717, contacts H2 and H1 in position 2 of sequence switch SS3, conductor 531, bank contact 530, brush 529, contacts K2 and K3 in position 6 of sequence switch SS2, conductor 169, contact 198, conductor 170, bank springs 251, contact 265, conductor 222, contact 485, conductor 223, contact 263, conductor 227, contact 416, conductor 225, lower terminal of relay 206. The upper terminal of 115 relay 206 is connected to earth over the following circuit: upper terminal of relay 206, bank springs 250, conductor 172, contact 190, conductor 168, contacts O1 and O2 in position 6 of sequence switch SS2, brush 526, bank contact 527, conductor 528, contacts M2 and M1 in position 1 of sequence switch SS3 to earth. The intermittent earth connected over contact 717 also extends to the upper 120 terminal of relay 704 over contact 714 and 125 130

maintains relay 704 energized during the motion of the trip spindle.

Relay 206 operates when the fundamental circuit is closed by the release of relay 208 and is short-circuited on each step taken by the trip spindle of selector R3, relay 203 intermittently de-energizes as before and impulses are sent to the hundreds relay set over a circuit which extends as follows:—earth, contact 257, conductor 224, contact 460, contact 454, contact 447, conductor 352, to the set of counting relays 321 to 325 inclusive. Consequently relays 321-325 are operated as indicated in Fig. 11 until the correct number 15 of retractive impulses have been received back, which by reference to the impulse table will be seen to be eight.

When the eighth retractive impulse has been received back from the selector R3 relays 20 321, 322, 324 and 325 will be locked operated and the following circuit is completed for relay 208:—battery, winding of relay 208, conductor 229, contact 459, lower winding of relay 406, contact 433, conductor 246, contact 286, conductor 247, contact 363, contact 375, contact 378, contact 374, contact 379, conductor 350, contact 458, conductor 232, contact 282 to earth.

Relay 208 operates and relay 406 operates 25 partially to close contact 456 only, which completes a circuit for its upper winding, whereupon after a short interval the relay operates fully. This circuit is similar to the circuit in which relay 208 and relay 405 operated and the subsequent operation is similar since relay 406 is similar to relay 405. Relay 406 upon completely operating disconnects earth from the holding conductor 353 at contact 458 and relays 321, 322, 323 and 40 324 de-energize.

Relay 208 upon operating opens the fundamental circuit at contact 263, relay 704 in the selector R3 releases, and relay 206 remains de-energized.

At contact 716 relay 704 completes a circuit as follows:—earth, contact 716, contacts B3 and B5 in position 2 of sequence switch SS3, winding of magnet 707 to battery. Magnet 707 energizes and the sequence switch 50 SS2 leaves position 2.

When the sequence switch reaches position 3 a circuit is closed as follows:—earth, relay 205, contact 258, bank springs 250, conductor 172, contact 190, conductor 168, contacts O1 and O2 in position 6 of sequence switch SS2, brush 526, bank contact 527, conductor 528, contacts M2 and M3 in position 3 of sequence switch SS3, winding of relay 701, contacts H3 and H1 in position 3 of sequence switch SS3, conductor 531, bank contact 530, brush 529, contacts K2 and K3 in position 6 of sequence switch SS2, conductor 169, contact 198, conductor 170, bank springs 251, contact 235, conductor 222, contact 485, conductor 223, contact 262, resistance 255 to battery. Re-

lay 205 accordingly energizes in this circuit as well as relay 701, relay 205 operates as before to hold relay 208 energized independently of the contacts of relay 406. Relay 208 has a second locking circuit extending as follows:—battery, winding of relay 208, contact 264, conductor 230, contact 441, contact 457, conductor 232, contact 282 to earth; this circuit is completed when relay 406 has fully energized which it does shortly after the energization of relay 205.

Relay 701 closes contact 710 so that when the sequence switch SS3 reaches position 4 a circuit is closed as follows:—battery, winding of relay 704, contact 713, contacts G3 and G1 in position 4 of sequence switch SS3, contact 710, contacts J1 and J2 in position 4 of sequence switch SS3, to earth. Sequence switch SS3 continues to advance until it reaches position 5, where it stops because contact 716 is open. Relay 704 remains operated in position 5, the sequence switch stops in position 5, and at contact 715 a circuit is completed for the brush carriage magnet 706 as follows:—battery, winding of magnet 706, contacts C3 and C1 in position 5 of sequence switch SS3, contact 715, to earth. Magnet 706 energizes and the selected set of brushes 719, 720 and 721 are set in rotation.

When a free trunk leading to a final selector is encountered such as that comprising conductors 760, 761 and 762, and leading to the selector R4 shown in Fig. 8, the following circuit is completed: earth, high resistance lower winding of relay 703, contacts F3 and F1 in position 5 of sequence switch SS3, brush 720, contact 723, conductor 761, contacts L2, L1 in position 1 of sequence switch SS4, contacts M5 and M2 in position 1 of sequence switch SS4, resistance 787, to battery. A breach of this circuit extends through contacts L2 and L3 in position 1 of sequence switch SS3, high resistance relay 751 to battery. Relay 751 and relay 703 energize in this circuit. Relay 751 locks energized in the following circuit: battery, lower and upper windings of relay 751 in series, contact 763, contact 790, to test conductor 761. Test relay 703 operates and opens the circuit of relay 704 at contact 713, and at contact 712 closes a locking circuit for itself as follows: test conductor 761, bank contact 723, conductor 720, low resistance upper winding of relay 703, contact 712, contacts G3 and G1 in position 5 of sequence switch SS3, contact 710, contacts J1 and J2 in position 5 of sequence switch SS3 to earth.

The brushes are correctly aligned on the selected bank contacts by arranging that a circuit is completed as follows: earth, tooth of rack 728, brush 709, contacts E1 and E3 in position 5 of sequence switch SS3, winding of relay 704 to battery; so that relay 704 can only release when the brushes properly engage the bank contacts. Relay 704 releases

and opens the circuit of magnet 706 and closes a circuit for magnet 727 as follows:— battery, winding of magnet 727, contacts B2 and B3 in position 5 of sequence switch SS3, 5 contact 716 to earth. Magnet H energizes and arrests the movement of the brushes 719, 720 and 721. A circuit is also closed for magnet 707 as follows: earth, contact 716, contacts B3 and B5 in position 5 of sequence 10 switch SS3, winding of magnet 707 to battery. Magnet 707 energizes and the sequence switch SS3 leaves position 5.

If the fourth series of impulses has not been completely registered on the tens register, relay 403 is still unoperated and the locking circuit of relay 208 extending over contact 441 on relay 403 and contact 457 on relay 406 is maintained to hold relay 208 operated. In such an event when sequence 20 switch SS3 reaches position 6, relay 701 (Fig. 7) would be operated over the following circuit: battery, resistance 255, contact 262, conductor 223, contact 485, conductor 222, contact 265, bank springs 251, conductor 25 170, contact 198, conductor 169, contacts K3 and K2 in position 6 of sequence switch SS2, brush 529, bank contact 530, conductor 531, contacts H1 and H3 in position 6 of sequence switch SS3, winding of relay 701, contacts 30 M3 and M1 in position 6 of sequence switch SS3, to earth. Relay 701 operates, and at contact 710 closes a circuit for relay 704 as follows: earth, contacts J2 and J1 in position 6 of sequence switch SS3, contact 710, contacts G1 and G4 in position 6 of sequence switch SS3, winding of relay 704 to battery. Relay 704 operates and opens the circuit of magnet 707 at contact 716, the sequence switch SS2 therefore stops in position 6. If, however, the fourth digit is registered, or when it is registered, relay 208 is or will be, de-energized. Consequently relay 701 releases and is followed by relay 704, and therefore the circuit for magnet 707 is again completed 45 and the sequence switch SS3 advances to position 9.

In this position the fundamental circuit is extended to the selector R4; and may now be traced as follows: earth, contacts O3 and 50 O2 in position 1 of sequence switch SS4, conductor 760, bank contact 722, brush 719, contacts M4 and M2 in position 9 of sequence switch SS3, conductor 528, bank contact 527, brush 526, contacts O2 and O1 in position 6 55 of sequence switch SS2, conductor 168, contact 190, conductor 172, bank springs 250, winding of relay 206, conductor 225, contact 416, conductor 227, contact 263, conductor 223, contact 485, conductor 222, contact 265, 60 bank springs 251, conductor 170, contact 198, conductor 169, contacts K2 and K3 in position 6 of sequence switch SS2, brush 529, bank contact 530, conductor 531, contacts J3 and J4 in position 9 of sequence switch 65 SS3, brush 721, bank contact 724, conductor

762, contacts G1 and G5 in position 1 of sequence switch SS4, winding of relay 753 to battery.

Relays 206 and 753 operate in this circuit and relay 753 upon operating closes a circuit 70 as follows: earth, contact 769, contacts B2 and B5 in position 1 of sequence switch SS4, winding of magnet 756 to battery. Magnet 756 energizes and the sequence switch SS4 advances into position 2. 75

In position 2 of sequence switch SS4 a circuit is completed for the trip spindle magnet 754 as follows: battery, winding of magnet 754, contacts C2 and C3 in position 2 of sequence switch SS4, contact 769 to earth. 80 The trip spindle and its interrupter 757 thereupon rotates, off-normal contact 773 is closed, and contact 774 closed intermittently whereby revertive impulses are sent back over the following circuit: earth, contact 773, contact 774, contacts G2 and G5 in position 2 of sequence switch SS4, contact 768, contacts J4 and J3 in position 2 of sequence switch SS4, to conductor 762. Relay 753 is maintained energized over the 90 following circuit, battery, winding of relay 753, contacts G5 and G2 in position 2 of sequence switch SS4, contact 774, contact 773 to earth. 95

Relay 206 at the register controller is intermittently short circuited over the fundamental circuit and the revertive impulses are repeated by relay 206 over the following circuit: earth, contact 257, conductor 224, contact 460, contact 455, conductor 358 to the 100 set of counting relays 331-335 inclusive.

When the calling subscriber sends the series of impulses corresponding to the tens digit the following circuit is completed: earth, contact 279, conductor 235, contact 442, contact 436, contact 428, upper winding of relay 403 to battery; relay 403 operates partially in this circuit at the beginning of the impulse series to close contact 438 only and operates completely at the end of the series 110 of impulses over the following circuit: battery, upper and lower windings of relay 403 in series, contact 438, conductor 232, contact 282 to earth. The four impulses transmitted by the calling subscriber are repeated at contact 179 of relay 162 and contact 272 of relay 218 and are received on the tens register over the following circuit: earth, contact 272, conductor 234, contact 444, contact 440, contact 430, conductor 358 to relays 331-335 inclusive (Fig. 4.). These relays are arranged similarly to relays 211-215, inclusive, and 321-325 inclusive, and consequently after four impulses relay 334 is locked energized to the holding conductor 357 which extends to earth over the following circuit: conductor 357, contact 464, conductor 232, contact 282, to earth. 115 120 125

The operation of the counting relays 331-335, inclusive, is now continued by the rever- 130

tive impulses. By referring to the impulse table it will be seen that the number of re-
tive impulses required to be sent back before the fundamental circuit is opened is
seven and it follows that the fundamental
circuit must be opened when relays 331-335,
inclusive, are all energized. When this hap-
pens, a circuit is completed for relay 208 as
follows: battery, winding of relay 208, con-
ductor 229, contact 465, lower winding of re-
lay 407, conductor 356, contact 380, contact
381, contact 382, contact 383, conductor 357,
contact 464, conductor 232, contact 282 to
earth.

15 Relay 208 operates in this circuit and relay
407 operates partially to close contact 462
only, thereby completing a circuit for its up-
per winding over which it operates complete-
ly. This relay, however, like relays 405 and
20 406, is slow to pull up. Relay 407 upon com-
pletely operating, disconnects earth from the
holding conductor 357 at contact 464 and re-
lays 331-335 inclusive de-energize.

25 Relay 208 upon operating closes contacts
258 and 262 but relay 205 is not energized
as previously occurred when relay 208 op-
erated because it is now short-circuited by
earth connected to its upper terminal in the
following circuit: upper terminal of relay
30 205, contact 258, bank springs 250, conductor
172, contact 190, conductor 168, contacts O1
and O2 in position 6 of sequence switch SS2,
brush 526, bank contact 527, conductor 528,
contacts M2 and M4 in position 9 of sequence
35 switch SS3, brush 719, bank contact 722, con-
ductor 760, contacts O3 and O2 in position 2
of sequence switch SS4 to earth.

40 As of course there is no hunting operation
in a final selector there is no waiting time be-
fore the next series of impulses can control the
final setting of the selector, and consequently
the operation of relay 205 is not required since
its function was to provide a locking circuit
45 for relay 208 at contact 256 during the hunt-
ing operation of switches R2 and R3. It is
however still necessary to hold the funda-
mental circuit open until the next digit has
been registered and a locking circuit is ac-
cordingly provided for relay 208 extending
50 as follows:—battery, winding of relay 208,
contact 264, conductor 230, contact 445, con-
tact 463, conductor 232, contact 282, to earth.

55 Relay 753 is short circuited by battery con-
nected to its upper terminal as follows: upper
terminal of relay 753, contact 768, contacts J4
and J3 in position 2 of sequence switch SS4,
conductor 762, contact 724, brush 721, con-
tacts J4 and J3 in position 9 of sequence
60 switch SS3, conductor 531, contact 530, brush
529, contacts K2 and K3 in position 6 of se-
quence switch SS2, conductor 169, contact
198, conductor 170, bank springs 251, contact
265, conductor 222, contact 485, conductor
223, contact 262, resistance 255 to battery.
65 Relay 753 accordingly de-energizes and opens

the circuit of magnet 754 at contact 769 and
closes contact 770 thereby completing a cir-
cuit as follows:—earth, contact 770, contacts
B1 and B5 in position 2 of sequence switch
70 SS4, magnet 756 to battery. Magnet 756 en-
ergizes and the sequence switch SS4 advances
into position 3.

75 Relay 208 remains energized until its lock-
ing circuit is opened, after the reception of
the units impulses. The number of impulses
in this series is eight and these are recorded
on relays 341-345, inclusive, which operate in
a manner similar to relays 211 to 215, inclu-
sive, as indicated in Fig. 11. At the beginning
80 of the impulse series the following circuit is
completed:—earth, contact 279, conductor
235, contact 442, contact 437, upper winding
of relay 404 to battery. Relay 404 operates
partially in the circuit to close contact 443
85 only. The impulsive circuit may be traced
as follows:—earth, contact 272, conductor
234, contact 444, contact 439, conductor 360
to relays 341-345, inclusive. The holding cir-
cuit for these relays may be traced from relay
90 345 over conductor 232 and contact 282 to
earth. Accordingly these relays are set to
register eight impulses, and relays 341, 343
and 345 will be locked operated at the end
95 of the impulse series over a circuit including
conductor 232, contact 282 to earth. At the
end of the impulse series, relay 404 operates
completely, thereby opening contact 445 and
releasing relay 208. Relay 208 de-energizes
100 and as before completes the fundamental cir-
cuit causing relays 206 and 753 to energize.

105 The fundamental circuit may be traced as
follows: battery, winding of relay 753, con-
tacts G5 and G1 in position 3 of sequence
switch SS4, conductor 762, bank contact 724,
brush 721, contacts J4 and J3 in position 9
110 of sequence switch SS3, conductor 531, bank
contact 530, brush 529, contacts K2 and K3
in position 6 of sequence switch SS2, con-
ductor 169, contact 198, conductor 170, bank
springs 251, contact 265, conductor 222, con-
tact 485, conductor 223, contact 263, con-
ductor 227, contact 416, conductor 225, winding
115 of relay 206, bank springs 250, conductor 172,
contact 190, conductor 168, contacts O1 and
O2 in position 6 of sequence switch SS1, brush
526, bank contact 527, conductor 528, contacts
M2 and M4 in position 9 of sequence switch
120 SS3, brush 719, bank contact 722, conductor
760, contacts O3 and O2 in position 3 of se-
quence switch SS4, to earth.

125 Relays 206 and 753 energize, in this cir-
cuit and relay 753 on energizing closes con-
tact 769 so that a circuit is completed for
magnet 756 as follows: earth, contact 769,
contacts B2 and B5 in position 3 of sequence
switch SS4, magnet 756 to battery. Magnet
756 energizes and the sequence switch ad-
vances into position 5 whereupon a circuit
130 is completed as follows:—battery, winding
of magnet 755, contacts C1 and C3 in position

5 of sequence switch SS4, contact 769 to earth. The brush carriage magnet 755 energizes and the selected brushes are released and moved over the bank contacts.

5 For each step taken by the brush carriage earth is connected over contact 771, contacts G2 and G5 in position 5 of sequence switch SS4, contact 768, contacts J4 and J3 in position 5 of sequence switch SS4, to the lower speaking conductor, thereby causing relay 206 to de-energize intermittently and transmit impulses to the units register over the following circuit: earth, contact 257, conductor 224, contact 461, conductor 360 to the units set of counting relays, 341-345, inclusive.

Reference to the impulse table shows that three revertive impulses are required to be sent back by the final selector before the fundamental circuit is opened; eight impulses have already been registered by the calling subscriber, so that the fundamental circuit must be opened when a total of eleven impulses have been registered, that is when relays 341, 342, 343, 344 and 345 are all operated. A circuit is then completed for relay 207 as follows: battery, winding of relay 207, conductor 226, contact 366, contact 386, contact 385, contact 387, contact 384, contact 388, conductor 232, contact 282 to earth. Relay 207 operates in this circuit and opens contact 265 thereby opening the fundamental circuit and releasing relay 753, whereupon the brush carriage stops with the brushes resting on the contacts of the wanted line.

Relay 207 also opens the circuit of relay 218, at contact 260, relays 218, 219 and 220 release but without effect since relay 404 is operated. Relay 207 also closes contact 259, thereby completing a circuit as follows: earth, contact 259, bank springs 252, conductor 199, contact 181, contact 194, contact 177, contact 192, winding of relay 167 to battery. Relay 167 operates and closes contacts 189 and 197 to prepare the speaking circuit: earth is connected to the upper speaking conductor over the following circuit: earth, lower winding of relay 166, contact 195, contact 177, contact 191, to conductor 168; this is without effect at this time. Battery is connected to the lower speaking conductor over the following circuit: battery, upper winding of relay 166, contact 197 to conductor 169. Relay 753 is thereby short circuited and remains de-energized. Relay 167 upon operating also closes a locking circuit for itself as follows:—battery, winding of relay 167, contact 193, contact 180 to earth. Relay 167 also opens contact 196 thereby opening the holding circuit of the plunger magnet 204 which de-energizes and allows the pairs of bank springs 250, 251, 252 and 253 to open. The circuit of relay 209 is also opened and this relay releases whereupon contact 282 opens and all the relays in the register controller

which are locked to conductor 232, release and the register controller may now be taken into use to set up another connection.

When the fundamental circuit was opened, relay 753 de-energized and at contact 769 opened the circuit of magnet 755, at contact 770 a circuit is completed for the holding magnet 784 as follows: earth, contact 770, contacts B1 and B3 in position 5 of sequence switch SS4, magnet 784 to battery. The brush carriage was thus stopped with its brushes 780, 781 and 782 resting on the contacts of the wanted line. At the same time that a circuit is completed for holding magnet 784 a branch circuit was completed as follows: earth, contact 770, contacts B1 and B5 in position 5 of sequence switch SS4, magnet 756 to battery. Magnet 756 energizes and the sequence switch SS4 leaves position 5.

It should be borne in mind at this time that sequence switch SS2 is in position 6, sequence switch SS3 is in position 9, while sequence switch SS4 has just left position 5. The holding circuit between switches R2 and R3 may be traced as follows:—earth, winding of relay 507 contacts F1 and F2 in position 6 of sequence switch SS2, brush 532, bank contact 533, conductor 534, contact 711, contacts G2 and G1 in position 9 of sequence switch SS3; contact 710, contacts K4 and K3 in position 9 of sequence switch SS3, winding of relay 702 to battery. Relay 702 it should be mentioned, is energized in the following circuit to keep contact 710 closed: earth, contact 716, contacts L2 and L1 in position 9 of sequence switch SS3, relay 701, contacts E2 and E4 in position 9 of sequence switch SS3, resistance 725 to battery. The holding circuit between switches R3 and R4 may be traced as follows: earth, contacts D1 and D4 in position 9 of sequence switch SS3, upper winding of relay 703, brush 720, bank contact 724, conductor 761, contact 790, contact 763, high resistance upper winding and low resistance lower winding of relay 751 in series to battery. Relays 703 and 751 are operated in this circuit.

Relay 751 is shunted by the relatively low resistance 787 until the sequence switch SS4 leaves position 5 and accordingly at this instant when the sequence switch SS4 leaves position 5 the high resistance relay 751 will be connected directly in series with the low resistance relay 703; relay 751 remains operated but the low resistance relay 703 de-energizes and completes the following circuit:—battery, winding of relay 704, contact 713, contacts D3 and D1 in position 9 of sequence switch SS3 to earth. Relay 704 energizes and at contact 716 opens the circuit of relay 701 which de-energizes and opens contact 710 in the circuit of relays 702 and 507, which relays accordingly de-energize.

Relay 704 also closes a circuit at contact 715 as follows: earth, contact 715, contacts

- B4 and B5 in position 9 of sequence switch SS3, magnet 707 to battery; magnet 707 energizes and the sequence switch SS3 advances from position 9.
- 5 Relay 702 upon de-energizing opens its holding circuit at contact 711, and relay 507 closes contact 523, thereby completing a circuit as follows:—earth, contact 523, contacts D2 and D1 in position 6 of sequence switch SS2, winding of magnet 510 to battery. Magnet 510 energizes and sequence switch SS2 advances into position 9. When the sequence switch SS2 reaches position 7 a circuit is completed as follows:—battery, winding of magnet 508, contacts G2 and G3 in position 7 of sequence switch SS2, off-normal contact 525, to earth. The trip spindle magnet 508 energizes and the trip spindle is thereupon rotated until it reaches its home position when contact 525 is opened and the trip spindle comes to rest.
- In position 9 of sequence switch SS2 a circuit is completed as follows: earth, lower winding of relay 166, contact 195, contact 177, contact 191, conductor 168, contacts N1 and N2 in position 9 of sequence switch SS2, winding of retard 502, upper and lower windings of relay 503 in series, contacts J3 and J2 in position 9 of sequence switch SS2, conductor 169, contact 197, upper winding of relay 166 to battery. Owing to the high resistance of the upper winding of relay 503 relay 166 cannot energize in this circuit, but relay 503 is held energized.
- 35 It will be noted that in position 9 of sequence switch SS2 the brushes 526 and 529 are bridged by a battery feed bridge including relay 504 and retard 501 as follows: battery, winding of relay 505, contacts K1 and K2 in position 9 of sequence switch SS2, to brush 529, and earth, contact 517, winding of retard 501, contacts O3 and O2 in position 9 of sequence switch SS2, to brush 526. It will also be noted that conductor 168 is connected to brush 526 through condenser 514 and that conductor 169 is connected to brush 529 through condenser 515 and the sequence switch SS2 is now in the speaking position.
- In position 14 of sequence switch SS3 it will be noted that conductors 528 and 531 are extended directly to the brushes 719 and 721 respectively, there being no bridge but a clean through circuit. When the sequence switch SS3 passes from position 9 the circuit of relay 704 is opened at contacts D3 and D1, relay 703 de-energizes and closes contact 716, but without effect. When sequence switch SS3 reaches position 10 a circuit is completed as follows:—earth, winding of low resistance relay 507, contacts F1 and F2 in position 9 of sequence switch SS2, brush 532, bank contact 533, conductor 534, contacts L4 and L1 in position 10 of sequence switch SS3, winding of high resistance relay 701, contacts E2 and E4 in position 10 of sequence switch SS3, resistance 725 to battery. Relay 701 energizes in this circuit; relay 507 does not energize but maintains low resistance earth on conductor 762 for guarding purposes. When sequence switch SS3 reaches position 13, relay 704 re-energizes in the following circuit: battery, winding of relay 704, contacts G4 and G1 in position 13 of sequence switch SS3, contact 710, contacts K4 and K1 in position 13 of sequence switch SS3, to earth; relay 704 opens the circuit of magnet 707 at contact 716 to allow the sequence switch SS3 to stop in position 14. While sequence switch SS2 is passing from position 6 to position 9 and when it stops in position 9, guarding earth is maintained on contact 533 through the winding of low resistance relay 507 and over contacts F1 and F2. While sequence switch SS3 is passing from position 9 to position 13 $\frac{1}{4}$ guarding earth is maintained on contact 723 through the low resistance upper winding of relay 703 and contacts D4 and D1, and while it is passing from position 13 to position 14 and when it stops in position 14 guarding earth is maintained on contact 723 through the low resistance upper winding of relay 703 and contacts C2 and C1.
- While the sequence switch SS4 in the final selector R4 is passing from position 5 to position 9 the selected line is tested; it will be assumed first of all that the selected line is busy. When sequence switch SS4 reaches position 9 a circuit is completed as follows:—battery, winding of relay 753, contacts F1 and F2 in position 9 of sequence switch SS4, contact 764 to earth. Relay 753 energizes and opens contact 770 so as to allow sequence switch SS4 to stay in position 9; busy tone is then sent to the calling subscriber as follows: earth, busy tone interrupter 776, contacts M3 and M1 in position 9 of sequence switch SS4, winding 788 of busy tone transformer to battery. This would induce a current in the secondary winding 789 which extends to the calling subscriber over the speaking leads 760, 762 as follows:—conductor 760, contacts O3 and O1 in position 9 of sequence switch SS4, winding 789 of busy tone transformer, condenser 775, contacts J2 and J3 in position 9 of sequence switch SS4, to conductor 762. In this manner the calling subscriber would receive the busy tone and release the connection by hanging up his receiver.
- When calling subscriber hangs up his receiver relay 162 de-energizes and at contact 178 opens the circuit of relay 163 which in turn de-energizes and opens contact 180, thereby removing earth from the release trunk conductor 114. The cut-off winding of the plunger magnet 102, relay 107 and relay 167 thereupon de-energize. When the plunger magnet de-energizes it allows the associated plunger arm to restore to normal and the pairs of bank springs 123, 124, 624 and 125 separate; when relay 107 releases a circuit

is completed as follows: earth, contact 149, contact 134, contact 137, off-normal contact 138, winding of release magnet 109 to battery. Magnet 109 energizes and allows the shaft of the selector to restore to normal. Switches C and S1 have thus been restored to normal and may be taken into use for another call.

When relay 162 releases it also opens contact 177 thereby opening the circuit of relay 503 which it will be remembered was operated by battery and earth connected through the upper and lower windings of relay 166 respectively. Relay 503 then releases, whereupon a circuit is completed as follows: earth, contact 516, contacts M3 and M2 in position 9, winding of relay 505 to battery. Relay 505 accordingly energizes and closes a circuit as follows: earth, contact 519, contacts B3 and B2 in position 9 of sequence switch SS2, magnet 510 to battery. Magnet 510 energizes and the sequence switch SS2 advances to position 11.

When the sequence switch SS2 leaves position 9, the guarding earth is removed from contact 533 at contacts F2 and F1, and relay 704 which was operated by this earth now releases and initiates the release of selector R3. When position 11 is reached a circuit is completed as follows: earth, contact 523, contacts D2 and D3 in position 11 of sequence switch SS2, winding of magnet 509 to battery. The brush carriage thereupon rotates until it reaches its home position and brush 535 engages contact 536 whereupon a circuit is completed as follows: earth, winding of relay 507, brush 535, home contact 536, contacts E1 and E2 in position 7 of sequence switch SS2, winding of magnet 511 to battery. Relay 507 and holding magnet 511 energize together in this circuit so that the brush carriage is stopped in its normal position. When relay 507 operates, a circuit is completed as follows: earth, contact 522, contacts C3 and C2 in position 11 of sequence switch SS2, winding of magnet 510 to battery: magnet 510 energizes and the sequence switch SS2 thereupon advances into position 1, when it leaves position 11, contacts E1 and E2 are opened and relay 507 de-energizes. When the sequence switch SS2 reaches position 1, the switch R2 has restored to normal, and may be operated to establish another call.

Referring now to the selector R3, when relay 704 fell back a circuit was completed as follows: earth, contact 716, contacts B3 and B5 in position 14 of sequence switch SS3, winding of magnet 707 to battery. Magnet 707 accordingly energizes and the sequence switch SS3 advances into position 17. In position 16 $\frac{3}{4}$ a circuit is completed as follows: earth, off-normal contact 718, contacts D2 and D3 in position 16 $\frac{3}{4}$ of sequence switch SS3, contact 713, winding of relay 704 to battery. Relay 704 accordingly energizes and completes a circuit as follows: earth, contact 715,

contacts C1 and C4 in position 17 of sequence switch SS3, winding of magnet 705 to battery. The trip spindle magnet 705 accordingly energizes and the trip spindle restores to normal, when contact 718 opens the circuit of relay 704. Relay 704 again de-energizes and closes contact 716, thereby completing a circuit for magnet 717 as follows: earth, contact 716, contacts B3 and B5 in position 17 of sequence switch SS3, winding of magnet 707 to battery.

The sequence switch SS3 advances from position 17 and in position 17 $\frac{3}{4}$ a circuit is completed as follows: battery winding of relay 704, contact 713, contacts D3 and D1 in position 17 $\frac{3}{4}$ of sequence switch SS3 to earth. Relay 704 energizes and opens the circuit of magnet 707 at contact 716 to allow sequence switch SS3 to stop in position 18. In position 18 a circuit is completed as follows: earth, contact 715, contacts C1 and C3 in position 18 of sequence switch SS3, winding of magnet 706 to battery. The brush carriage magnet 706 energizes and the brush carriage thereupon rotates until it reaches its home position when a circuit is completed as follows: battery, resistance 725, home contact 726, brush 709, contacts F2 and F3 in position 18 of sequence switch SS3, lower winding of relay 703 to earth. Relay 703 energizes and at contact 713 opens the circuit of relay 704, which thereupon de-energizes and closes the following circuit: earth, contact 716, contacts B3 and B5 in position 18 of sequence switch SS3, winding of magnet 707 to battery. The sequence switch SS3 thereupon passes into position 1, and relay 703 de-energizes when contacts F2 and F3 open.

It will be remembered that sequence switch SS4 was left in position 9 and that busy tone was being fed back to the calling subscriber and that relay 751 was operated by earth connected through the upper winding of relay 703. When sequence switch SS3 passes out of position 13 $\frac{1}{4}$ the circuit of relay 751 is opened at contact D1 of sequence switch SS3, relay 751 accordingly de-energizes and opens contact 764, thereby releasing relay 753. Relay 753 at contact 770 completes the following circuit: earth, contact 770, contacts B1 and B5 in position 9 of sequence switch SS4, winding of magnet 756 to battery. Magnet 756 energizes and the sequence switch SS4 advances to position 11. In this position a circuit is completed as follows: battery, brush carriage magnet 755, contacts C1 and C4 in position 11 of sequence switch SS4, contact 770 to earth.

Magnet 755 energizes and the brush carriage restores to normal and when normal position is reached a circuit is completed as follows: earth, brush 772, contact 783, contacts E3 and E1 in position 11 of sequence switch SS4, contacts G4 and G5 in position 11 of sequence switch SS4, winding of relay 753.

to battery. Relay 753 energizes and completes the following circuits at contact 769; battery, winding of magnet 784, contacts B3 and B2 in position 11 of sequence switch SS4, contact 769 to earth, and: battery, winding of magnet 756, contacts B5 and B2 in position 11 of sequence switch SS4, contact 769 to earth. Holding magnet 784 accordingly energizes to stop the brush carriage, and magnet 756 energizes to cause the sequence switch SS4 to advance.

When position 12 is reached, a circuit is completed for magnet 756 as follows: battery, winding of magnet 756, contacts B5 and B4 in position 12 of sequence switch SS4, contact 765 to earth. Magnet 756 energizes and causes the sequence switch SS4 to advance to position 17. In position 17 a circuit is completed for relay 753 as follows: earth, off-normal contact 773, contacts G3 and G5 in position 17 of sequence switch SS4, winding of relay 753 to battery. Relay 753 energizes and closes a circuit for the trip spindle magnet as follows: battery, winding of magnet 754, contacts C2 and C3 in position 17 of sequence switch SS4, contact 769 to earth. Magnet 754 energizes and restores the trip spindle to normal and when this occurs contact 773 is opened and relay 753 de-energizes, thereby completing a circuit as follows: earth, contact 770, contacts B1 and B5 in position 17 of sequence switch SS4, winding of magnet 756 to battery.

Magnet 756 energizes and the sequence switch SS4 advances to position 18. In this position a circuit is completed for relay 753 as follows: earth, brush 772, contact 783, contacts E3 and E1 in position 18, contacts G4 and G5 in position 18 of sequence switch SS4, winding of relay 753 to battery. Relay 753 accordingly energizes and at contact 769 closes the following circuit: earth, contact 769, contacts B2 and B5 in position 18 of sequence switch SS4, winding of magnet 756 to battery; magnet 756 energizes and the sequence switch SS4 advances into position 1. When the sequence switch SS4 leaves position 18 the circuit of relay 753 is opened and the selector R3 is restored to normal.

It will now be assumed that the selected line is idle. When sequence switch SS4 reaches position $5\frac{1}{4}$ a circuit is completed for the test relay 752 as follows: earth contacts H3 and H4 in position $5\frac{1}{4}$ of sequence switch SS4, resistance 791, winding of relay 752, brush 782, contact 794, conductor 805, winding of cut-off relay 802 to battery. Relays 802 and 752 operate in this circuit and relay 802 opens contacts 806 and 807 thereby disconnecting the line relay 801 from the called subscriber's line. Relay 752 upon operating closes a locking circuit for itself as follows: battery, winding of relay 802, conductor 805, bank contact 794, brush 782, winding of relay 752, contacts D2 and D1 in position

5 $\frac{1}{4}$ of sequence switch SS4, contact 767, contact 764 to earth. On reaching position 9, relay 753 will not be energized since contact 766 is open and consequently the circuit for magnet 756 will remain completed over contact 770 and contacts B1 and B5 in position 9 of sequence switch SS4 and the sequence switch SS4 continues to advance.

In position 10 of sequence switch SS4 a circuit is completed as follows: earth, contact 764, contacts E2 and E1 in position 10 of sequence switch SS4, contacts G4 and G5 in position 10 of sequence switch SS4, winding of relay 753 to battery. Relay 753 energizes and remains energized in position 11 of sequence switch SS4 whereupon a circuit is completed as follows: earth, contact 769, contacts B2 and B5 in position 11 of sequence switch SS4, winding of magnet 756 to battery. Magnet 756 energizes and the sequence switch SS4 advances to position 12; when sequence switch SS4 leaves position 11 the circuit of magnet 753 is opened at contacts E1 and E2.

In position 12 of sequence switch SS4 the locking circuit of relay 752 is rendered independent of contact 764 by being extended to earth over contacts H2 and H3 in position 12 of sequence switch SS4. The sequence switch SS4 stops in position 12 and ringing current is transmitted to the called subscriber's instrument over the following circuit: earth, ringing generator 778, contacts K2 and K4 in position 12 of sequence switch SS4, brush 781, bank contact 793, conductor 804 through the called subscriber's instrument at substation B, conductor 803, contact 792, brush 780, contacts N4 and N3 in position 12 of sequence switch SS4, winding of relay 750 to battery. A circuit is also completed as follows: earth, ringing generator 777, contacts M4 and M1 in position 12 of sequence switch SS4, primary winding 788 of transformer to battery. A tone is therefore induced in the secondary winding of the transformer and sent back to the calling subscriber over the speaking leads, the circuit extends as follows: conductor 760, contacts O3 and O1 in position 12 of sequence switch SS4, secondary winding 789, condenser 775, contacts J2 and J3 in position 12 of sequence switch SS4 to conductor 762.

Either immediately or after a short interval earth is connected up by the continuously driven interrupter 785, thereby completing a circuit as follows: earth, black conducting sector of interrupter 785, contacts E4 and E1 in position 12 of sequence switch SS4, contacts G4 and G5 in position 12 of sequence switch SS4 winding of relay 753 to battery. Relay 753 energizes and at contact 769 completes a circuit as follows: earth, contact 769, contacts B2 and B5 in position 12 of sequence switch SS4, winding of magnet 756 to bat-

tery. Magnet 756 energizes and the sequence switch SS4 advances into position 13; in position 13 a circuit is completed by the interrupter 786 as follows: earth, black conducting sector of interrupter 786, contacts E5 and E1 in position 13 of sequence switch SS4, contacts G4 and G5 position 13 of sequence switch SS4, winding of relay 753 to battery. Relay 753 therefore again energizes and at 10 contact 769 causes magnet 756 to energize and advance the sequence switch SS4 to position 14. When it leaves position 13 the circuit of relay 753 is opened at contact G5. In position 14, intermittent ringing over conductor 779 replaces the continuous ringing over conductor 778 and this continues until the called subscriber lifts his receiver.

When the called subscriber removes his receiver either in the continuous or intermittent or silent period of ringing, relay 750 energizes and opens contact 790, thereby causing relay 751 to release, whereupon a circuit is closed as follows: earth, contact 765, contacts B4 and B5 in position 14 of sequence switch SS4, winding of magnet 756 to battery. Magnet 756 energizes and advances sequence switch SS4 to position 15. Just before this position is reached a transient circuit is completed for relay 751 as 20 follows: earth, contacts L4 and L5 in position 14½ of sequence switch SS4, lower winding of relay 751 to battery. Relay 751 energizes, opens contact 765 so as to allow the sequence switch SS4 to remain in position 15, and closes contact 764. Relay 751 locks energized in the following circuit; battery, lower and upper windings of relay 751 in series, contacts L3 and L2 in position 15 of sequence switch SS4, conductor 761, bank contact 723, brush 720, upper winding of relay 703, contacts C2 and C1 in position 14, contact 715 to earth.

In position 15 of sequence switch SS4 the brushes 780 and 781 are connected to conductors 760 and 762 over contacts N4 and N1 and contacts J1 and J3 respectively. Accordingly a circuit is completed for relay 501 of the selector R2 as follows: battery, winding of relay 504, contacts K1 and K2 in 45 position 9 of sequence switch SS2, brush 529, bank contact 530, conductor 531, contacts J3 and J4 in position 14 of sequence switch SS3, brush 721, bank contact 724, conductor 762, contacts J3 and J1 in position 15 of sequence switch SS4, brush 781, bank contact 793, conductor 804, called instrument set, conductor 803, bank contact 792, brush 780, contacts N4 and N1 in position 15 of sequence switch SS4, conductor 760, bank contact 722, 55 brush 719, contacts M4 and M2 in position 14 of sequence switch SS3, conductor 528, bank contact 527, brush 526, contacts O2 and O3 in position 9 of sequence switch SS2, winding of retard 501, contact 517 to earth.

60 Relay 504 operates in this circuit and at

contact 518 short circuits the high resistance upper winding of relay 503, whereupon relay 163 in the repeater D operates and at contact 188 closes a circuit for relay 161 which operates and reverses the battery connections to 70 the speaking conductors 113 and 115. This reversal, as is well known in the art, is used for metering purposes or for supervision signifying that the called subscriber has answered and must therefore be charged for, 75 or for notifying an operator that the called subscriber has answered. The conversation can now take place, current being fed to the calling subscriber from relay 162 and to the called subscriber from relay 504 and retard 80 501. At the end of the conversation the subscribers hang up their receivers and the switches C, S1, R2 and R3 restore to normal 85 in the same manner as described in connection with the release when the called line was found busy.

The release of the switch R4 is initiated when sequence switch SS3 passes out of position 14 and opens the circuit of relay 751. Relay 751 accordingly de-energizes and 90 closes contact 765, thereby completing a circuit as follows: earth, contact 765, contacts B4 and B5 in position 15 of sequence switch SS4, winding of magnet 756 to battery; magnet 756 energizes and the sequence switch 95 SS4 advances to position 16.

On passing position 15½ a transient circuit for relay 751 was completed as follows: battery lower winding of relay 751, contacts L5 and L4 in position 15½ of sequence switch 100 SS4 to earth. Relay 751 again energizes and if the called subscriber has not hung up his receiver, relay 751 locks energized in the following circuit: battery, lower and upper windings of relay 751 in series, contacts K1 105 and K4 in position 16 of sequence switch SS4, brush 781, bank contact 793, conductor 804, called subscriber's instrument set, conductor 803, bank contact 792, brush 780, contacts N4 and N1 in position 16 of sequence switch 110 SS4, contacts O3 and O2 in position 16 of sequence switch SS4 to earth. The alarm lamp 759 is lit in a branch of this circuit over contact N2 so that if the called subscriber delays to hang up, the attention of 115 an attendant may be called. It will be assumed that the called subscriber hangs up either after the sequence switch reaches position 16 or shortly after. In either case relay 751 releases and the following circuit 120 is completed: earth, contact 765, contacts B4 and B5 in position 16 of sequence switch SS4, winding of magnet 756 to earth.

The sequence switch SS4 accordingly advances into position 17 and the following circuit is completed: earth, off-normal contact 125 773, contacts G3 and G5 in position 17 of sequence switch SS4, winding of relay 753 to battery. Relay 753 energizes and completes the following circuit: earth, contact 130

769, contacts C3 and C2 in position 17 of sequence switch SS4, winding of magnet 754 to battery. The trip spindle magnet 754 energizes and restores the trip spindle to normal whereupon the circuit of relay 753 is opened at contact 773; relay 753 then releases and the following circuit is closed: earth, contact 770, contacts B1 and B5 in position 17 of sequence switch SS4, winding of magnet 756 to battery.

The sequence switch SS4 accordingly advances into position 18, and in this position a circuit is closed as follows: earth, contact 770, contacts C4 and C1 in position 18 of sequence switch SS4, winding of magnet 755 to battery. The brush carriage magnet 755 energizes and the brush carriage thereupon rotates to its normal position and when it reaches its normal position a circuit is completed as follows: earth, brush 772, contact 783, contacts E3 and E1 in position 18 of sequence switch SS4, contacts G4 and G5 in position 18 of sequence switch SS4, winding of relay 753 to battery. Relay 753 operates and a circuit is then completed as follows: earth, contact 769, contacts B2 and B5 in position 18 of sequence switch SS4, winding of magnet 756 to battery, while a branch circuit extends through contact 83 to holding magnet 784 and the brush carriage is therefore held in its normal position, while the sequence switch SS4 advances to position 1 and as the circuit of relay 752 has been opened at contact 784 and H2 the switch R4 is fully restored to normal.

The case has been considered of a call to both an idle and a busy subscriber. The following conditions remain to be dealt with:—

1. Release when the calling subscriber hangs up before a final selector has been seized.
2. Release when the calling subscriber hangs up after a final selector has been seized.
3. Release when the calling subscriber delays to dial after seizure of a register, and before a final selector has been seized.
4. Release when the calling subscriber delays to dial after a final selector has been seized.

The reason why the release has to be considered separately according as to whether a final selector has been seized or not is that the release arrangements of a final selector of the revertive control type are different from the release arrangements of the group selectors of the revertive control type. If a calling subscriber hangs up before a call is completed, either he will hang up before a register has been seized, in which case the release is as usual in step-by-step systems and need not, therefore, be described, or he will hang up after a register has been seized and either before or after a final selector has been seized.

If the calling subscriber hangs up his receiver after a register has been seized, and before a final selector has been seized, relays 162 and 163 in the repeater D, release as before. In this case earth is removed from relay 209 and plunger magnet 204 in the register by the release of relay 163 in the repeater. The release of relay 209 and magnet 204 causes the complete release of both register and repeater, as well as the incoming selector switch in the revertive control exchange.

It will now be assumed that the calling subscriber hangs up just after the selector R3 has been seized, it will be recollect that when the selector was seized relay 702 was energized over conductor 534 from selector R2, relay 704 was operated over the fundamental circuit and the sequence switch SS3 advanced to position 2. In this position a circuit was completed for magnet 705 so that the trip spindle rotated and impulses were being transmitted over conductors 528 and 531.

When the calling subscriber hangs up, the plunger magnet 204 de-energizes and the fundamental circuit is opened, relay 704 thereupon de-energizes and the circuit of magnet 705 is opened in exactly the same way as it is opened when the requisite number of impulses have been sent back to the register controller; relay 704 also completes a circuit for magnet 707 and the sequence switch SS3 advances to position 6. In position $\frac{5}{4}$ of sequence switch SS3 a circuit is completed as follows: battery, resistance 725, home contact 726, brush 709, contacts F2 and F3 in position $\frac{5}{4}$ of sequence switch SS3, lower high resistance winding of relay 703 to earth. Relay 703 operates in this circuit and opens contact 713 so that relay 704 will not be able to operate in position 6 as it otherwise would in the following circuit: battery, winding of relay 704, contact 713, contacts D3 and D1 in position 6 of sequence switch SS3 to earth.

The circuit of magnet 707 therefore remains closed in positions 6 and 7 and the sequence switch SS3 advances to position 9. In this position a circuit is completed as follows: earth, contacts D1 and D3 in position 9 of sequence switch SS3, contact 713, winding of relay 704 to battery. Relay 704 energizes and at contact 715 completes a circuit as follows: earth, contact 715, contacts B4 and B5 in position 9 of sequence switch SS3, winding of magnet 707 to battery.

The sequence switch SS3 thereupon advances to position 14, in this position relay 704 is de-energized and consequently a circuit extends as follows: earth, contact 716, contacts B4 and B5 in position 14 of sequence switch SS3, winding of magnet 706 to battery. The sequence switch SS3 advances to

- position 17. In this position, relay 704 is energized in the following circuit: battery winding of relay 704, contact 713, contacts D3 and D2 in position 17, off-normal 5 contact 718 to earth; relay 704 closes contact 715 and a circuit is then completed as follows: earth, contact 715, contacts C1 and C4 in position 17 of sequence switch SS3, winding of magnet 705 to battery.
- 10 Magnet 705 energizes and restores the trip spindle to normal; when this occurs contact 718 opens and relay 704 releases to complete a circuit as follows: earth, contact 716, contacts B3 and B5 in position 17 of sequence switch 15 SS3, winding of magnet 707 to battery. Magnet 714 energizes and the sequence switch SS3 advances to position 18. In position 18 a circuit is completed for relay 703 as follows: earth, lower winding of relay 703, contacts F3 and F2 in position 18 of sequence switch SS3, brush 709, home contact 726, resistance 725 to battery. Relay 703 operates and at contact 713 opens a point in the circuit of magnet 704 to prevent this relay operating, the circuit of magnet 707 is therefore maintained in this position and the sequence switch advances to its normal position.
- When sequence switch SS3 left position 8 the circuit of relay 702 was opened and accordingly relay 507 in the selector R2 was de-energized, the sequence switch SS1 would be in position 6 at that time, and accordingly a circuit is completed as follows: earth, contact 523, contacts D2 and D1 in position 6 of 20 sequence switch SS2, winding of magnet 510 to battery. Magnet 510 energizes and sequence switch SS2 accordingly advances to position 9.
- When the sequence switch reaches position 25 7 a circuit is completed for the trip spindle magnet 508 as follows: earth, off-normal contact 525, contacts G3 and G2 in position 7 of sequence switch SS2, winding of magnet 508 to battery. This circuit is maintained all the way to position 1 to ensure that the trip spindle returns to normal. The trip spindle rotates until it reaches its normal position whereupon the circuit of magnet 508 is opened at contact 525. In position 9 a circuit is completed as follows: earth, contact 513, contacts M3 and M2 in position 9 of sequence switch SS2, winding of relay 505 to battery. Relay 505 energizes and completes a circuit for magnet 510 as follows: 30 earth, contact 519, contacts B3 and B2 in position 9 of sequence switch SS2, winding of magnet 510 to battery. Magnet 510 energizes and the sequence switch SS2 accordingly advances to position 11.
- 40 In position 11 a circuit is completed as follows: earth, contact 523, contacts D2 and D3 in position 11 of sequence switch SS2, winding of magnet 509 to battery; magnet 509 energizes and the brush carriage accordingly returns to normal. When the brush carriage returns to normal a circuit is completed as follows: battery, winding of magnet 511, contacts E2 and E1 in position 11 of sequence switch SS2, contact 536, brush 535, winding of relay 507 to earth. Relay 507 energizes and a circuit is completed as follows: earth, contact 522, contacts C3 and C2 in position 11 of sequence switch SS2, winding of magnet 510 to battery; magnet 510 energizes and the sequence switch SS2 thereupon restores to normal. All the apparatus is now in its normal position and may be taken into use for another call.
- If, however, the calling subscriber hangs up after the second series of retractive impulses have been received back, the release arrangements must be modified in order that the final selector shall release. The manner in which the modification is brought about will now be described. Referring to the register it will be remembered that relay 406 energizes after the trip spindle of the selector R3 has been set; when relay 406 operates a circuit is completed as follows: earth, contact 180, upper winding of relay 165, contact 182, contact 187, contact 196, conductor 171, bank springs 253, contact 261, conductor 228, contact 453, contact 483, contact 477, upper winding of relay 411 to battery. Relay 411 partially energizes and closes contact 487 only to prepare a locking circuit for itself.
- Therefore, if the calling subscriber hangs up at this time, immediately earth is removed at contact 180, relay 411 energizes and operates completely in the following circuit: battery, upper and lower winding of relay 411 in series, contact 487, conductor 232, contact 282 to earth. Relay 411 upon operating connects up earth so as to hold relay 209 and magnet 204 energized in the following circuit: earth, contact 476 or 482, contact 484, contact 453, conductor 228, contact 261, winding of relay 209 to battery, and in a branch circuit over bank springs 253, winding of magnet 204 to battery. A further branch circuit extends over conductor 171, contact 196, contact 187, contact 183, winding of relay 164 to battery. Relay 164 energizes and at contact 184 places earth on conductor 114 and so prevents the repeater being seized. Relay 411 on energizing also opens contact 485 and closes contact 486, thereby connecting together conductors 221 and 222, that is to say, it places a short circuit across the speaking conductors.
- Now it will be remembered that relay 751 of the selector R4 operates immediately the switch is seized and that relay 753 operates when sequence switch SS3 extends the fundamental circuit to the final selector by advancing into position 9. Relay 753 upon operating completes a circuit for magnet 756, at contact 769, whereupon the sequence switch SS4 advances into position 2, in this position the magnet 754 of the trip spindle

is energized and the trip spindle commences to rotate and continues to rotate until the loop across conductor 760 and 762 is opened.

5 If the calling subscriber releases during the rotation of the trip spindle of selector R4, relay 411 operates completely and the loop across the speaking conductors which included the winding of relay 206 is replaced by a short circuit as previously described;

10 the circuit of relay 753 is then maintained in position 2 of sequence switch SS4 as follows: battery, winding of relay 753, contact 768, contacts J4 and J3 in position 2 of sequence switch SS4, conductor 762, over the

15 speaking lead to the short circuit over contacts 486, 466 at the register, and back to conductor 760, contacts O3 and O2 in position 2 of sequence switch SS4 to earth.

Under these conditions the trip spindle 20 will continue to rotate until the fundamental circuit is opened and this is effected by a timing device associated with the register. When relay 209 operated and closed contact 281 the timing device was connected to conductor 231, this device periodically connects earth to conductor 231 for a moment at intervals of about 30 seconds.

When earth is first connected to conductor 231 (which may occur immediately the register controller is seized, or after an interval of up to 30 seconds) a circuit is completed as follows: earth, contact 281, conductor 231, contact 470, contact 467, upper winding of

35 relay 408 to battery. Relay 408 operates partially to close contact 469 only, and when earth is removed from conductor 231, relay 408 energizes completely in the following circuit: battery, upper and lower windings of relay 408 in series, contact 469, contact 473,

40 conductor 233, contact 275, contact 282 to earth. Immediately the calling subscriber hangs up, relay 162 releases and after a short interval relay 163 releases whereupon a circuit is completed as follows: earth, contact

45 179, contact 181, conductor 199, bank springs 252, contact 260, winding of relay 218 to battery. Relay 218 operates and at contact 273 completes a circuit for relay 219 which in turn operates and opens contact 275 there-

50 by releasing relay 408. Relay 219 also closes a circuit for relay 220 at contact 276 which in turn operates and closes contact 279. Shortly afterwards relays 218, 219 and 220 release, when relay 218 releases the first relay in the next counting set operates completely and when relay 220 releases and opens contact 279, the next input control relay operates completely. It will be seen therefore

55 that if relay 408 is locked operated when the calling subscriber releases, its circuit will be opened at contact 275 and it will accordingly release and remain de-energized until the next earth pulse is received.

60 When relay 408 operates it opens the fundamental circuit at contact 466 and relay 753

in the selector R4 releases and closes the following circuit: earth, contact 770, contacts B1 and B5 in position 2 of sequence switch SS4, winding of magnet 756 to battery. Magnet 756 energizes and the sequence switch SS4 advances into position 3. The sequence switch SS4 remains in this position until the fundamental circuit is again closed as will now be described.

70 When earth is again connected to conductor 231, relay 409 operates partially over contacts 470 and 468 to close contact 472 only and when earth is removed from conductor 231, relay 409 operates completely and holds energized over the following circuit: battery, upper and lower windings of relay 409 in series, contact 472, contact 480, conductor 233, contact 275, contact 282 to earth. At contact 471 relay 409 transfers the pulse lead 231 to relay 410 and at contact 473 opens the holding circuit of relay 408. Relay 408 thereupon releases and re-closes the fundamental circuit at contact 466.

75 A circuit is thereby closed for relay 753 which extends as follows: battery, winding of relay 753, contacts G5 and G1 in position 3 of sequence switch SS4, conductor 762, over the speaking lead to the short circuit over contacts 486 and 466 at register, back to conductor 760, contacts O3 and O2 in position 3 of sequence switch SS4 to earth; relay 753 operates in this circuit and at contact 769 completes a circuit as follows: earth, contact 769, contacts B2 and B5 in position 3 of sequence switch SS4, winding of magnet 756 to battery. Magnet 756 energizes and the sequence switch SS4 advances into position 5.

80 Relay 753 on energizing, locked energized in the following circuit: battery, winding of relay 753, contact 768, contacts J4 and J3 in position 3 of sequence switch SS4, conductor 762, over the speaking lead to the short circuit over contacts 486 and 466 at register, back to conductor 760, contacts O3 and O2 in position 3 of sequence switch SS4 to earth, and at contacts J4 and J3, and O3 and O2 are continuously closed until position 5 is reached, relay 753 remains operated and the sequence switch SS4 therefore remains in position 5 until the fundamental circuit is again opened. In position 5, the following circuit is completed: earth, contact 769, contacts C3 and C1 in position 5 of sequence switch SS4, winding of magnet 755 to battery, and the brush carriage accordingly commences to rotate.

85 When earth is again connected to conductor 231, relay 410 operates partially over contact 471 to close contact 479 only. A circuit is thereby completed for relay 412 as follows: battery, winding of relay 412, contact 488, contact 479, conductor 232, contact 282 to earth. Relay 412 operates and closes contact 489 so as to maintain the holding circuit 90

of relay 409 when relay 410 operates completely which it does shortly afterwards.

When earth is removed from conductor 231, relay 410 operates completely in the following circuit: battery, upper and lower windings of relay 410 to series, contact 479, conductor 232, contact 282 to earth. The opening of contact 480 is without effect since this is now shunted at contact 489. The circuit of relay 209 and magnet 204 in Fig. 3 and relay 164 in Fig. 2 is opened at contact 482 earth already having removed at contact 476, consequently all said devices de-energize; the energized relays in the register release 15 and the fundamental circuit is finally opened.

Relay 753 in the final selector now releases and a circuit is completed as follows: earth, contact 770, contacts B1 and B3 in position 5 of sequence switch SS4, winding of magnet 20 784 to battery; while a branch of this circuit extends over contacts B1 and B5 in position 5 of sequence switch SS4, winding of magnet 756 to battery. Magnet 756 accordingly energizes and the sequence switch SS4 advances.

When sequence switch SS4 leaves position 5 resistance 787 no longer shunts high resistance relay 751 as contacts M2 and M5 are opened as well as contacts L1 and L3, the effect of this is to connect the high resistance 30 relay 751 directly in series with the low resistance winding of relay 703 in the selector R3 the circuit being as follows: earth, contacts D1 and D4 in position 9 of sequence switch SS3, low resistance upper winding of 35 relay 703, brush 720, bank contact 723, conductor 761, contact 790, contact 763, high resistance relay 751 to battery. Relay 703 accordingly de-energizes, as it does not in this circuit obtain sufficient current to keep it energized, whereupon a circuit is completed as 40 follows: earth, contacts D1 and D3 in position 9 of sequence switch SS3, contact 713, winding of relay 704 to battery. Relay 704 energizes and completes a circuit as follows: 45 earth, contact 715, contacts B4 and B5 in position 9 of sequence switch SS3, winding of magnet 707 to battery; magnet 707 energizes and the sequence switch SS3 advances from position 9. When the sequence switch leaves 50 position 9 the circuit of relay 704 is opened at contact D3, the sequence switch however continues to advance.

Relay 704 on energizing opens the circuit of relay 701 at contact 716, relay 701 de-55 energizes and opens contact 710 in the circuit of relays 702 and 507, which relays accordingly de-energize. Relay 507 on de-energizing completes a circuit for magnet 510 as follows: earth, contact 523, contacts D2 60 and D1 in position 6 of sequence switch SS2, winding of magnet 510 to battery. Magnet 510 energizes and the sequence switch SS2 advances to position 9 as has already been described. Since, however, relay 167 has not 65 operated and the fundamental circuit is

opened at the register, relay 503 will not energize and consequently the following circuit will be closed: earth, contact 516, contacts M3 and M2 in position 9 of sequence switch SS2, winding of relay 505 to battery. Relay 505 70 therefore energizes and completes a circuit in position 9 for magnet 510 as has already been described. The sequence switch thereupon advances and the selector R2 is restored to normal in the same way as when it is released either at the end of a conversation or after a called subscriber has had his line tested and been found busy.

It will be recollected that in the setting up of a normal call relay 701 is energized at 80 this time in the following circuit: battery, resistance 725, contacts E4 and E2 in positions 10—15 of sequence switch SS3, winding of high resistance relay 701, contacts L1 and L4 in positions 10—15 of sequence switch SS3, 85 conductor 534, bank contact 533, brush 532, contacts F2 and F1 in positions 6—9 of sequence switch SS2, winding of low resistance relay 507 to earth, and that when sequence switch SS3 reached position 13 the normal 90 circuit for energizing relay 704 in this position would extend as follows: battery, winding of relay 704, contacts G4 and G1 in position 13 of sequence switch SS3, contact 710, contacts K4 and K1 in position 13 of sequence 95 switch SS3 to earth.

In the present case, however, sequence switch SS2 advances past position 9 whereupon the circuit previously described for relay 701 is opened at contacts F2 and F1 of sequence switch SS2, hence contact 710 will be open in position 13 of sequence switch SS3; as a result relay 704 will be de-energized in position 14 and the sequence switch SS3 will advance beyond this position, the restoration 100 of the selector R3 then takes place in the same manner as already described.

Referring now to the selector R4 it will be remembered that sequence switch SS4 has left position 5 and initiated the release of selectors 110 R2 and R3. When sequence switch SS3 leaves position 13½, earth is removed from the upper winding of relay 703 at contacts D1 and D4, so that relay 751 in the selector R4 releases. If the brush carriage was stopped in 115 an off-normal position relay 753 remains de-energized and the sequence switch SS4 advances into position 11. If, however, the brush carriage has stopped in normal position, then in position 5¾ of sequence switch 120 SS4, a circuit is completed as follows: battery, winding of relay 753, contacts G5 and G4 in position 5¾ of sequence switch SS4, contacts E1 and E3 in position 5¾ of sequence switch SS4, home contact 783 of the brush 125 carriage interrupter, brush 772 to earth.

Relay 753 operates in this circuit and opens contact 770 so that sequence switch SS4 is stopped in position 6; relay 753 also completes a circuit as follows: earth, contact 130

769, contacts C3 and C1 in position 6 of sequence switch SS4, winding of magnet 755 to battery. Magnet 755 thereupon energizes and the brush carriage moves off-normal; 5 when brush 772 moves off its home contact 783 the circuit of relay 753 is opened. Relay 753 releases and at contact 769 opens the circuit of the brush carriage magnet 755 and at contact 770 completes a circuit as 10 follows: earth, contact 770, contacts B1 and B5 in position 6 of sequence switch SS4, winding of magnet 756 to battery. A branch circuit is also completed for holding magnet 784. Magnet 756 energizes and the sequence switch SS4 advances. As relay 751 15 has already released, the circuit which is closed for relay 753 in position 9 in the case of a call to a busy subscriber, is open at contact 764; hence relay 753 cannot operate in position 9 and the sequence switch SS4 advances into position 11.

A circuit is established in position 11 of sequence switch SS4 for the brush carriage magnet as follows: earth, contact 770, contacts C4 and C1 in position 11 of sequence switch SS4, winding of magnet 755 to battery. Magnet 755 energizes and the brush carriage rotates until it reaches its home position, when a circuit is completed as follows: earth, 25 brush 772 and home contact 783 of the brush carriage interrupter, contacts E3 and E1 in position 11 of sequence switch SS4, contacts G4 and G5 in position 11 of sequence switch SS4, winding of relay 753 to battery.

30 Relay 753 operates and completes the following circuit: earth, contact 769, contacts B2 and B3 in position 11 of sequence switch SS4, winding of holding magnet 784 to battery. Magnet 784 energizes and holds the brush carriage in its home position. A parallel circuit is also completed as follows: earth, contact 769, contacts B2 and B5 in position 11 of sequence switch SS3, winding of magnet 756 to battery. Magnet 756 energizes 35 and the sequence switch SS4 advances into position 12. When it leaves position 11 the circuit of relay 753 is opened at contact E3 and this relay releases.

In position 12 of sequence switch SS4 40 a circuit is completed as follows: earth, contact 765, contacts B4 and B5 in positions 12-16 of sequence switch SS4, winding of magnet 756 to battery. Magnet 756 energizes and the sequence switch SS4 passes into position 17. In this position a circuit is completed for relay 753 as follows: battery, winding of relay 753, contacts G5 and G3 in position 17 of sequence switch SS4, off-normal contact 773 to earth. Relay 753 operates and closes a circuit for the trip spindle magnet as follows: earth, contact 769, contacts C3 and C2 in position 17 of sequence switch SS4, winding of magnet 754 to battery.

45 The trip spindle magnet 754 energizes and

the trip spindle rotates to its home position, whereupon the circuit of relay 753 is opened at contact 773 and this relay releases. A circuit is then completed for magnet 756 as follows: earth, contact 770, contacts B1 and B5 in position 17 of sequence switch SS4, winding of magnet 756 to battery. Magnet 756 energizes and the sequence switch SS4 advances out of position 17; the circuit of relay 753 is opened at contact G3 and this relay releases but again operates when the sequence switch reaches position 17 $\frac{3}{4}$ in the following circuit: earth, brush 772, home contact 783, contacts E3 and E1 in position 17 $\frac{3}{4}$ of sequence switch SS4, contacts G4 and G5 in position 17 $\frac{3}{4}$ of sequence switch SS4 winding of relay 753 to battery. Relay 753 operates and completes a circuit as follows: earth, contact 769, contacts E2 and E5 in position 18 of sequence switch SS4, winding of magnet 756 to battery. Magnet 756 energizes and sequence switch SS4 passes into position 1, and relay 753 releases, so that everything is now restored to normal.

If the calling subscriber releases during the rotation of the brush carriage, the release operation will be performed in the same manner as above, except that it commences at a later stage, that is to say, in position 5.

If the calling subscriber releases after the brush carriage has been set but before the sequence switch SS4 has reached position 9, release is accomplished in a manner that will now be described.

50 Relay 751 is de-energized as previously described so that the circuit for relay 753 in position 9 over contacts F1 and F2, contact 766 and contact 764 is open. The sequence switch SS4 thereupon passes from position 9 to position 11 where a circuit is completed for the brush carriage magnet as follows: earth, contact 770, contacts C4 and C1 in position 11 of sequence switch SS4, winding of magnet 755 to battery. Magnet 755 energizes and the brush carriage returns to its home position; when it reaches its home position, a circuit is completed for relay 753 as follows: earth, brush 772, home contact 783, contacts E3 and E1 in position 11 of sequence switch SS3, contacts G4 and G5 in position 11 of sequence switch SS3, winding of relay 753 to battery. Relay 753 operates and closes a circuit for magnet 756 as follows: earth, contact 769, contacts B2 and B5 in position 11 of sequence switch SS4, winding of magnet 756 to battery. Magnet 756 energizes and the sequence switch SS4 passes into position 12, whereupon the release proceeds as already described.

55 If the calling subscriber fails to complete his connection and abandons the call without hanging up his receiver the release takes place under the control of the timing device and the time pulse relays 408, 409, 410.

60 The case will be first considered in which

the hundreds register has not been operated by revertive impulses and consequently relay 406 has not been operated. When earth is first connected to conductor 231, which occurs at an interval not greater than 30 seconds after the dialling of the last digit, relay 408 is operated partially to close contact 469 only and when earth is removed from conductor 231 relay 408 operates completely over the following circuit: battery, upper and lower windings of relay 408 in series, contact 469, contact 473, conductor 233, contact 273, contact 282 to earth.

Relay 408 upon operating transfers the time pulse lead to relay 409 at contact 468 and when earth is again connected to conductor 231, relay 409 operates partially to close contact 472 only; when earth is removed from conductor 231 relay 409 operates completely in the following circuit: battery, upper and lower windings of relay 409 in series, contact 472, contact 480, conductor 233, contact 275, contact 282 to earth.

Relay 409 upon operating, transfers the time pulse lead to relay 410 at contact 471 and at contact 473 opens the circuit of relay 408 which releases but without effect. When earth is connected to conductor 231 for the third time, relay 410 operates partially to close contact 479 only and when earth is removed from conductor 231 relay 409 operates completely in the following circuit: battery, upper and lower windings of relay 410 in series, contact 479, conductor 232, contact 282 to earth.

Relay 410 upon operating, opens the holding circuit of relay 409 at contact 480 and relay 409 releases. Relay 410 also closes a circuit at contact 478 as follows: battery, low resistance 492, contact 478, contact 452, conductor 228, contact 261, bank springs 253, conductor 171, contact 196, contact 187 contact 182 upper winding of relay 165, contact 180 to earth. Relay 165 operates under these conditions and closes a locking circuit for itself at contact 186 as follows: battery, lower winding of relay 165, contact 186, contact 180 to earth. At contact 185 the circuit of a signal is closed to attract the attention of an attendant and at contact 187 earth is removed from conductor 171 whereupon relay 209 and plunger magnet 204 de-energize.

When relay 209 releases it opens the locking circuit of the locked energized relays in the register at contact 282. The release of the plunger magnet 204 causes bank springs 250-253 inclusive, to open and the release of the switches R2 and R3 takes place as previously described in the case in which the calling subscriber released when switches R2 and R3 had been operated up to the selection of a final selector. It will be understood that while the release of the register had been taking place, switches R2 and R3 have been operated in accordance with the digits which

were registered before the calling subscriber released.

If the calling subscriber delays to dial after sending in the hundreds digit, then selectors such as R2 and R3 will be set and a final selector will be seized. Relay 406 will be energized and conductor 228 will be extended over contact 453, contact 483, contact 477, upper winding of relay 411 to battery.

Relay 411 energizes partially in this circuit but nothing further happens until an interval has elapsed sufficient to permit relays 408, 409 and 410 to operate. When this occurs contact 477 is opened and relay 411 operates fully in a circuit already described over contact 487. Relay 410 on energizing opens contact 480 thereby permitting relay 409 to release, since although the circuit of relay 412 is closed at contact 488 immediately relay 411 energizes, relay 412 is slow to operate and cannot close contact 489 in time to lock relay 409 energized, as happens when the release takes place due to a calling subscriber hanging up before the final selector has completely operated but after it has been seized, the difference in the latter case being that relay 411 has already completely operated when relay 410 partially operates.

Due to relay 409 releasing a circuit is prepared for relay 408 so that after the lapse of the specified time interval relay 408 will be partially energized and eventually completely energized to open contact 466, thereby opening a point in the fundamental circuit. After a further interval relay 409 energizes and locks energized over contact 489, opens contact 473 and thereby allows relay 408 to release, whereupon the fundamental circuit is again closed.

The effect of opening and closing the fundamental circuit at this stage has already been described in the case where a calling subscriber hangs up after the final selector has been seized and it will be recollect that it was only necessary to open the fundamental circuit once more to cause the selector R4, and in consequence, the whole train of switches, to restore to normal.

When relay 409 energizes a circuit is completed as follows: battery, low resistance 492, contact 474, contact 481, contact 484, contact 453, conductor 228, contact 261, bank springs 253, conductor 171, contact 196, contact 187, contact 182, upper winding of relay 165, contact 180 to earth. Relay 165 accordingly energizes, and opens contact 187, thereby permitting the register controller to release as has already been described in the case where the calling subscriber delays to dial before sending in the hundreds digit. The fundamental circuit is again opened at bank springs 250 and 251 and consequently the final selector and the other switches in the train can restore to normal.

It will be noted that when relay 409 ener-

gizes it simultaneously effects the closure of the fundamental circuit at contact 463 by releasing relay 408, and the release of the register controller by operating relay 165 over contact 474, the result of this would be that plunger magnet 204 and relay 209 would release before relay 753 in the final selector R4 had time to energize. In order to ensure, therefore, that relay 753 in the selector R4 will energize, it is necessary to provide means to delay the release for a short interval of time and this is effected by having an earth connected to conductor 228 before relay 409 operates and then removing this earth a short interval after relay 409 has operated. The earth is connected up at contact 490 at the time when relay 410 energizes. When relay 410 energizes, relay 409 releases and a circuit for relay 413 can be traced as follows: earth, contact 476, contact 481, contact 475, winding of relay 413 to battery. Relay 413 operates and at contact 490 closes the following circuit: earth, resistance 493, contact 490, contact 484, contact 453, conductor 228, contact 261, windings of relay 209 and magnet 204 in parallel to battery; the circuit of relay 413 is maintained until relay 409 energizes for the second time. When this occurs, earth will be removed from conductor 228 at both contacts 476 and 482, but due to relay 413 being slow to release, earth is maintained over contact 490, for a short interval of time so as to delay the release of relay 209 and magnet 204. The fundamental circuit is closed for a sufficient time to enable relay 753 to energize and step on the sequence switch SS4. When relay 413 de-energizes the register controller is released, and the fundamental circuit is opened, thereby allowing the switch R4 to restore to normal.

It will be noted that in the previous description, it was assumed the called subscriber's number was 26248. All the digits registered in the register were therefore even numbers. A description will now be given of the modifications which arise when the thousands and hundreds digits are odd, there being no modification whether the tens and units digits are odd or even.

On the first impulse of each series dialled into the register by a calling subscriber, relay 218 completes the following circuit: earth, contact 274, contact 266, upper winding of relay 216 to battery. Relay 216 operates partially to close contact 268 only; since relay 219 and 220 are energized throughout the impulse series, the lower winding of relay 216 is short circuited at the time by earth connected to its lower terminal over contacts 271 and 280 which winding is short circuited at this time. At the end of the impulse, contact 274 opens and the short circuit is removed from the lower winding of relay 216 and this relay operates completely and closes contacts 269 and 267. The closure of contact 269 is

without effect since relay 219 remains operated throughout the impulse series, but at contact 267 a circuit is prepared for relay 217 and this circuit is closed at contact 274 when relay 218 operates on the second impulse. Relay 217 then operates and transfers the circuit of relay 216 to earth passing over contacts 270 and 274 so that when contact 274 is opened at the end of the second impulse relays 216 and 217 release.

This sequence of operations is continued as long as impulses are sent to relay 218 and it follows that at the end of an odd series of impulses relay 216 will be held operated over contact 280, until relay 220 releases. If, however, the number of impulses in the series is even, relays 216 and 217 will release when contact 274 is opened immediately after the end of the impulse series.

The object of the operation of relay 216 is to determine the operation of certain connecting relays associated with the counting relay sets. If the thousands digit is odd, relay 216 will be locked energized and after relay 219 has fallen back but before relay 220 has opened contact 279 to permit relay 401 to operate completely, a circuit will be closed as follows: earth, contact 277, contact 269, conductor 236, contact 414, conductor 248, winding of relay 210, to battery. Relay 210 operates and closes a locking circuit for itself as follows: battery, winding of relay 210, contact 284, contact 282 to earth. When relay 220 releases, the locking circuit of relays 216 and 217 is opened at contact 280 and if the series of impulses has been odd and relay 216 is therefore still operated, its circuit is now opened and relay 216 releases.

Assuming that the thousands digit was 7, then it will be noted by reference to Fig. 11 that relays 211, 212 and 215 would remain operated at the end of the impulse series sent by the calling subscriber. Referring to the impulse table it will be noted that when the thousands digit is 7 three revertive impulses have to be sent back from a selector such as R2 and consequently the circuit of relay 208 will be completed when the third revertive impulse has been received and relays 211, 212, 214 and 215 have been operated. A circuit is then completed for relay 208 as follows: battery, winding of relay 208, conductor 229, contact 451, lower winding of relay 405, contact 423, conductor 241, contact 292, contact 287, contact 302, contact 316, conductor 240, contact 450, conductor 232, contact 232 to earth. It will be seen that this circuit requires that relays 211, 212, 214 and 215 shall be operated.

It should be mentioned that there is one other correction to be made at this stage, viz. if the thousands digit should be 0. In this case it will be noted that the impulse table referred to above shows that nine revertive impulses must be returned when the digit 0 is

dialled, and as the digit 0 consists of ten impulses special provision has to be made in the register controller to correct for this. Referring to Fig. 11 and to the thousands relay set in Fig. 3, it will be seen that when the tenth impulse has been sent by the calling subscriber, relays 211, 212, 214 and 215 will have been operated. When relay 214 has completely operated at the end of the tenth impulse a circuit is closed for relay 330, this circuit extending as follows: battery, winding of relay 330, conductor 355, contact 424, conductor 241, contact 292, contact 287, contact 302, contact 316, conductor 240, contact 450, conductor 232, contact 282 to earth. Relay 330 operates and at contact 367 opens the holding circuit of counting relays 211-215 inclusive, causing the same to release. After an interval during which relays 219 and 220 release, contact 279 opens and relay 401 thereupon operates completely.

At this point it may be pointed out that contacts 367 and 425 shunt one another, since the holding conductor 244 is earthed by being connected to conductor 240 over either contact 367 or contact 425. The thousands register is therefore restored to normal when relay 330 operates, due to the dialling of the digit 0, before relay 401 operates at the end of the thousands impulse series. When relay 401 operates after the digit 0 has been dialled, it closes contact 425 to provide a holding circuit for the relays of the thousands register which are operated when revertive impulses are received. Relay 401 also opens the circuit of relay 330 at contact 424 and relay 330 releases after a short interval to reclose the holding circuit at contact 367.

Shortly afterwards, revertive impulses are received by the thousands register, all the relays of which are restored to normal; the first revertive impulse will therefore operate relay 211 and subsequent impulses will operate the relays 212, 213, 214, 215 as previously described. As the number of impulses in the 0 digit is even, relay 210 will not have been operated and contact 283 will be closed so that when nine revertive impulses have been received a circuit will be closed for relay 208 to cause the opening of the fundamental circuit as previously described.

Because the thousands digit has been changed to an odd digit, viz. 7, it will be noted that by reference to the impulse table that an alteration is required in the number of hundreds revertive impulses. Assuming the hundreds digit is 2 then the number of revertive impulses required will be seven instead of eight. Consequently when the seventh revertive impulse from the switch R3 has been registered, relays 321, 322 and 325 will be operated and a circuit is closed for relay 208 as follows: battery, winding of relay 208, conductor 229, contact 459, lower winding of relay 406, contact 433, conductor 246, contact

285, conductor 245, contact 361, contact 378, contact 374, contact 379, conductor 350, contact 458, conductor 232, contact 282 to earth. Relay 208 operates and opens the fundamental circuit and the rotation of the trip spindle is stopped as previously described.

Different conditions again arise if the hundreds digit had been odd e. g. 3, in this case if the thousands digit has been even, it will be seen from the impulse table that eight revertive impulses are required to be sent back before the fundamental circuit is opened. It follows that all the relays 321-325 must be operated before a circuit is completed for relay 208.

Since the hundreds digit is odd, relay 216 will be operated at the end of the impulse series and will remain operated until relay 220 releases. A circuit is completed for relay 320 in the interval as follows: battery, winding of relay 320, conductor 354, contact 426, contact 415, conductor 236, contact 269, contact 277 to earth. Relay 320 operates and completes a locking circuit for itself as follows: battery, winding of relay 320, contact 364, contact 368, conductor 232, contact 282 to earth.

When all the relays 321-325 have been operated a circuit is completed for relay 208 as follows: battery, winding of relay 208, conductor 229, contact 459, lower winding of relay 406, contact 453, conductor 246, contact 377, contact 375, contact 378, contact 374, contact 379, conductor 350, contact 458, conductor 232, contact 282 to earth. Relay 208 operates in this circuit and the rotation of the trip spindle is stopped as previously described.

If the thousands digit has however been odd, relay 210 will have been locked operated, relay 320 will lock operated after the hundreds digit (3) has been registered. Referring to the impulse table it will be seen that seven revertive impulses are required to be sent back before the fundamental circuit is opened, that is, a total of ten impulses must be registered before a circuit is completed for relay 208. Although this condition viz. that relays 321, 322, 324 and 325 shall be operated, is the same as that which arose when the thousands digit was 6 and the hundreds digit was 2, it is satisfied in a different manner. Relays 210 and 320 are in the present case operated and the circuit of relay 208 will therefore extend as follows: battery, winding of relay 208, conductor 229, contact 459, lower winding of relay 406, contact 453, conductor 246, contact 285, conductor 245, contact 362, contact 375, contact 378, contact 374, contact 379, conductor 350, contact 458, conductor 232, contact 282 to earth. Relay 208 operates in this circuit and the rotation of the trip spindle is stopped as previously described.

Apart from the corrections just dealt with, 130

further corrections are necessary when the units revertive impulses are received back; if the hundreds digit has been odd, reference to the impulse table will show that when the units digit is 8, thirteen revertive impulses are required to be received back before the fundamental circuit is opened. At the end of the odd hundreds impulse series relay 320 operates and prepares a circuit for relay 340 at contact 365. When the units digit (8) has been transmitted by the calling subscriber, relays 341, 343 and 345 are operated, the brush carriage of the final selector then rotates and revertive impulses are sent back. When three revertive impulses have been received back by the counting relays 341-345 inclusive, so that eleven impulses are registered thereon, then upon the completion of the third revertive impulse the circuit of relay 340 is completed as follows: battery, winding of relay 340, contact 365, contact 386, contact 385, contact 387, contact 384, contact 388, conductor 232, contact 282 to earth. Relay 340 operates and extends the impulse conductor 360 to the tens counting relays 331-335 inclusive, over contacts 346, 347 and 371.

The revertive impulses then operate the tens counting relays until the required number, viz. 13 has been received back. Since three revertive impulses were required to complete the operation of the units register the remaining ten impulses will operate the tens register and relays 331, 332, 334 and 335 will finally be operated. A circuit is then completed for relay 207 as follows: battery, winding of relay 207, conductor 226, contact 373, contact 380, contact 370, contact 382, contact 383, contact 369, conductor 232, contact 282 to earth. Relay 207 thereupon operates to cause the switch-through of the repeater and release the register as previously described.

A further correction not mentioned above is to be made if the hundreds digit is 0. It will be noted from the table on page 4 that when the hundreds digit is 0 either ten or nine revertive impulses have to be sent back according as to whether the thousands digit is even or odd. It will be recollected that when 0 is dialled for the hundreds digit, ten impulses are sent to the relay set comprising relays 321-325 inclusive, and that at the end of the tenth impulse, relays 321, 322, 324 and 325 are locked operated onto conductor 353. Shortly after the end of the impulse series, relay 219 releases and then before relay 402 has time to operate completely a circuit is completed as follows: battery, winding of relay 413, conductor 238, contact 278, conductor 237, contact 435, conductor 351, contact 376, contact 375, contact 378, contact 374, contact 379, conductor 350, contact 458, conductor 232, contact 282 to earth. Relay 413 energizes and opens con-

tact 391. It will be recollected that the locking circuit for relays 321, 322, 324, 325 extended over conductor 353, contact 491, contact 458, conductor 232, contact 282, to earth; consequently the energization of relay 413 opens this locking circuit and the relays 321, 322, 324 and 325 restore to normal. Hence, when revertive impulses are received from the selector which is to be set in accordance with the hundreds digit counting will begin with relay 321 and it follows that relay 208 will be energized either when ten revertive impulses have been received if the thousands digit was even or when nine revertive impulses have been received if the thousands digit was odd, as determined by the condition of relay 210.

A description will now be given of the operation of setting up special service calls, in which case the repeater D2 (Fig. 16) and the selector R7 (Fig. 17) are taken into use to establish connection to an operator's position (shown in Fig. 18). To set up a special service call the calling subscriber will dial the number 19. By dialling 1 the selector S1 will be operated to select an idle trunk in the first level such as that comprising conductors 116, 117 and 118 extending to the repeater D2, whereupon relay 601 is operated in the following circuit: battery, upper winding of relay 601, conductor 116, wiper 156, contact 145, bank springs 123, conductor 112, subscriber's loop, conductor 111, bank springs 125, contact 150, wiper 158, conductor 118, lower winding of relay 601 to earth.

Relay 601 on energizing at contact 621 completes a circuit for relay 602. Relay 602 on energizing closes contact 624 thereby connecting earth to conductor 117 to hold the selector S1 and line switch C. At contact 626 it prepares a locking circuit for relays 611-615 inclusive which are permanently associated with the repeater D2. The subscriber then dials the second series of impulses which are repeated in D2 over the following circuit: earth, contact 622, contact 625, contact 643 to the relays 611-615 inclusive, and in a branch circuit through the winding of relay 606 to battery. Relay 606 is slow to release and is maintained operated throughout the impulse train, while the relays 611-615 inclusive are operated in a similar manner to that which has already been described in connection with the sets of relays illustrated in Figs. 4 and 5.

On the first impulse a circuit is completed as follows: earth, contact 622, contact 625, contact 643, contact 654, contact 656, contact 657, contact 658, contact 659, upper winding of relay 611 to battery; relay 611 operates partially to close contact 664 only and fully operates at the end of the first impulse in the following circuit: battery, upper and lower windings of relay 611 in series, contact 664,

contact 679, contact 668, contact 657, contact 670, contact 673, contact 678, contact 632, contact 626 to earth.

At the beginning of the second impulse, a circuit may be traced as follows: earth, over contact 654, contact 656, contact 557, contact 558, contact 660, upper windings of relay 612 to battery; relay 612 partially energizes to close contact 666 only, and at the end of the second impulse fully energizes in the following circuit: battery, upper and lower windings of relay 612 in series, contact 666, contact 675, contact 670, contact 673, contact 678, contact 632, contact 626 to earth. Relay 612 on operating opens contact 668, thereby releasing relay 611.

At the beginning of the third impulse, a circuit may be traced as follows: earth, over contact 654, contact 656, contact 657, contact 661, upper winding of relay 613 to battery. Relay 613 partially energizes to close contact 669 only, and at the end of the third impulse energizes completely in the following circuit: battery, upper and lower windings of relay 613 in series, contact 669, contact 673, contact 678, contact 632, contact 626 to earth. Relay 613 operates completely and opens contact 670 thereby releasing relay 612.

At the beginning of the fourth impulse, a circuit can be traced as follows: earth, over contact 654, contact 656, contact 662, upper winding of relay 614 to battery. Relay 614 partially energizes to close contact 671 only and at the end of the fourth impulse fully energizes in the following circuit: battery, upper and lower windings of relay 614 in series, contact 671, contact 678, contact 632, contact 626 to earth. Relay 614 fully energizes and opens contact 673 thereby releasing relay 613.

At the beginning of the fifth impulse a circuit may be traced as follows: earth, over contact 654, contact 663, upper winding of relay 615 to battery. Relay 615 partially energizes to close contacts 676 only and at the end of the fifth impulse fully energizes in the following circuit: battery, upper and lower windings of relay 615 in series, contact 676, contact 632, contact 626 to earth. Relay 615 fully energizes and opens contact 678, thereby releasing relay 614.

At the beginning of the sixth impulse a circuit may be traced as follows; earth, over contact 655, contact 657, contact 658, contact 659, upper winding of relay 611 to battery. Relay 611 partially energizes to close contact 664 only and at the end of the sixth impulse completely energizes in the following circuit: battery, upper and lower windings of relay 611 in series, contact 664, contact 677, contact 632, contact 626 to earth.

At the beginning of the seventh impulse a circuit can be traced as follows: earth over contact 655, contact 657, contact 658, contact 660, upper winding of relay 612 to battery.

Relay 612 partially energizes to close contact 666 only and at the end of the seventh impulse fully energizes in the following circuit: battery, upper and lower windings of relay 612 in series, contact 666, contact 675, contact 670, contact 673, contact 665, contact 632, contact 626 to earth.

At the beginning of the eighth impulse a circuit may be traced as follows: earth over contact 655, contact 657, contact 661, upper winding of relay 613 to battery. Relay 613 partially energizes to close contact 669 only and at the end of the eighth impulse fully energizes in the following circuit: battery, upper and lower windings of relay 613 in series, contact 669, contact 673, contact 665, contact 632, contact 626 to earth. Relay 613 fully energizes and opens contact 670 thereby allowing relay 612 to release.

At the beginning of the ninth pulse a circuit may be traced as follows: earth over contact 655, contact 662, upper winding of relay 614 to battery. Relay 614 partially energizes to close contact 671 only and at the end of the ninth impulse fully energizes in the following circuit: battery, upper and lower windings of relay 614 in series, contact 671, contact 665, contact 632, contact 626 to earth. Relay 614 fully energizes and opens contact 673 thereby releasing relay 613.

Shortly after the end of the ninth impulse, relay 606 de-energizes; contact 640 on being closed completed a partial energizing circuit for the upper winding of relay 608 over contact 645 which was sufficient to close contact 646 only. When relay 606 de-energizes after the series of impulses just described has been received, relay 608 fully energizes in the following circuit: battery, upper and lower windings of relay 608 in series, contact 646, contact 632, contact 626 to earth. Accordingly contacts 643 and 645 are opened and contacts 642 and 644 are closed.

The closure of contact 642 completes a loop across the conductors 636 and 638 so that a circuit may be traced as follows: battery, winding of relay 903 (Fig. 17) contacts F2 and F3 in position 1 of sequence switch SS7, resistance 922, contacts J3 and J2 in position 1 of sequence switch SS7, conductor 638, contact 634, contact 642, winding of relay 607, contact 628, conductor 636, contacts M1 and M2 in position 1 of sequence switch SS7 to earth; relays 903 and 607 energize in this circuit. Relay 607 closes a circuit at contact 641 for the upper winding of relay 612 as follows: earth, contact 641, contact 644, contact 655, contact 657, contact 658, contact 660, upper winding of relay 612 to battery. Relay 612 partially energizes to close contact 666 only but nothing further happens at this time.

Relay 903 on energizing closes a circuit at contact 919 extending as follows: earth, contact 919, contacts C3 and C4 in position 1 of

sequence switch SS7, winding of magnet 904 to battery. The sequence switch accordingly advances in position 2. In this position a circuit is completed for the trip spindle magnet 905 as follows: earth, contact 919, contacts C3 and C2 in position 2, of sequence switch SS7, winding of magnet 905 to battery. Magnet 905 energizes and the trip spindle commences to rotate.

It should be mentioned at this point that the relay 903 on energizing closed contact 908 so that in position 2 it is maintained operated from conductor 638 as follows: battery, winding of relay 903, contact 198, contacts F4 and F3 in position 2 of sequence switch SS7, resistance 922, contacts J3 and J2 in position 2 of sequence switch SS7, conductor 638. When the trip spindle commences to rotate, off-normal contact 909 is closed and contact 910 is intermittently closed. For each intermittent operation of contact 910 relay 607 is caused to de-energize, while relay 903 is maintained operated.

On the first opening of contact 641, relay 612 fully energizes in the following circuit: battery, upper and lower windings of relay 612 in series, contact 636, contact 674, contact 632, contact 626 to earth. When contact 910 opens, relay 607 again energizes and at contact 641 closes a circuit which may be traced as follows: earth, contact 641, contact 644, contact 655, contact 657, contact 661, upper winding of relay 613 to battery. Relay 613 operates partially in this circuit to close contact 669 only. On contact 910 again closing, relay 607 de-energizes and relay 613 now fully energizes in the following circuit: battery, upper and lower windings of relay 613 in series, contact 669, contact 667, contact 672, contact 665, contact 632, contact 626 to earth.

Relay 613 on energizing closes contact 652 whereupon a circuit may be traced for relay 604 as follows: earth, contact 653, contact 652, contact 651, contact 650, winding of relay 604 to battery. Relay 604 accordingly energizes, and closes a locking circuit for itself as follows: battery, winding of relay 604, contact 631, contact 626 to earth. Relay 604 also opens contact 634 thereby disconnecting relay 607, extends the speaking conductors at contacts 633 and 629, and at contact 632 opens the holding circuit of relays 611-615 inclusive, whereupon these relays together with relay 608 restore to normal. Relay 604 also opens contacts 628 and 634 whereupon relay 903 de-energizes and opens a circuit of the trip spindle 905 at contact 919 and completes a circuit as follows: earth, contact 920, contacts B1 and B5 in position 2 of sequence switch SS7, winding of magnet 904 to battery. Magnet 904 energizes and the sequence switch SS7 advances into position 5. Relay 604 also completes a circuit for relay 901 as follows: battery,

winding of relay 901, conductor 637, contact 630, winding of retard 605 to earth.

In this circuit relay 901 which is of high resistance energizes and on energizing closes a circuit as follows: earth, contact 915, contact K3 and K4 in position 5 of sequence switch SS7, contact 916, relay 903 to battery. Relay 903 thereupon energizes and at contact 919 completes the following circuit: earth, contact 919, contacts C3 and C1 in position 5 of sequence switch SS7, winding of magnet 906 to battery.

The brush carriage thereupon commences to rotate and during its rotation a test circuit is completed as follows: test brush 936, contacts H1 and H4 in position 5 of sequence switch SS7, lower winding of relay 902 to earth; so that as soon as an idle line is found such as that comprising conductors 932 and 935 leading to the operator's position shown in Fig. 18, a circuit will be completed as follows: battery, resistance 864, bank contact 937, brush 936, contacts H1 and H4 in position 5 of sequence switch SS7, lower winding of relay 902 to earth.

Relay 902 accordingly energizes, opens the circuit of relay 903 at contact 916 and closes a locking circuit for itself as follows: earth, contact 915, contacts L3 and L4 in position 5 of sequence switch SS7, contact 917, upper winding of relay 902, brush 936, bank contact 937, resistance 864 to battery. As the upper winding of relay 902 is of low resistance the operator's circuit taken into use is thereby guarded.

The de-energization of relay 903 closes the following circuit: earth, contact 920, contacts B1 and B5 in position 5 of sequence switch SS7, winding of magnet 904 to battery; magnet 904 energizes and the sequence switch accordingly advances into position 9. It should be mentioned that a branch circuit extends for the holding magnet 907 as follows: battery, winding of holding magnet 907, contacts B3 and B1 in position 5 of sequence switch SS7, contact 920 to earth. Magnet 907 energizes so that the brush carriage is stopped with the brushes correctly aligned, the correct alignment being ensured by earth on the teeth of the rack 912, brush 913, contacts G1 and G2 in position 5 of sequence switch SS7, winding of relay 903 to battery, so that relay 903 can only be energized when the brushes are correctly aligned.

When the sequence switch passes into position $7\frac{3}{4}$ a circuit is completed as follows: earth, contact 859, winding of relay 851, conductor 935, bank contact 934, brush 933, contacts K3 and K1 in position $7\frac{3}{4}$ of sequence switch SS7, resistance 921, winding of relay 903 to battery. Relay 903 energizes in this circuit but relay 851 being of low resistance does not energize and relay 903 is locked energized in the following circuit: battery, winding of relay 903, contact 918, contacts D3

and D4 in positions 8 to 9 of sequence switch SS7, to earth. Accordingly when the sequence switch reaches position 9, a circuit is completed as follows: earth, contact 919, contacts C3 and C4 in position 9 of sequence switch SS7 winding of magnet 904 to battery.

The sequence switch accordingly advances to position 10, the circuit of relay 903 is opened and this relay de-energizes. In position 10 the following circuit is completed: battery, winding of relay 854, conductor 932, bank contact 931, brush 930, contacts M3 and M1 in position 10 of sequence switch SS7, conductor 636, contact 629, contact 620, upper winding of relay 603 to earth, while another circuit is completed as follows: battery, lower winding of relay 603, contact 633, conductor 638, contacts J2 and J2 in position 10 of sequence switch SS7, brush 933, bank contact 934, conductor 935, winding of relay 851, contact 859 to earth. Relays 851 and 854 accordingly energize.

Relay 851 completes a locking circuit for itself independently of contact 859 as follows: earth, contact 856, contact 863, winding of relay 851, and then over conductor 935 and the previously described circuit of the lower winding of relay 603. Relay 851 completes a circuit for relay 852 as follows: earth, contact 856, upper winding of relay 852 to battery. Relay 852 on energizing completes a circuit for relay 853 as follows: earth, contact 857, winding of relay 853 to battery. Relay 853 energizes and at contact 858 completes a circuit for the lamp 862 as follows: earth, contact 858, contact 861 lamp 862 to battery.

The operator is thereby signalled and on answering operates the answering key AK, thereby extending the conductors 932 and 952 to the speaking set and at the same time closing contact 868 thereby causing the relay 855 to energize and open contact 861 so that the lamp 862 is extinguished. The calling subscriber may now converse with the operator. When the calling subscriber has finished he hangs up his receiver thereby opening the circuit of relay 601. This relay de-energizes and opens contact 620 thereby causing relay 854 to de-energize. Relay 854 on de-energizing completes the following circuit: earth, contact 856, contact 865, lower winding of relay 852 to battery. The magnetic field of relay 852 is thereby neutralized and contact 857 opens so that relay 853 de-energizes shortly after.

Relay 853 is slow to release, as is also relay 852 and consequently in the interval the circuit of relay 851 and the lower winding of relay 603 is open at contacts 863 and 859. Relay 851 accordingly de-energizes so that for an interval conductor 935 is isolated. When the operator restores her answering key the relay 855 de-energizes and the relay group in Fig. 18 is then restored to normal.

Contact 621 also opens when relay 601 releases and after a short interval relay 602 releases and opens the locking circuit of relay 604 at contact 626. Relay 604 releases and at contact 630 opens the circuit of relay 901. Relay 901 thereupon releases and at contact 914 completes the following circuit: earth, contact 914, contacts G3 and G2 in position 10 of sequence switch SS7, winding of relay 903 to battery. Relay 903 energizes and completes the following circuit: earth, contact 919, contacts C3 and C4 in position 10 of sequence switch SS7, winding of magnet 904 to battery. Magnet 904 accordingly energizes and the sequence switch advances out of position 11.

In position 14 the circuit of magnet 904 is maintained as follows: earth, contact 919, contacts B2 and B5 in position 14 of sequence switch SS7, winding of magnet 904 to battery. The sequence switch therefore advances to position 17. When the sequence switch leaves position 14 the circuit of relay 902 is opened at contact D2 and this relay releases. In position 17 a circuit is completed as follows: earth, off-normal contact 909, contacts E3 and E4 in position 17 of sequence switch SS7, contact 916, winding of relay 903 to battery. Relay 903 energizes in this circuit and at contact 919 completes the following circuit: earth, contact 919, contacts C3 and C2 in position 17 of sequence switch SS7, winding of magnet 905 to battery.

The trip spindle magnet 905 energizes in this circuit and the trip spindle accordingly rotates to normal whereupon the circuit of relay 903 is opened at contact 909, and this relay releases. At contact 920 a circuit is completed as follows: earth, contact 920, contacts B1 and B5 in position 17 of sequence switch SS7, winding of magnet 904 to battery; magnet 904 energizes and the sequence switch advances to position 18. In position 18, relay 903 is energized in the following circuit: earth, contacts D4 and D1 in position 18 of sequence switch SS7, contact 916, winding of relay 903 to battery. Relay 903 at contact 919 thereupon completes the following circuit: earth, contact 919, contacts C3 and C1 in position 18 of sequence switch SS7, winding of magnet 906 to battery.

The brush carriage thereupon rotates and when the normal position is reached a circuit is completed as follows: battery, normal contact 911, brush 913, contacts H3 and H4 in position 18 of sequence switch SS7, lower winding of relay 902 to earth. Relay 902 energizes and opens the circuit of relay 903 which then de-energizes and completes the following circuit: earth, contact 920, contacts B1 and B5 in position 18 of sequence switch SS7, winding of magnet 904 to battery. Magnet 904 energizes and the sequence switch advances to position 1, the selector R7

is now restored to normal, as is also the repeater D2.

The circuits of the revertive control systems in some installations differ from those described with reference to Figs. 7, 8 and 9 in that when a subscriber delays to complete a connection the release arrangements for the revertive control intermediate group selector switches corresponding to R3 (Fig. 8) are controlled locally instead of from the register as in the arrangement described.

An example of such an installation will be considered, the incoming second selector being similar to selector R2 while the intermediate and final selectors are shown in Figs. 14 and 15 respectively.

Various modifications have been made in the circuit of the repeater, and the register controller. Fig. 12 shows a modified repeater circuit and Fig. 13 shows modified arrangements for the time pulse relays. The remainder of the circuit in Fig. 13 is the same as that shown in Fig. 5, with the exception of relays 412 and 413 which are now omitted.

To avoid unnecessary duplication of the drawings, Figs. 1, 3, 4 and 6 may be employed as indicated in the layout. The operation of the repeater D1 up to the end of the transmission of impulses into the register is similar to that of repeater D and need not be again described, except to say that relay 209 is energized in the following circuit: earth, contact 1905, upper winding of relay 1165 (which corresponds to relay 165) contact 1182, contact 1187, contact 1193, conductor 171, bank springs 253, winding of relay 209 to battery.

The operation of the register controller proceeds on lines similar to those already described until the closure of the fundamental circuit, which now extends in the register controller from bank springs 250, winding of relay 206, conductor 225, contact 416, conductor 227, contact 263, conductor 223, conductor 222, contact 265, bank springs 251. Selector R2 is then operated as previously described to select a free trunk line such as that comprising conductors 528, 531 and 534 extending to selector R5.

When this occurs a circuit is completed as follows: battery, winding of relay 1552, contacts N2 and N1 in position 1 of sequence switch SS5, conductor 534, bank contact 533, brush 532, contacts F2 and F3 in position 3 of sequence switch SS2, high resistance lower winding of relay 506 to earth. Relay 508 upon operating, completes a circuit for relay 507 in series with its own low resistance upper winding, at contact 521. Relay 507, however, is short-circuited by earth connected over the rack 512 and brush 535, until the brushes are correctly centred on the selected set of contacts.

When the brushes are correctly centred relay 507 operates, and opens the circuit of

magnet 509 and closes the circuit of magnet 511 as previously described, and also completes a circuit for magnet 510 whereupon the sequence switch SS2 passes into position 6. In position 6, relay 506 is short-circuited and releases, relay 507 however remains operated in series with relay 1552. When relay 1552 operates it completes a circuit as follows: earth, contact 1570, contacts B1 and B2 in position 1 of sequence switch SS5, winding of magnet 1555 to battery. Magnet 1555 energizes and the sequence switch SS5 thereupon passes into position 2. Relay 1552 also closes a holding circuit for itself at contact 1568 as follows: battery, winding of relay 1552, contact 1568, conductor 534, brush 532, contacts F2 and F1 in position 6 of sequence switch SS2, winding of relay 507 to earth.

During this time, the subscriber has been dialling the hundreds digit into the register. At the beginning of the series of impulses relay 402 operates partially to close contact 429 only, and at the end of the impulse series operates completely.

When the selector R5 is seized, earth is connected to conductor 528 over contacts Q1 and Q2 in position 1 of sequence switch SS5 and battery is connected to conductor 531 through the winding of relay 1551 and contacts P1 and P2 in position 1 of sequence switch SS5. These connections persist in position 2 and sequence switch SS5 remains in this position until the hundreds digit has been registered, and relay 402 has operated completely, whereupon the fundamental circuit is completed as follows: earth, contacts Q1 and Q2 in position 2 of sequence switch SS5, conductor 528, contact 527, brush 526, contacts O2 and O1 in position 6 of sequence switch SS2, conductor 168, contact 1190, conductor 172, bank spring 250, conductor 221, winding of relay 206, conductor 225, contact 416, conductor 227, contact 263, conductor 223, conductor 222 (which are now joined together) but are shown separate for convenience in tracing the relation between the two sets of circuits, contact 265, bank springs 251, conductor 170, contact 1198, conductor 169, contacts K3 and K2 in position 6 of sequence switch SS2, brush 529, contact 530, conductor 531, contacts P2 and P1 in position 2 of sequence switch SS5, winding of relay 1551 to battery.

Relays 1551 and 206 operate in this circuit. Relay 1551 upon operating, completes a circuit as follows: earth, contact 1566, contacts O1 and O2 in position 2 of sequence switch SS5, winding of magnet 1555 to battery. Magnet 1555 energizes and the sequence switch SS5 thereupon advances out of position 3. In position 4, relay 1551 remains operated and the sequence switch SS5 advances into position 5.

In position 5, a circuit is completed for

magnet 1556 as follows: battery, winding of magnet 1556, contacts F2 and F3 in position 5 of sequence switch SS5, contact 1566 to earth.

- 5 The trip spindle thereupon rotates together with the interrupter 1559, off-normal contact 1563 is closed and contact 1564 closes intermittently. For each step taken by the trip spindle, earth is connected to the lower 10 speaking conductor over the following circuit: earth, contact 1563, contact 1564, contacts G1 and G2 in position 5 of sequence switch SS5, contacts P1 and P2 in position 5 of sequence switch SS5 to conductor 531. 15 Relay 1551 is maintained operated by this earth and relay 206 in the register controller is intermittently short circuited.

When relay 206 first operates, contact 257 is closed, and a circuit is completed for the 20 upper winding of the next relay in the hundreds register dependent upon the value of the digit dialled by the calling subscriber, and when relay 206 releases owing to the short circuit, this relay in the hundreds register operates completely. This operation continues until the hundreds register has been completely set by revertive impulses whereupon a circuit is completed for relay 208 as previously described, and this relay 25 operates to open the fundamental circuit at contact 263.

When the fundamental circuit is opened, relay 1511 releases and a circuit is completed as follows: earth, contact 1567, contacts O3 35 and O2 in position 5 of sequence switch SS5, winding of magnet 1555 to battery. Magnet 1555 energizes and the sequence switch SS5 thereupon passes into position 6. It will be noted at this point that battery is not connected to the upper speaking conductor and relay 205 is therefore not operated. A locking circuit is, however, completed for relay 208 as follows: battery, winding of relay 208, contact 264, conductor 230, contact 441, contact 457, conductor 232, contact 282 to earth. This locking circuit is dependent upon relay 403 only, and does not depend upon the operation of the revertive control selector as in the example previously described.

- 50 When the sequence switch SS5 reaches position 6, a circuit is completed for relay 1551 as follows: battery, winding of relay 1551, contacts G2 and G3 of sequence switch SS5 in position 6, off-normal contact 1563 to earth. 55 A circuit is also completed for the brush carriage magnet 1557 as follows: battery, winding of magnet 1557, contacts E1 and E2 in position 6 of sequence switch SS5, contact 1573 to earth. The brush carriage is thereupon set in rotation, the set of selected brushes are released, and moved over a corresponding level of bank contacts.

When an idle trunk leading to a final selector is encountered, such as the trunk comprising conductors 1578, 1571 and 1574 leading

to the selector R6 shown in Fig. 15, a circuit is completed as follows: battery, winding of relay 1603, contacts L2 and L3 in position 1 of sequence switch SS6, conductor 1574, bank contact 1573, brush 1572, contacts H1 and H2 in position 6 of sequence switch SS5, upper high resistance winding of relay 1553 to earth. 70

It will be noted that relay 1603 is shunted by resistance 1627 connected over contacts M2 and M3 in positions 1-4 of sequence switch SS6, and the value of this resistance is adjusted so that relay 1553 will energize in the circuit of relay 1603 when shunted by resistance 1627, and will remain operated 80 over its low resistance lower winding.

Relays 1603 and 1553 operate in this circuit, relay 1603 closes a holding circuit for itself at contact 1614 and relay 1553 completes a circuit as follows: battery, winding of low resistance relay 1554, contact 1571, low resistance lower winding of relay 1553, contacts K2 and K1 in position 6 of sequence switch SS5, brush 1572, bank contact 1573, conductor 1574, contact 1614, contacts M3 and M2 in 85 position 1 of sequence switch SS5, resistance 1627 to battery. Relay 1554 however is short-circuited by earth connected over rack 1560 and brush 1562 until the brushes are correctly centred on the selected bank contacts, 90 whereupon relay 1554 operates and opens the circuit of the brush carriage magnet 1557 at contact 1573.

A circuit is also completed for the holding magnet 1558 as follows: battery, winding of 100 magnet 1558, contacts D2 and D3 in position 6 of sequence switch SS5, contacts C2 and C1 in position 6 of sequence switch SS5, contact 1574 to earth. A parallel circuit is also closed for magnet 1555 as follows: battery, 105 winding of magnet 1555, contacts C2 and C1 in position 6 of sequence switch SS5, contact 1574 to earth. Magnet 1555 energizes and the sequence switch SS5 advances from position 6, and the above circuit is maintained 110 in position 8 the sequence switch advances into position 9. In position 9 the circuit for relays 1553 and 1554 is opened, at contacts K1 and K2, relay 1553 releases, but relay 1554 is maintained operated over the following 115 circuit: battery, resistance 1627, contacts M1 and M2 in position 1 of sequence switch SS6, contact 1614, conductor 1574, bank contact 1573, brush 1572, contacts L3 and L2 in position 9 of sequence switch SS5, contact 1572, 120 winding of relay 1554 to earth.

In position 9 the speaking conductors are connected through and provided that the tens digit has been registered, the fundamental circuit is completed as follows: earth, contacts T1 and T2 in position 1 of sequence switch SS5, conductor 1578, bank contact 1577, brush 1576, contacts Q3 and Q2 in position 9 of sequence switch SS5, conductor 528, bank contact 527, brush 526, contacts O2 and 125

- 5 O1 in position 6 of sequence switch SS2, conductor 168, contact 1190, conductor 172, bank springs 250, winding of relay 206, conductor 225, contact 416, conductor 227, contact 263, conductor 223, conductor 222, contact 265, bank springs 251, conductor 170, contact 1198, conductor 169, contacts K3 and K2 in position 6 of sequence switch SS2, brush 529, bank contact 530, conductor 531, contacts 10 P2 and P3 in position 9 of sequence switch SS5, brush 1579, bank contact 1570, conductor 1571, contacts Q2 and Q3 in position 1 of sequence switch SS6, winding of relay 1602 to battery. Relays 1602 and 206 operate in this circuit.

- 15 When relay 1602 operates it completes a circuit as follows: earth, contact 1610, contacts C2 and C1 in position 1 of sequence switch SS6, winding of magnet 1606 to battery. Magnet 1606 energizes and the sequence switch SS6 advances into position 2. In position 2, a circuit is completed for the trip spindle magnet 1607 as follows: battery, winding of magnet 1607, contacts D2 and D3 20 in position 2 of sequence switch SS6, contact 1610 to earth. Magnet 1607 energizes, whereupon the trip spindle and its interrupter 1630 are rotated. When the interrupter 1630 leaves its home position off-normal contact 1629 is closed and contact 1628 closes on each step taken by the trip spindle.

- 25 Earth is thereby intermittently connected to the lower speaking conductor over the following circuit: earth contact 1629, contact 1628, contacts J2 and J1 in position 2 of sequence switch SS6, contacts Q1 and Q2 in position 2 of sequence switch SS6, to the lower speaking conductor 1571. Relay 1602 is maintained energized by this earth, and 30 relay 206 in the register controller is intermittently short-circuited.

- 35 When the tens register has been completely set by revertive impulses, relay 208 operates as previously described, and opens the fundamental circuit at contact 263. Battery and earth are connected to the speaking conductors over contacts 262 and 258 but without effect in the present connection. Relay 208 closes a locking circuit for itself as follows: battery, winding of relay 208, contact 264, conductor 230, contact 445, contact 464, conductor 232, contact 282 to earth. This locking circuit is dependent upon relay 404 and is opened when the units digit has been 40 registered by the calling subscriber.

- 45 When the fundamental circuit is opened relay 1602 releases and completes a circuit as follows: earth, contact 1611, contact 1616, contacts F2 and F1 in position 2 of sequence switch SS6, winding of magnet 1606 to battery. Magnet 1606 energizes and the sequence switch SS6 advances into position 3.

- 50 When the units register has been set by the calling subscriber, relay 208 releases and the fundamental circuit is completed as follows:

55 earth, contacts T1 and T2 in position 3 of sequence switch SS6, conductor 1578, bank contact 1577, brush 1576, contacts Q3 and Q2 in position 9 of sequence switch SS5, conductor 528, bank contact 527, brush 526, contacts O2 and O1 in position 6 of sequence switch SS2, conductor 168, contact 1190, conductor 172, bank springs 250, winding of relay 206, conductor 225, contact 416, conductor 227, contact 263, conductor 223, conductor 222, contact 265, bank springs 251, conductor 170, contact 1198, conductor 169, contacts K3 and K2 in position 6 of sequence switch SS2, brush 529, bank contact 530, conductor 531, contacts P2 and P3 in position 9 of sequence switch SS5, brush 1579, bank contact 1570, conductor 1571, contacts Q2 and Q3 in position 3 of sequence switch SS6, winding of relay 1602 to battery.

60 Relay 1602 operates and completes the following circuit: earth, contact 1610, contacts C2 and C1 in position 3 of sequence switch SS6, winding of magnet 1606 to battery. Magnet 1606 energizes and the sequence switch SS6 advances into position 4. In position 4 a circuit is completed for the brush carriage magnet 1608 as follows: battery, winding of magnet 1608, contacts C3 and C2 in position 4 of sequence switch SS6, contact 1610 to earth. The brush carriage accordingly rotates and the selected set of brushes are moved over their corresponding bank contacts. The interrupter 1633 is also brought into operation and for each step taken by the brush carriage contact 1631 is closed and 65 earth thereby connected to the lower speaking conductor in the same manner as when the trip spindle rotated. Relay 1602 is maintained operated and relay 206 in the register controller is short-circuited intermittently as 70 previously described.

75 When the units register has been completely set by revertive impulses a circuit is completed for relay 207 as follows: battery, winding of relay 207, conductor 226, contact 366, contact 386, contact 385, contact 387, contact 384, contact 388, conductor 232, contact 282 to earth. It is assumed that in the case described the hundreds digit is even and consequently contact 366 is closed. As the operation of relay 207 has been previously described when the hundreds digit is odd and when it is even no description will be given now of the case in which the hundreds digit is odd as the circuits may be readily traced 80 by those versed in the art.

85 Relay 207 operates and opens the fundamental circuit at contact 265, whereupon the movement of the brush carriage is arrested as will be described later. Relay 207 also closes the following circuit: earth, contact 259, bank springs 252, conductor 199, contact 1181, contact 1194, contact 1177, contact 1192, winding of relay 1167 to battery. Relay 1167 operates 90 and closes a locking circuit for itself as follows:

lows: battery, winding of relay 1167, contact 1193, contact 1180 to earth. Relay 1167 opens contact 1196 and thereby removes earth from magnet 204 and relay 209; plunger magnet 204 accordingly releases and allows the bank springs 250, 251, 252 and 253 to separate and release the register while relay 209 allows the locked up relays in the register to restore to normal so that it may now be taken into use for another call. Relay 1167 also disconnects conductors 170 and 172 at contacts 1198 and 1199 respectively, and connects the speaking conductors of repeater D1 to the trunk line conductors 168 and 169 at contacts 1189 and 1197 respectively.

Returning now to the final selector R6, when the fundamental circuit is opened at contact 265, relay 1602 releases and completes a circuit as follows: earth, contact 1611, contact 1616, contacts F2 and F1 in position 4 of sequence switch SS6, winding of magnet 1606 to battery. A branch of this circuit extends over contacts B2 and B3 winding of holding magnet 1609 to battery, so that the brush carriage is stopped with the brushes on the line of the wanted subscriber. Magnet 1606 energizes and the sequence switch SS6 advances from position 4.

It will first of all be assumed that the line 30 of the called subscriber is idle. When the sequence switch SS6 leaves position 4, resistance 1627 which has hitherto been shunted across relay 1603 is disconnected at contact M2 and relay 1554 in the selector R5 thereupon releases. A circuit is then completed as follows: earth, contact 1573, contacts E2 and E3 in position 9 of sequence switch SS5, winding of magnet 1555 to battery. Magnet 1555 energizes and the sequence switch SS5 35 advances from position 9.

In position 11, if relay 1554 remains de-energized, the above circuit is maintained and the sequence switch SS5 passes through position 11 and stops in position 12.

45 It should be mentioned that in position 9 the brush 1572 was connected to earth in the following branch circuit: contacts J1 and J2 in position 9 of sequence switch SS5, resistance 1575, contact 1570 to earth, and in position 11 relay 1554 is disconnected and relay 1603 in the final selector is maintained energized over this branch circuit including resistance 1575. In position 12 the homing circuit for the trip spindle of the selector R5 50 is completed as follows: battery, winding of magnet 1556, contacts F2 and F1 in position 12 of sequence switch SS5, off-normal contact 1563 to earth. The trip spindle thereupon rotates until it reaches its home position and contact 1563 is opened.

When sequence switch SS5 leaves position 55 11, resistance 1565 which has hitherto been shunted across relay 1552 is disconnected at contacts M2 and M1 and relay 507 in selector R2 releases. A circuit is then completed as

follows: earth, contact 523, contacts D2 and D1 in position 6 of sequence switch SS2, winding of magnet 510 to battery. Magnet 510 energizes and the sequence switch SS2 advances out of position 6.

When the sequence switch SS2 arrives at position 7, a circuit is completed for relay 503 as follows: earth, lower winding of relay 1166, of repeater D1, contact 1195, contact 1177, contact 1191, conductor 168, contacts N1 and N2 in position 7 of sequence switch SS2, winding of retard 502, high resistance upper winding and low resistance lower winding of relay 503 in series, contacts J3 and J2 in position 7 of sequence switch SS2, conductor 169, contact 1197, upper winding of relay 1166 to battery. Relay 503 operates in this circuit and closes contact 517 but the windings of relay 1166 are of comparatively low resistance, and this relay does not operate in series with the high resistance winding of relay 503.

In position 7 a homing circuit is completed for the trip spindle as follows: battery, winding of magnet 508, contacts G2 and G3 in position 7 of sequence switch SS2, off-normal contact 525 to earth. The trip spindle thereupon rotates until it reaches its home position and contact 525 is opened. Sequence switch SS2 continues to advance until it reaches position 9. The sequence switch SS2 remains in this position during the conversation and current is fed to the line of the called subscriber as follows: earth is connected to the upper speaking conductor, from earth, contact 517, winding of retard 501, contacts O3 and O2 in position 9 of sequence switch SS2, to the upper speaking conductor. Battery is connected to the lower speaking conductor as follows: battery, winding of relay 504, contacts K1 and K2 in position 9 of sequence switch SS2, to the lower speaking conductor.

Returning now to the final selector R6 it will be remembered that sequence switch SS6 has just left position 4. When the sequence switch SS6 reaches position 5, a circuit is completed as follows: battery, winding of relay 1602, contacts K3 and K2 in position 5 of sequence switch SS6 to earth. Relay 1602 operates and is maintained operated in this circuit until position 6 is reached. In position 6 a circuit is completed for magnet 1606 as follows: earth, contact 1610, contacts C2 and C1 in position 6 of sequence switch SS6, winding of magnet 1606 to battery. Magnet 1606 remains energized therefore and the sequence switch SS6 continues to advance.

When sequence switch SS6 reaches position 7 a circuit is prepared as follows: bank contact 1641, brush 1640, high resistance upper winding of relay 1604, contacts G1 and G2 in position 7 of sequence switch SS6 to earth. The line of the wanted subscriber is therefore tested, and if this line is idle, a cir-

cuit will be completed as follows: earth, contacts G2 and G1 in position 7 of sequence switch SS6, high resistance upper winding of relay 1604, brush 1640, bank contact 1641, conductor 805, winding of relay 802 to battery.

Relays 802 and 1604 operate in this circuit and relay 802 upon operating disconnects the line relay 801 from the wanted subscriber's line at contacts 806 and 807. When relay 1604 operates, its circuit is changed to include relay 1605 as follows: bank contact 1641, brush 1640, low resistance lower winding of relay 1604, contact 1615, winding of low resistance relay 1605, contact 1612 to earth. In this connection it will be noted that although relay 1554 of selector R5 is released owing to the disconnection of resistance 1627 in selector R6, relay 1603 of selector R6 has remained operated over contacts 1614 and 1570.

When relay 1605 operates (and releases owing to relay 1602 having released due to the opening of the fundamental circuit) a circuit is completed as follows: earth, contact 1611, contact 1617, contacts E2 and E3 in positions 6—11 of sequence switch SS6, winding of magnet 1606 to battery. The circuit of relay 1606 is therefore maintained in positions 10 and 11 and the sequence switch SS6 accordingly advances into position 12.

In this position, ringing current is connected to the selected line, by ringing current generator, contacts O1 and O2 in position 12 of sequence switch SS6, brush 1638, bank contact 1639, conductor 804, subscriber's loop, conductor 803, bank contact 1637, brush 1636, contacts S2 and S3 in position 12 of sequence switch SS6, winding of relay 1601 to battery.

A small portion of the ringing current is also fed back to the calling subscriber over contacts S2 and S3 in position 12 of sequence switch SS6, contacts R2 and R3 in position 12 of sequence switch SS6, winding 1624, condenser 1625, contacts Q1 and Q2 in position 12 of sequence switch SS6, conductor 1571, and then over the lower speaking conductor to the calling subscriber.

In position 12 a homing circuit is also completed for the trip spindle as follows: battery, winding of magnet 1607, contacts D2 and D1 in position 12 of sequence switch SS6, off-normal contact 1629, to earth. The trip spindle thereupon rotates until it reaches its home position, and contact 1629 is opened. Interrupter 1635 closes its contact to earth for one second in each fifteen and a circuit is completed for relay 1602 as follows: battery, winding of relay 1602, contacts H2 and H3 in position 12 of sequence switch SS6, interrupter 1635 to earth.

Relay 1602 operates and completes a circuit for magnet 1606 as follows: earth, contact 1610, contacts C2 and C1 in position 12 of sequence switch SS6, winding of magnet

1606 to battery. Magnet 1606 energizes and the sequence switch advances into position 13. In position 13, the circuit of relay 1602 is opened, and this relay releases. Interrupter 1626 operates in a similar manner to interrupter 1635 and closes a circuit for relay 1602 as follows: battery, winding of relay 1602, contacts N2 and N1 in position 13 of sequence switch SS6, interrupter 1626 to earth.

Relay 1602 operates and completes a circuit as follows: earth, contact 1610, contacts C2 and C1 in position 13 of sequence switch SS6, winding of magnet 1606 to battery. Magnet 1606 energizes and the sequence switch SS6 passes into position 14. When the sequence switch leaves position 13, the circuit of relay 1602 is opened at contacts N1 and N2 and this relay releases. Intermittent ringing is connected up over contacts P3 and P2 in position 14 of sequence switch SS6, due to the interrupter which for $1\frac{1}{2}$ seconds every 4—5 seconds sends ringing current to the called subscriber, and in the interval connects contact P3 to earth.

Ringing current is fed to the wanted subscriber in the following circuit: intermittent ringing generator, contacts P3 and P2 in position 14 of sequence switch SS6, brush 1638, bank contact 1639, conductor 804, through the subscriber's condenser and bell in series, conductor 803, bank contact 1637, brush 1636, contacts S2 and S3 in position 14 of sequence switch SS6, winding of relay 1601 to battery. A small portion of the ringing current is also sent back to the calling subscriber over a circuit connected in parallel from contacts S2 and S3 in position 14 of sequence switch SS6, contacts R3 and R2 in position 14 of sequence switch SS6, winding 1624, condenser 1625, contacts Q1 and Q2 in position 14 of sequence switch SS6, and thence over the lower speaking conductor to the calling subscriber's instrument.

When the called subscriber removes his receiver, either in the continuous or in the intermittent ringing or in the silent period, a circuit is completed for relay 1601 as follows: battery, winding of relay 1601, contacts S3 and S2 in position 12—14 of sequence switch SS6, brush 1636, bank contact 1637, conductor 803, subscriber's instrument, conductor 804, bank contact 1639, brush 1638, and thence either over contacts O2 and O1 in position 12—13 of sequence switch SS6, or contacts P2 and P3 in position 14 of sequence switch SS6 to earth. Relay 1601 operates and completes a circuit as follows: earth, contact 1609, contacts C2 and C1 in position 14 of sequence switch SS6, winding of magnet 1606 to battery. Magnet 1606 energizes and the sequence switch SS6 advances into position 15.

It will be remembered that sequence switch SS2 is now in position 9, and sequence switch SS5 is in position 12. A circuit is then com-

pleted for relay 504 in selector R2, as follows: battery, winding of relay 504, contacts K1 and K2 in position 9 of sequence switch SS2, brush 529, bank contact 530, conductor 531, contacts P2 and P3 in position 12 of sequence switch SS5, brush 1579, bank contact 1570, conductor 1571, contacts P1 and P2 in position 15 of sequence switch SS6, brush 1638, bank contact 1639, conductor 804, subscriber's instrument, conductor 803, bank contact 1637, brush 1636, contacts S2 and S1 in position 15 of sequence switch SS6, conductor 1578, bank contact 1577, brush 1576, contacts Q3 and Q2 in position 12 of sequence switch SS5, conductor 528, bank contact 527, brush 526, contacts O2 and O3 in position 9 of sequence switch SS2, winding of retard 501, contact 5-7 to earth.

Relay 504 operates in this circuit, and short-circuits the high resistance upper winding of relay 503 at contact 518. Relay 1166 in the repeater E1 then operates in the following circuit: battery, upper winding of relay 1166, contact 1197, conductor 169, contacts J2 and J3 in position 9 of sequence switch SS2, low resistance lower winding of relay 503, contact 518, winding of retard 502, contacts N2 and N1 in position 9 of sequence switch SS2, conductor 168, contact 1191, contact 1177, contact 1167, lower winding of relay 1166 to earth.

Relay 1166 upon operating, completes a circuit for relay 1161 at contact 1188; relay 1161 operates and reverses the battery connections to the speaking conductors, battery being now connected to the lower speaking conductor 115, over contact 1176, and earth being connected to the upper speaking conductor 113 over contact 1174. This reversal of current may be utilized, to effect a metering or similar operation in the usual manner. The subscribers may now converse and at the end of the conversation replace their receivers.

If the called subscriber hangs up first relay 504 releases and the high resistance winding of relay 503 is again connected in circuit and relay 1166 releases. The battery connections are then again restored to normal, but the remainder of the connection remains unaltered until the calling subscriber hangs up. When the calling subscriber hangs up the circuit of line relay 1162 is opened, and this relay releases to open the circuit of relay 1163 which in turn releases after a short interval.

When relay 1163 releases, contact 1180 is opened and earth is removed from conductor 114, and the preceding step-by-step selector releases as previously described. The locking circuit of relay 1167 is also opened at contact 1180, and this relay releases to allow contacts 1191 and 1197 to open. Conductors 168 and 169 are thereby disconnected at the step-by-step exchange and relay 503 releases. A circuit is thereby completed for relay 505 as

follows: earth, contact 516, contacts M3 and M2 in position 9 of sequence switch SS2, winding of relay 505 to battery. Relay 505 operates and closes a circuit as follows: earth, contact 519, contacts B3 and B2 in position 9 of sequence switch SS2, winding of magnet 510 to battery. Magnet 510 energizes and the sequence switch SS2 advances into position 11. When the sequence switch leaves position 9, the circuit of relay 505 is opened and this relay releases. In position 11, a circuit is completed for the brush carriage magnet 509 as follows: battery, winding of magnet 509, contacts D3 and D2 in position 11 of sequence switch SS2, contact 523 to earth.

The brush carriage thereupon rotates until it reaches its normal position when a circuit is completed for relay 507 as follows: earth, winding of relay 507, brush 535, home contact 536, contacts E1 and E2 in position 11 of sequence switch SS2, winding of holding magnet 511 to battery. Relay 507 and holding magnet 511 operate in this circuit, magnet 511 brings the brush carriage to rest in its home position, and relay 507 completes a circuit as follows: earth, contact 522, contacts C3 and C2 in position 11 of sequence switch SS2, winding of magnet 510 to battery. Magnet 510 energizes and the sequence switch SS2 advances into position 1. The circuits of relays 507 and magnet 511 are opened as soon as the sequence switch passes out of position 11. The repeater D1 and the selector R2 have now restored to normal and may be taken into use for another call.

While selector R2 has been releasing similar operations have been taking place in the selector R5. When sequence switch SS2 left position 9, and the circuit of relay 1552 in the selector R5 was opened at contact F2, relay 1552 released and completed a circuit as follows: earth, contact 1569, contacts B3 and B2 in position 12 of sequence switch SS5, winding of magnet 1555 to battery. Magnet 1555 energizes and sequence switch SS5 advances into position 14.

In position 14 a circuit is completed for the brush carriage magnet as follows: battery, winding of magnet 1557, contacts E1 and E2 in position 14 of sequence switch SS5, contact 1573 to earth. The brush carriage thereupon rotates until it reaches its home position, whereupon a circuit is completed as follows: battery, winding of relay 1554, brush 1562, home contact 1561, contacts D1 and D2 in position 14 of sequence switch SS5, winding of magnet 1558 to battery. Magnet 1558 and relay 1554 operate in this circuit, and the holding magnet arrests the brush carriage in its home position.

Relay 1554 upon operating, completes a circuit as follows: earth, contact 1574, contacts C1 and C2 in position 14 of sequence switch SS5, winding of magnet 1555, to battery. Magnet 1555 energizes and the sequence

switch SS5 advances into position 1. When the sequence switch leaves position 14 the circuit of relay 1554 and magnet 1556 is opened, and when the sequence switch reaches position 5, selector R5 is completely restored to normal and may be taken into use for another call.

While selectors R2 and R5 have been releasing, similar operations have been taking place in the final selector R6. When relay 1552 in selector R5 releases, the circuit of relay 1603 in selector R6 is opened at contact 1570, and relay 1603 releases. A circuit is thereupon completed as follows: earth, contact 1613, contacts B1 and B2 in position 15 of sequence switch SS6, winding of magnet 1606 to battery. Magnet 1606 energizes and the sequence switch SS6 advances into position 17.

It may be noted at this point that if the 20 called subscriber has not yet hung up, relay 1601 would be operated in position 16 in the following circuit: battery, winding of relay 1601, resistance 1618, contacts O8 and O2 in position 16 of sequence switch SS6, brush

25 1638, bank contact 1639, conductor 804, subscriber's instrument, conductor 803, bank contact 1637, brush 1636, contacts S2 and S1 in position 16 of sequence switch SS6, contacts T2 and T1 in position 16 of sequence 30 switch SS6, to earth; and relay 1601 remains operated in position 17 and closes a circuit as follows: earth, contact 1609, contacts L1 and L2 in position 17 of sequence switch SS6, winding of relay 1603 to battery. Relay 1603 35 energizes and opens the circuit of magnet 1606 at contact 1613, and the sequence switch is stopped in position 17.

When the called subscriber hangs up relay 1601 releases and opens the circuit of relay 1603 and the circuit of magnet 1606 is closed in position 17 as follows: battery winding of magnet 1606, contacts B2 and B1 in position 17 of sequence switch SS6, contact 1613 to earth. Magnet 1606 energizes and 45 the sequence switch advances into position 18. When the sequence switch SS6 leaves position 17, a circuit of relay 1605 is opened at contact G1 and relays 1605 and 1604 release. Relay 802 therefore releases and relay 50 801 is again connected to the subscriber's loop at contacts 806 and 807, and the subscriber at sub-station B may then either receive or initiate another call.

When the sequence switch SS6 reaches 55 position 18 a circuit is completed for magnet 1608 as follows: battery, winding of magnet 1608, contacts F3 and F2 in position 18 of sequence switch SS6, contact 1616, contact 1611, to earth. The brush carriage 60 thereupon rotates until it reaches its home position, whereupon a circuit is completed for relay 1602 as follows: battery, winding of relay 1602, contacts H2 and H1 in position 18 of sequence switch SS6, home contact 1634, brush 1632 to earth.

Relay 1602 operates in this circuit and completes a circuit for magnet 1606 and holding magnet 1609 as follows: earth, contact 1610, contacts C2 and C1 in position 18 of sequence switch SS6, winding of magnet 1606 70 to battery. A branch of this circuit extends over contacts B2 and B3 in position 18 of sequence switch SS6, winding of magnet 1609 to battery. Magnet 1606 energizes and the sequence switch SS6 advances into position 75 1, whereupon relay 1602 and magnet 1609 de-energize, the selector R6 is restored to normal, and may be taken into use for another call.

It will now be assumed that the called 80 subscriber is busy; in which case relay 1605 will not be energized when the brush 1604 engages with contact 1640, and the sequence switch SS6 stops in position 10. In this position a circuit is completed as follows: 85 earth, interrupter 1619, windings of busy tone transformer 1621 and 1623, contacts M1 and M2 in position 10 of sequence switch SS6, resistance 1627 to battery.

Busy tone is induced in the windings 90 1622 and 1624, the upper winding being connected to the upper speaking conductor over contacts T3 and T2 in position 10 of sequence switch SS6, and the lower winding being connected through condenser 1625 and contacts Q1 and Q2 in position 10 of sequence switch SS6 to the lower speaking conductor. Battery is intermittently connected in the following circuit: battery, interrupter 1620, contacts R1 and R2 in position 10 of sequence 95 switch SS6, winding 1622, contacts T3 and T2 in position 10 of sequence switch SS6, conductor 1578, bank contact 1577, brush 1576, contacts Q3 and Q2 in position 11 of sequence switch SS5, conductor 528, bank 105 contact 527, brush 526, contacts O2 and O3 in position 9 of sequence switch SS2, winding of relay 501, contact 517 to earth. Relay 501 intermittently short-circuits the upper winding of relay 503 at contacts (not shown) 110 and relays 1166 and 1161 in the repeater D1 also release intermittently.

This serves, in the case of a call being set up by an operator, to give a visual busy signal 115 at her position. In the present case, however, the calling subscriber hears the busy tone and replaces his receiver and the repeater D1 restores to normal as previously described, and is followed by the release of selector R2 and selector R5, as previously 120 described. When the sequence switch SS5 leaves position 12 the circuit of relay 1603 is opened at contact J1 in position 12 of sequence switch SS5, and relay 1603 releases. A circuit is then completed for magnet 1606 125 as follows: earth, contact 1613, contacts B1 and B2 in position 10 of sequence switch SS6, winding of magnet 1606 to battery. Magnet 1606 energizes and the sequence switch leaves position 10.

In position 11 a circuit is completed for the brush carriage magnet 1608 as follows: battery, winding of magnet 1608, contacts F3 and F2 in position 11 of sequence switch SS6, contact 1616, contact 1611 to earth. Magnet 1608 energizes and the brush carriage rotates until it reaches its home position, whereupon a circuit is completed as follows: earth, brush 1632, home contact 1634, contacts H1 and H2 in position 11 of sequence switch SS6, winding of relay 1602 to battery. Relay 1602 operates, opens the circuit of magnet 1608 at contact 1611 and completes a circuit for the holding magnet 1609 as follows: earth, contact 1610, contacts C2 and C1 in position 11 of sequence switch SS6, contacts B2 and B3 in position 11 of sequence switch SS6, winding of magnet 1609 to battery. Magnet 1609 energizes and holds the brush carriage in its home position. A parallel circuit is simultaneously completed for magnet 1606 over contacts C2 and C1 in position 11 of sequence switch SS6, and sequence switch SS6 accordingly advances into position 12.

In position 12 a circuit is completed for magnet 1606 as follows: earth, contact 1613, contacts B1 and B2 in position 12 of sequence switch SS6, winding of magnet 1606 to battery. This circuit is maintained closed until sequence switch SS6 reaches position 17, and the sequence switch therefore continues to advance until position 18 is reached.

In position 18 a circuit is completed for relay 1602 as follows: battery, winding of relay 1602, contacts H2 and H1 in position 18 of sequence switch SS6, home contact 1634, brush 1632 to earth. Relay 1602 operates and completes a circuit as follows: earth, contact 1610, contacts C2 and C1 in position 18 of sequence switch SS6, winding of magnet 1606 to battery. Magnet 1606 energizes and the sequence switch SS6 advances into position 1, relay 1602 releases and the selector R6 is restored to normal and may be taken into use for another call.

Consideration will now be given to the release under special conditions such as the subscriber delaying to complete the dialling of a wanted subscriber's number and the subscriber hanging up his receiver before completing the dialling of a wanted subscriber's number. In the first case if the subscriber delays to dial, the release of the register controller is controlled by time pulses. When the register controller is taken into use, relay 209 operates and at contact 281 connects up a timing device to conductor 231 so that a momentary earth is connected to conductor 231 at intervals of, say 30 seconds.

If the subscriber should delay to dial after having seized the register controller, an interval of up to 30 seconds may elapse and the earth will be connected to conductor 231 and a circuit completed as follows: earth, con-

tact 281, conductor 231, contact 1470, contact 1467, upper winding of relay 1408 to battery. Relay 1408 operates partially to close contact 1469 only, and when earth is removed from conductor 231, relay 1408 operates completely in the following circuit: battery, upper and lower windings of relay 1408 in series, contact 1469, contact 1473, contact 1481, conductor 233, contact 275, contact 282 to earth. 70

After another interval has elapsed and earth is again connected to conductor 231 then if the calling subscriber still delays to dial a circuit is completed as follows: earth, contact 281, conductor 231, conductor 1470, contact 1468, upper winding of relay 1409 to battery. Relay 1409 operates partially to close contact 1472 only, and when earth is removed from conductor 231, relay 1409 operates completely in the following circuit: battery, upper and lower windings of relay 1409 in series, contact 1472, contact 1481, conductor 233, contact 275, contact 282 to earth. Relay 1409 upon operating opens contact 1473 to release relay 1408. 75

It may be noted at this point that if the subscriber at any time during these periods resumes the transmission of impulses to the register controller, relay 219 is operated, opening contact 275, and either relay 1408 or 80

1409 will release, if either has been operated. 95

If, however, the subscriber still delays to dial and earth is again connected up, a circuit is completed as follows: earth, contact 281, conductor 231, contact 1471, upper winding of relay 1410 to battery. Relay 1410 operates partially to close contact 1479 only, and when earth is again removed from conductor 231, relay 1410 operates completely in the following circuit: battery, upper and lower windings of relay 1410 in series, contact 1479, conductor 232, contact 282 to earth. 100

Relay 1410 remains locked onto this conductor until the register controller is released, and is not affected if digits are now dialled into the register controller. At contact 1481, relay 1410 opens the locking circuit of relay 1409, and this relay releases, relay 1410 also completes the following circuit: battery, low resistance 1488, contact 1477, contact 1485, conductor 228, contact 261, bank springs 253, conductor 171, contact 1196, contact 1187, contact 1182, low resistance upper winding of relay 1165, contact 1905 to earth. 115

The current flow through the upper winding of relay 1165 is increased sufficiently to cause this relay to operate and to close contact 1186. Relay 1165 thereupon operates fully in the following circuit: battery, lower winding of relay 1165, contact 1186, contact 1905 to earth. Relay 1165 opens contact 1187 thereby disconnecting earth through its low resistance upper winding from conductor 171. Plunger magnet 204 thereupon de-energizes and allows the pairs of bank springs 120

125

130

250, 251, 252 and 253 to open and disconnect the register controller. Relay 209 also releases and at contact 282 removes earth from conductor 232 whereupon all the locked operated relays in the register controller release and it may now be taken into use for another call.

Relay 1165 also closes contact 1185 to light the lamp, and the repeater D1 remains in this condition until the selector switch R2 has reached its normal position and sequence switch SS2 is in position 1. When this occurs, a circuit is completed as follows: earth, winding of relay 1901, contact 1908, contact 1190, conductor 168, contacts M1 and M2 in position 1 of sequence switch SS2, winding of relay 505 to battery. Relay 1901 is of very high resistance so that this relay alone energizes in this circuit and opens contacts 1905 and 1906. At contact 1905 the locking circuit for relay 1165 is opened and this relay accordingly de-energizes. Nothing further happens until the calling subscriber hangs up. It may be that the calling subscriber would hang up before switch R2 had reached normal position in which case the line relay 1162 and release relay 1163 in repeater D1 would release, but the repeater D1 would be guarded over earth, contact 1907, contact 1902, conductor 114 so as to prevent it being taken into use until the switch R2 had restored to normal.

The manner in which the selector switch R2 restores to normal will now be described.

Firstly it will be understood that until one digit has been registered by the register controller the selector R2 will not have its fundamental circuit closed and consequently will be at normal, and immediately the release of the register controller has taken place, as previously described, a circuit will be found for relay 1901. If the thousands digit and the thousands digit only has been registered, when the subscriber delays to dial, then the selector R5 will be taken into use, but as the second digit has not been registered no fundamental circuit will be completed and relay 1551 will not be energized. Relay 1552 will, however, be locked energized and the selector R2 will be in position 6.

In position 2, of sequence switch SS5, a circuit is completed as follows: earth, winding of relay 1554, contact 1572, contacts L2 and L1 in position 2 of sequence switch SS5, winding of holding magnet 1558 to battery. Relay 1554 energizes in this circuit and opens contact 1573. If, however, relay 1551 remains unoperated for a certain time the sequence switch remains in position 2 and in due course

a time impulse over lead 1580, contacts H3 and H2 in position 2, upper winding of relay 1553 to earth, causes relay 1553 to energize and open contact 1572, whereupon relay 1554 releases and a circuit is closed as follows: earth, contact 1573, contacts E2 and E3 in

position 2 of sequence switch SS5 winding of magnet 1555 to battery, magnet 1555 energizes and sequence switch SS5 passes into position 5.

In this position, as relay 1551 will still be de-energized, a circuit is completed as follows: earth, contact 1567, contacts O3 and O2 in position 5 of sequence switch SS5, winding of magnet 1555 to battery; the sequence switch thereupon advances to position 8. In this position a circuit is completed as follows: earth, winding of relay 1554, brush 1562, normal contact 1561, contacts B1 and B2 in position 8 of sequence switch SS5, winding of holding magnet 1558 to battery. Relay 1554 energizes and completes a circuit as follows: earth, contact 1574, contacts C1 and C2 in position 8 of sequence switch SS5, winding of magnet 1555 to battery; magnet 1555 energizes and the sequence switch advances into position 9.

In position 9 of sequence switch SS5 the above described circuit for relay 1554 is opened and consequently this relay on de-energizing completes the following circuit: earth, contact 1573, contacts E2 and E3 in position 9 of sequence switch SS5, winding of magnet 1555 to battery; magnet 1555 energizes and the sequence switch thereupon advances into position 12. In position 11 the resistance 1565 is removed from across relay 1552, thereby causing the selector R2 to advance to position 9, as has already been described.

In these circumstances battery and earth are not fed forward to the selector R2 over conductors 168 and 169, relay 503 cannot energize and accordingly relay 505 operates in the following circuit: earth, contact 516, contacts M3 and M2 in position 9 of sequence switch SS2, winding of relay 505 to battery. Relay 505 energizes and at contact 519 closes the following circuit: earth, contact 519, contacts B3 and B2 in position 9 of sequence switch SS2, winding of magnet 510 to battery; magnet 510 energizes and the sequence switch SS2 thereupon advances to position 11, and the restoration to normal of R2 proceeds as previously described. The selector R3 cannot stay in position 12, since, due to the release of R2 the relay 1552 has de-energized and a circuit is completed as follows: earth, contact 1569, contacts B3 and B2 in position 12 of sequence switch SS5, winding of magnet 1555 to battery; magnet 1555 energizes, the sequence switch accordingly advances to position 14 and the restoration takes place, as has already been described.

The next condition which arises is where the thousands and hundreds digits have been registered after which the subscriber delays to dial. In this case the selectors R2 and R5 will be set in the usual way and the final selector R6 seized. No circuit, however, will be completed for the relay 1602, which is in

the fundamental circuit and consequently the sequence switch SS6 cannot advance out of position 1. Therefore no release of this switch is necessary except to de-energize relay 5 1603, which relay is de-energized when the selector R5 restores to normal, as will now be described.

The sequence switch SS5 of selector R5 this time is in position 9, where after an interval, 10 a circuit will be completed as follows: earth, time pulse lead 1580, contacts H3 and H2 in position 9, upper winding of relay 1553 to earth. Relay 1553 operates and at contact 1572 opens the circuit of relay 1554 which is 15 energized in the following circuit: earth, winding of relay 1554, contact 1572, contacts L2 and L3 in position 9 of sequence switch SS5, brush 1572, bank contact 1573, conductor 1574, contact 1614, contacts M3 and M2 20 in position 1 of sequence switch SS6, resistance 1627, to battery. Relay 1554 accordingly releases and a circuit is completed as follows: earth, contact 1573, contacts E2 and E3 in position 9, magnet 1555 to battery; the sequence switch thereupon advances to position 12. In position 11, the shunt resistance 1565 is removed from across relay 1552 and accordingly the release of the selector R2 is caused to take place, as previously described. 25

When this occurs relay 1552 de-energizes and a circuit is completed as follows: earth, contact 1569, contacts B3 and B2 in position 12, magnet 1555 to battery; the sequence switch thereupon advances to position 14 and the 30 release of the selector R5 takes place as already described.

The last case to be considered is where the subscriber delays to dial after dialling the tens digit. In this case selectors R2 and R5 40 will be operated so far that the sequence switches SS2 and SS5 are in positions 6 and 9 respectively, while in the selector R6 the sequence switch SS6 will advance into position 3. The time limiting device connected to 45 conductor 1580 then comes into operation.

When sequence switch SS5 has reached position 9 and a suitable interval has elapsed, battery is connected to conductor 1580 and then after a further interval battery is again 50 connected to conductor 1580. When battery is first connected up a circuit is completed for relay 1553 as follows: battery, conductor 180, contacts H3 and H2 in position 9 of sequence switch SS5, upper winding of relay 1553 to earth. Relay 1553 operates and at contact 55 1572 opens the circuit of relay 1554.

Relay 1554 thereupon releases and completes a circuit as follows: earth, contact 1573, contacts E2 and E3 in position 9 of sequence switch SS5, winding of magnet 1555 to battery. Magnet 1555 energizes and the sequence switch SS5 advances into position 11. Relay 1603 in the selector R6 remains operated over the following circuit: battery, winding of relay 1603, contact 1614, conductor

70 1574, bank contact 1573, brush 1572, contacts J1 and J2 in position 11 of sequence switch SS5, resistance 1575, contact 1570 to earth.

Battery is then removed from conductor 180, relay 1553 releases, and relay 1554 again 75 operates over the test conductor.

After a suitable interval battery is again connected to conductor 180 and completes a circuit for the upper winding of relay 1553. Relay 1553 operates and opens the circuit of relay 1554 at contact 1572. Relay 1554 releases and completes a circuit as follows: earth, contact 1573, contacts E2 and E3 in position 11 of sequence switch SS5, winding of magnet 1555 to battery. Magnet 1555 energizes and the sequence switch SS5 advances 80 into position 12.

On leaving position 11 of sequence switch SS5 resistance 1565 is disconnected at contact 85 M2 and relay 507 in selector R2 releases. A circuit is thereby completed as follows: earth, contact 523, contacts B2 and B1 in position 6 of sequence switch SS2, winding of magnet 510 to battery. Magnet 510 energizes and the sequence switch SS2 advances into position 9. The selectors R2 and R5 are now under the control of the conductors 168 and 169, and are released by the opening of the loop across these conductors at the register controller, whereupon the switches R2 and R5 restore to normal as previously described. 90 95

In the selector R6, relay 1602 is not operated, while relay 1603 remains operated until its circuit is opened when the sequence switch SS5 passes out of position 12. When 100 this occurs, a circuit is completed as follows: earth, contact 1613, contacts B1 and B2 in position 3 of sequence switch SS6, winding of magnet 1606 to battery. Magnet 1606 energizes and the sequence switch SS6 advances into position 4.

In this position a circuit is completed as follows: earth, contact 1611, contact 1616, contacts F2 and F1 in position 4 of sequence switch SS6, winding of magnet 1606 to battery. Magnet 1606 energizes and the sequence switch SS6 advances 105 into position 4.

In this position a circuit is completed as follows: earth, contact 1610, contacts C2 and C1 in position 6 of sequence switch SS6, winding of magnet 1606 to battery. Magnet 1606 energizes and the sequence switch 110 advances into position 6.

In position 6 a circuit is completed for magnet 1606 as follows: earth, contact 1613, contacts B1 and B2 in position 10 of sequence switch SS6, winding of magnet 1606 to battery. Magnet 1606 energizes, sequence switch SS6 advances from position 10 and the release of the selector R6 proceeds as previously 115 120 125 described.

Consideration will now be given to the release of the switches when the calling subscriber hangs up before the switches have advanced into speaking position. The first case to be considered is when the register controller has been seized but no digits have been sent to the register controller. Relays 1162 and 1163 in the repeater E1 are operated, and the selector R2 has been taken into use, but is still in position 1.

10 The calling subscriber then hangs up, and the following circuit is completed: earth, contact 1179, contact 1181, conductor 199, bank springs 252, contact 260, winding of relay 218 to battery. Relay 218 operates and relay 401 operates partially as previously described. Shortly after relay 1162 releases, relay 1163 also releases and opens the previously described circuit at contact 1181. Relay 401 is thereupon completely operated, relay 211 is also completely operated, and relay 210 is locked energized over contact 284. When relay 1163 releases, it also opens the circuit of the upper winding of relay 1165 at contact 1182.

25 At this point it may be noted that when the repeater D1 and the register controller are taken into use a circuit is completed as follows: earth, contact 1905, upper winding of relay 1165, contact 1182, contact 1187, contact 1196, conductor 171, bank springs 253, contact 261, conductor 228, contact 1485, contact 1476, upper winding of relay 1411 to battery. Relay 1411 operates partially to close contact 1487 only.

30 When, therefore, the circuit of the upper winding of relay 1165 is opened at contact 1182, earth is removed from the mid-point of the winding of relay 1411, and this relay operates completely in the following circuit: battery, upper and lower windings of relay 1411 in series, contact 1487, conductor 232, contact 282 to earth. Relay 1411 upon operating completes a circuit as follows: earth, contact 282, conductor 232, contact 1480, contact 1486, conductor 228, contact 261, winding of relay 209 to battery. A parallel circuit is also completed from contact 261, bank springs 253, upper winding of plunger magnet 204, contact 200, lower winding of plunger magnet 204 to battery.

35 Plunger magnet 204 and relay 209 are therefore held operated as long as the previously described circuit is maintained. At the same time, a circuit is completed from contact 261, bank springs 253, conductor 171, contact 1196, contact 1187, contact 1183, upper winding of relay 1164 to battery. Relay 1164 operates and completes a locking circuit for itself as follows: battery, lower winding of relay 1164, contact 1904, contact 1906 to earth. Relay 1164 also closes contact 1184 to mark the repeater D1 busy.

40 Relay 1164 also closes contact 1903 and completes a circuit as follows: earth, winding

of high resistance relay 1901, contact 1903, contact 1190, conductor 168, contacts M1 and M2 in position 1 of sequence switch SS2, winding of relay 505 to battery. Relay 1901 operates in this circuit, but owing to the high resistance of relay 1901, relay 505 does not operate. The register controller remains in this condition until the first earth pulse is connected up to conductor 231. Relay 1408 then operates, as previously described, and is followed after an interval of 30 seconds by the operation of relay 1409, and this in turn after a further interval of 30 seconds is followed by the operation of relay 1410. Relay 1410 upon operating opens contact 1480, thereby removing the earth connection from relay 209 and plunger magnet 204 and the register controller restores to normal as previously described.

45 When relay 1901 operated, it opened the locking circuit of relay 1164 at contact 1906 but without effect at that time, since the circuit for the upper winding was still completed over contact 261. This circuit, however, has now been broken and relay 1164 releases and is followed by the release of relay 1901. Relay 1164 upon releasing also removes the earth from conductor 114 at contact 1184 and the repeater may now be taken into use for another call.

50 The case in which the subscriber has dialled the thousands digit into the register controller and then releases will now be considered. When the thousands digit has been completely registered and relay 401 has operated, the fundamental circuit is closed and the selector R2 is taken into use. Sequence switch SS2 then passes into position 2 and retractive impulses are sent back over contact 524. If the calling subscriber hangs up at this stage relay 1411 operates completely as previously described, and a locking circuit is closed at contact 1486 for relay 209, and plunger magnet 204. Relay 1164 operates and closes a locking circuit for itself at contact 1904 as previously described.

55 Since the selector R2 is now in position 2, relay 1901 is short-circuited by earth connected to its upper terminal over the following circuit: upper terminal of relay 1901, contact 1903, contact 1190, conductor 168, contacts L2 and L1 in position 2 of sequence switch SS2 to earth. The fundamental circuit, however, is maintained closed, and the trip spindle continues to rotate and the brush carriage is set in rotation and hunts for a free line as previously described.

60 A selector such as R5 will therefore be seized and furthermore as the hanging up of the receiver causes a momentary pulse to be sent to relay 218, the first relay of the hundreds register will be operated and consequently the selector R5 will hunt as if the numeral 1 had been registered for the hundreds digit and a free final selector such as

R6 will be seized. After this no fundamental circuit will be closed, the register will be held up as already described and consequently the selector R5 will release under the control of the time pulse lead in the same manner as was described in connection with the case where the subscriber delays to dial after the hundreds digit has been registered.

The release of the switches R2 and R6 also proceeds as described in connection with the release after the subscriber has delayed to dial after the hundreds digit. Similarly, in the case where the calling subscriber hangs up after two digits have been registered, an impulse is sent to the register controller which operates as though the digit 1 had been dialled as the tens digit; the switches will then be set up to the position where the final selector switch R6 has responded to the tens digit and is waiting to start the units selection. Here again, the release then follows in the same manner as in the case of where the calling subscriber delays to dial after the tens series of impulses.

If the calling subscriber should hang up after the tens series of impulses, then the effect of hanging up will be to register 1 on the units register. In this case the equivalent of the whole four series of impulses will have been registered, but the last series is, of course, a false impulse and it will be noted that while the final selector R6 will be operated to a position corresponding to the false number, as soon as the brush carriage has been set a circuit is completed for relay 207, whereupon contact 261 is opened and the magnet 204 restores to normal. The opening of the fundamental circuit causes the release of relay 503 in selector R2 and the switches at once restore to normal in the manner already described. In consequence the subscriber having the number which has been called falsely will not be disturbed.

If the calling subscriber hangs up after the transmission of the units series of impulses but before the register has released, the register will simply be held up until the final selector has been set on to the required line, whereupon relay 207 will energize and release will take place as already described.

It will be noted that in the two last mentioned cases, relay 1411 simply serves to hold up the register until relay 207 is operated. In the other cases, relay 1411 holds up the register until the time period determined by the relays 1408, 1409 and 1410 has elapsed.

It might be mentioned that relay 1410 is arranged when operated to connect earth to the middle point of relay 1411 so as to prevent this relay energizing fully when battery is connected to contact 1477 to energize relay 1165. Furthermore contact 1476 is opened at this time to prevent the low resistance battery being connected through the lower

winding of relay 1411 to earth on conductor 232.

Referring to Figures Nos. 19, 20, 20a, 21 and 22, a description will now be given of the detailed operation of a system with respect to the setting up of a call between a subscriber at substation X in the revertive control exchange and a subscriber at substation Y in the step-by-step exchange, whose number we will assume to be 93846. The subscriber at substation X initiates the call by lifting his receiver off the switch-hook, whereby a loop is closed across the conductors leading to the revertive control exchange in the usual manner.

The circuits at the revertive control exchange are of a type well known to those skilled in the art, and are shown diagrammatically, sufficient detail being given in order that the interworking arrangement may be fully understood. The line circuit LC when operated by the calling subscriber causes the primary finder PF to search for the calling line and the secondary finder SF searches in like manner for the hunting primary finder. The register selector RS associated with the secondary finder is then set in operation to select a free register such as the one shown at RG in the lower part of Fig. 19. When a free register has been found, the calling subscriber receives dial tone and then proceeds to dial the five digits of the wanted number in the usual manner. The sequence switch SSP controls the connecting or cord circuit which is made up of the secondary finder SF and primary selector PR. In position 1 of sequence switch SSP, the secondary finder SF hunts for the calling line. In position 4 the register selector RS hunts for a free register. In position 5 the register is connected up in readiness for the reception of the impulses sent by the calling subscriber and a loop circuit is closed as follows: battery, upper winding of relay 2105, bank contact 2127, brush 2125, contacts J3 and J2 in position 5 of sequence switch SSP, conductor 2112, through the secondary finder, primary finder, line circuit, loop at subscriber's substation, back to conductor 2113, contacts O2 and O3 in position 5, brush 2126, bank contact 2128, lower winding of relay 2105 to earth. Relay 2105 energizes when the register is seized and releases on each impulse, and thereby controls the registers in a manner well-known in the art.

When the ten thousands digit has been received the sequence switch SSI prepares a circuit for the thousands digit, after this has been received the sequence switch prepares a circuit for the hundreds digit, after this has been received it prepares a circuit for the tens digit, and after this has been received it prepares a circuit for the units digit. When the ten thousands digit has been registered

the primary selector PR operates in well known manner by sending revertive impulses back to the ten thousands register until the fundamental circuit is opened. The brush carriage of the primary selector PR is then set in rotation to select a free trunk leading to the step-by-step exchange. When a free trunk has been selected the sequence switch SSP advances to position 9.

10 It will be assumed that the trunk line comprising conductors 2131 and 2132 leading to the step-by-step exchange terminating in the repeater translator RT shown in Figs. 20 and 20a has been selected. When the register is 15 ready to receive the thousands revertive impulses the sequence switch SSO advances into position 10 and a circuit is thereupon completed as follows: earth, contact 2212, conductor 2131, bank contact 2134, brush 2129, contacts N2 and N3 in position 9 of sequence switch SSP, brush 2120, bank contact 2123, contacts J2 and J1 in position 10 of sequence switch SSD, contact 2133, winding of relay 2109, contacts P3 and P2 in position 20 6-14 of sequence switch SSI, contact 2122, brush 2121, contacts L2 and L1 in position 9 of sequence switch SSP, brush 2130, bank contact 2135, conductor 2132, contact 2218, resistance 2282, winding of relay 2202 to 25 battery.

Relay 2202 in the repeater translator RT and relay 2109 in the register RG operate in this circuit. Relay 2202 upon operating, closes a circuit as follows: earth, contact 2222, contact 2249, winding of relay 2203 to battery, whereupon relay 2203 operates and connects earth to conductor 2267 at contact 2226, and also closes a circuit for relay 2211 at contact 2226.

20 Relay 2211 operates and at contact 2256 closes a circuit for the lower winding of relay 2207, and closes a circuit for relay 2401 of selector S2 as follows: battery, upper winding of relay 2401, contact 2420, conductor 2281, contact 2255, winding of retard 2206, upper winding of relay 2207, contact 2245, conductor 2279, contact 2427, lower winding of relay 2401 to earth. Relay 2401 operates and closes a circuit for relay 2402 as follows: earth, contact 2425, contact 2409, winding of relay 2402 to battery. Relay 2402 operates and at contact 2411 connects earth to conductor 2280 and at contact 2412 prepares a circuit for magnet 2406 and relay 2403 in 25 series.

When relay 2211 energizes a circuit was also completed for relay 2209 as follows: battery, winding of relay 2209, contact 2248, contact 2243, contact 2220, contact 2234, contact 2256 to earth. Relays 2209 and 2208 are a pair of self-interrupting relays adjusted so as to operate with approximately the speed of the dial so that the opening of a back contact on relay 2208 approximately corresponds 20 to the break contact of the dial springs.

These relays continue to operate alternately as long as the above mentioned circuit is maintained, since when relay 2209 operates a circuit is completed for relay 2208 at contact 2246 and relay 2208 upon operating opens the energizing circuit of relay 2209 at contact 2243.

When relay 2209 operates the following circuit is also completed: earth, contact 2247, conductor 2275, contact 2365, contact 2357, contact 2352, contact 2345, contact 2339, upper winding of relay 2305 to battery. Relay 2305 partially operates and closes contact 2341 only thereby short-circuiting its lower winding, by connecting earth to its lower terminal as follows: lower terminal of relay 2305, contact 2341, conductor 2276, contact 2253, conductor 2277, contact 2370, contact 2349, contact 2363, contact 2355, contact 2361, contact 2369, conductor 2278, contact 2251, contact 2234, contact 2256 to earth. When earth is removed from the mid-point of the winding of relay 2305, this relay operates completely.

At contact 2340 the impulsing circuit is transferred to relay 2306, impulses continuously sent to the chain of relays 2305-2309 inclusive, until earth is removed from contact 2220. It will be convenient at this point to give a complete description of the operation of these relays up to their full counting capacity.

On the reception of the second impulse, relay 2306 operates partially to close contact 2347 only, and at the end of the impulse operates completely over the following circuit: 100 battery, upper and lower windings of relay 2306 in series, contact 2347, contact 2363, contact 2355, contact 2361, contact 2369, conductor 2278, contact 2251, contact 2234 contact 2256 to earth. Relay 2306 upon operating, 105 transfers the impulse lead to relay 2307 and opens the locking circuit of relay 2305 at contact 2349.

When relay 2209 operates for the third time, the following circuit is completed: 110 earth, contact 2247, conductor 2275, contact 2365, contact 2357, contact 2352, contact 2346, upper winding of relay 2307 to battery. Relay 2307 operates partially to close contact 2354 only, the lower winding being 115 short-circuited by earth at contact 2354 when earth is removed from conductor 2275 the short circuit is removed from the lower winding, and relay 2307 operates completely over the following circuit: battery, upper and 120 lower winding of relay 2307 in series, contact 2354, contact 2361, contact 2369, conductor 2278, over the previously traced circuit to earth. Upon operating, relay 2307 transfers the impulse lead to relay 2308 at 125 contact 2353, and at contact 2355 opens the locking circuit of relay 2306.

On the fourth impulse, relay 2308 operates partially to close contact 2359 only, and at the end of the impulse operates complete- 130

ly over the following circuit: battery, upper and lower winding of relay 2308 in series, contact 2359, contact 2369, conductor 2278, to earth as previously described. Relay 2308

5 upon operating transfers the impulse lead to relay 2309 at contact 2358, and at contact 2361 opens the locking circuit of relay 2307 and this relay releases.

On the fifth impulse, relay 2309 operates 10 partially to close contact 2367 only, and at the end of the impulse operates completely over the following circuit: battery, upper and lower windings of relay 2309 in series, contact 2367, to earth on conductor 2278. Relay 2309 upon operating, transfers the impulse lead 2275 to relay 2305 at contact 2366 15 and a circuit extending over contact 2352, contact 2345, and contact 2339. Relay 2309 also opens the locking circuit of relay 2308 at contact 2369 and this relay releases.

On the 6th impulse, relay 2305 operates 20 partially to close contact 2341 only, and at the end of the impulse operates completely over the following circuit: battery, upper and lower windings of relay 2305 in series, contact 2341, conductor 2276, contact 2253, conductor 2277, contact 2368, to earth on conductor 2278. Relay 2305 upon operating extends the impulse lead to relay 2306.

25 On the 7th impulse, relay 2306 operates partially to close contact 2347 and at the end of the impulse operates completely over the following circuit: battery, upper and lower windings of relay 2306 in series, contact 2347, contact 2363, contact 2355, contact 2361, contact 2342, to earth on conductor 2278. Relay 2306 upon operating extends the impulse lead to relay 2307.

30 On the 8th impulse relay 2307 operates partially to close contact 2354 only, and at the end of the impulse operates completely in the following circuit: battery, upper and lower windings of relay 2307 in series, contact 2354, contact 2361, contact 2342 to earth on conductor 2278. Relay 2307 upon operating opens the locking circuit of relay 2306 at contact 2355 and relay 2306 de-energizes. Relay 2307 also extends the impulse lead to relay 2308 at contact 2353.

35 On the 9th impulse, relay 2308 operates partially to close contact 2359 only, and at the end of the impulse operates completely in the following circuit: battery, upper and lower windings of relay 2308 in series, contact 2359, contact 2342 to earth on conductor 2278. Relay 2308 upon operating opens the locking circuit of relay 2307 at contact 2361 which thereupon releases and connects the impulse lead to relay 2303 in the following circuit: impulse lead 2275, contact 2366, contact 2352, contact 2345, contact 2340, to the mid-point of the winding of relay 2306.

40 On the 10th impulse relay 2306 operates partially to close contact 2347 only, and at the end of the impulse operates completely over

the following circuit: battery, upper and lower windings of relay 2306 in series, contact 2347, contact 2362, to earth on conductor 2278. Relay 2306 upon operating extends the impulse lead to relay 2307 at contact 2346.

On the 11th impulse, relay 2307 operates 45 partially to close contact 2354 only, and at the end of the impulse operates completely in the following circuit: battery, upper and lower windings of relay 2307, contact 2354, contact 2348, contact 2360, contact 2342, to earth on conductor 2278. The counting relay set, however, does not in one operation 50 operate completely as described, and certain operations which take place in the repeater translator and which control its operation 55 will now be considered.

Each time relay 2208 operates, a circuit 60 is closed as follows: earth, contact 2242, contact 2219, resistance 2282, contact 2218, conductor 2132, bank contact 2135, brush 2130, contacts N2 and N3 in position 9 of sequence switch SSP, brush 2121, contact 2122, winding of relay 2109, contact 2133, contact 2123, 65 wiper 2120, contacts C3 and C2 in position 9 of sequence switch SSP, brush 2129, bank contact 2134, conductor 2131, contact 2212 to earth.

70 Relay 2109 in the register RG is therefore 75 short-circuited, whilst relay 2202 in the repeater translator RT is maintained energized. Each time that relay 2109 falls back, contact 2138 is closed, and the thousands register advances one step; it is therefore evident that 80 each operation of relay 2208 in the repeater translator causes the associated register in this case, the thousands register, to be advanced one step and also causes one of the 85 counting relays 2305-2309, inclusive to operate.

90 It will be convenient at this point to refer to the relationship between the step-by-step impulses which are transmitted from the repeater translator to the step-by-step switches 110 and the actual revertive control impulses which are transmitted from the repeater translator to the register in the revertive control exchange. As already pointed out, one 95 of the advantages of the repeater translator 115 shown in Figs. 20 and 20a is that it sends back revertive impulses to the revertive control exchange and sends forward impulses to operate the step-by-step switches without requiring the necessity of any storing between successive impulse trains. For this purpose, as has been already mentioned, the step-by-step switches are arranged so as to have large capacity final selector switches

120 having access to 200 lines, these lines are connected to two one hundred point banks and the switches are provided with two sets of wipers, one of which is taken into use when the hundreds digit is even, and the other is taken into use when the hundreds digit is odd; 125 130

discrimination is effected by a switching impulse which is transmitted to the final selector from the repeater translator during the transmission of the units reverteive impulses.

- 5 In the incoming selector only the odd levels are used, and this will be apparent from the following table, in which the reverteive impulses sent back to the reverteive control exchange and the impulses sent forward to operate the step-by-step switches are shown side by side for each digit, in which the value of the digit is varied from 1 to 0.

Number dialled	1000 digit		100 digit			
			1000 digit even		1000 digit odd	
	Rever- tive control impulses	Step-by- step impulses	Rever- tive control impulses	Step-by- step impulses	Rever- tive control impulses	Step-by- step impulses
1	9	1	10	1	9	2
2	7	3	8	3	7	4
3	7	3	8	3	7	4
4	5	5	6	5	5	6
5	5	5	6	5	5	6
6	3	7	4	7	3	8
7	3	7	4	7	3	8
8	1	9	2	9	1	10
9	1	9	2	9	1	10
0	9	1	10	1	9	2

Number dialled	10 digit		Units digit			
			100 digit even		100 digit odd	
	Rever- tive control impulses	Step-by- step impulses	Rever- tive control impulses	Step-by- step impulses	Rever- tive control impulses	Step-by- step impulses
1	10	1	10	1	20	1
2	9	2	9	2	19	2
3	8	3	8	3	18	3
4	7	4	7	4	17	4
5	6	5	6	5	16	5
6	5	6	5	6	15	6
7	4	7	4	7	14	7
8	3	8	3	8	13	8
9	2	9	2	9	12	9
0	1	0	1	0	11	0

NOTE.—When the hundreds digit is odd and more than ten reverteive impulses have to be sent to reverteive control exchange, then in addition to the step-by-step impulses shown in the last column a switching over from one set of wipers to another in the final selector is effected in addition.

It will be noted by reference to this table that for the thousands digit, the total number of impulses which are dealt with at the repeater translator, that is to say, the number of reverteive control impulses sent back to the reverteive control exchange plus the number of impulses sent forward to operate the incoming step-by-step selector is a constant and always equals ten. Referring to the table as regards the hundreds digit, it will be noted that the repeater translator again deals always with a constant number of impulses, but in this case, the number is eleven. Referring to the tens impulses it will again be noted that the number dealt with is eleven, while in the units impulses the number is either 11 or 21. In the example under consideration, the number dialled by the calling

subscriber at the reverteive control exchange is 93846, the first digit 9 is utilized to select a trunk to the step-by-step exchange and the remaining digits are translated by the repeater translator. By referring to the table just given, it will be seen that the thousands digit 3 is translated into three step-by-step impulses, the hundreds digit 9 is translated into ten step-by-step impulses, the tens digit 4 is translated into four step-by-step impulses, and the units digit 6 is translated into 6 step-by-step impulses. If the number dialled had been 93946, the step-by-step impulses transmitted would be the same as before, namely, 3, 10, 4 and 6 respectively. In the latter case, however, a special switching impulse is transmitted to the final selector so as to cause its wipers to connect with the odd hundreds digit bank. In this way, full use is made of the capacity of the incoming third selector S3, the odd levels only of the incoming second selector S2 are equipped, and in this manner by arranging the layout of the incoming selectors of the step-by-step exchange so that they correspond closely with those of a corresponding reverteive control exchange, a total capacity of 10,000 lines is obtained. It will be understood that in the case of local calls having an odd hundreds digit, access to the required subscriber is obtained over the odd hundreds bank of the special final selectors as is illustrated in Fig. 25, since of course in this case no switching impulse is sent to the final selector. Local calls to subscribers having an even hundreds digit are obtained in the usual manner over the regular final selector switch SL4, and it will be seen that subscriber 93846, for example, is connected both to the even bank of the incoming final selector and to the bank of the regular final selector.

In the present example, the thousands digit is 3, and referring to the table of impulses required to be sent back to the trunk switches it will be seen that seven impulses are required before the fundamental circuit is opened. Hence, the thousands register will be advanced into its 10th position, and the relay set 2305—2309 will have responded to seven impulses so that relays 2305, 2306 and 2309 will be locked energized at that time. When the thousands register reaches its 10th position, a circuit is completed for relay 2108 which operates to open contact 2123. This circuit is shown in simplified form as follows: earth, contact 2140, winding of relay 2108 to battery, it being assumed that contact 2140 is closed whenever the registers are in an appropriate position for causing the fundamental circuit to be opened. Such arrangements are well known in the art and need not be described in detail; for an understanding as to how the required operation may take place reference may be had to Figs. 3, 4 and 5, and the operation of relay 208.

The fundamental circuit is thereby opened and relay 2202 in the repeater translator is de-energized since relay 2208 de-energizes. Relay 2202 opens the circuit of relay 2209 at contact 2220 and the impulsing circuit from contact 2242 at contact 2219. The circuit of relay 2203 is opened at contact 2222, but this relay is slow to release and remains operated for a short interval after relay 2202 has released; so that a circuit is completed as follows: battery, winding of relay 2201, contact 2225, contact 2221 to earth.

Relay 2201 operates and closes a locking circuit for itself at contact 2214 as follows: battery, winding of relay 2201, contact 2214, contact 2239, contact 2256 to earth, since relay 2211 being also slow to release has its circuit maintained closed at contact 2226 for a short interval before relay 2203 releases. Relay 2211 it should be mentioned is maintained energized throughout the connection, either over contact 2226 or during the transmission of impulses to the step-by-step exchange, over contact 2244.

When relay 2201 operates, the pair of relays 2208, 2209 are then again set in operation by the energization of relay 2209 which has a circuit completed as follows: battery, winding of relay 2209, contact 2248, contact 2243, contact 2227, contact 2215, contact 2234, contact 2256 to earth. A circuit is also completed for relay 2205 as follows: battery, resistance 2141, contacts I1 and I2 in position 8 of sequence switch SSO, contacts P4 and P2 in position 6—14 of sequence switch SSI, contact 2122, brush 2121, contacts L2 and L1 in position 9 of sequence switch SSP, brush 2130, contact 2135, conductor 2132, contact 2217, conductor 2272, contact 2336, contact 2326, conductor 2274, winding of relay 2205, conductor 2284, contact 2316, contact 2371, conductor 2265, contact 2236, contact 2213, conductor 2131, contact 2134, brush 2129, contacts N2 and N3 in position 9 of sequence switch SSP, brush 2120, contact 2123, relay 2142, contacts P2 and P1 in position 8 of sequence switch SSO to earth.

Relay 2205 operates and an alternative locking circuit is provided for relay 2201 which extends as follows: battery, winding of relay 2201, contact 2214, contact 2239, contact 2256 to earth. It should be mentioned here that relay 2211 is slow to release and during the interval that is liable to take place between the release of relay 2203 and the operation of relay 2205 relay 2211 remains operated and maintains the circuit of relay 2401 at contact 2255.

Relays 2209 and 2208 operate alternately in the manner previously described, and at contact 2247 relay 2209 transmits impulses to the counting relay set comprising relays 2305-2309 inclusive, which continue to operate until relay 2306 operates for the third time, that is, when ten impulses have been

registered. Since relays 2305, 2306 and 2309 were already operated, relay 2306 will operate for the third time when three further impulses have been transmitted by relay 2209. Relay 2208 opens the loop circuit to the selector S2 at contact 2245, each time it is operated by relay 2209, that is, three times.

This contact was shunted at contact 2223 of relay 2202 when revertive impulses were transmitted to the thousands register. This shunt is, however, removed when relay 2202 releases, while at contact 2224 retard 2206 and relay 2207 are short-circuited. This short circuit may be traced as follows: lower terminal of relay 2207, contact 2224, contact 2259, contact 2329, conductor 2273, lower terminal of relay 2206. By this means the impedance of the retard and relay are cut out of the impulsing circuit. Three impulses are now transmitted to the selector S2 and relay 2401 falls back at each impulse and completes a circuit as follows: earth, contact 2425, contact 2410, contact 2412, winding of relay 2403, winding of vertical magnet 2406 to battery.

Relay 2402 is slow to release, and is therefore maintained energized during the impulse series. The vertical magnet accordingly operates to raise the wipers opposite the third level of contacts; on the first step off-normal contacts 2414 and 2424 are closed. Relay 2404 is energized in the following circuit: earth, contact 2411, contacts 2415, 2424, 2419, relay 2404 to battery. Relay 2404 energizes and locks energized in the following circuit: battery, relay 2404, contacts 2419, 2424, 2417 to earth. At the end of the series of impulses relay 2403 releases.

The number of steps taken by the step-by-step selector depends upon the setting of the counting relays referred to above. When the tenth step is taken, that is, on the third operation of relay 2306, a circuit is closed for relay 2204 as follows: battery, winding of relay 2204, conductor 2285, contact 2310, contact 2315, contact 2344, contact 2338, conductor 2261, contact 2231, conductor 2262, contact 2356, contact 2364 to earth.

Relay 2204 operates and closes a locking circuit for itself over contact 2232 which extends over contact 2216 of relay 2201 to earth. With the operation of relay 2204, the holding circuit of relay 2201 is transferred to the following circuit: earth, contact 2240, conductor 2271, contact 2327, conductor 2266, contact 2238, contact 2214, winding of relay 2201 to battery. Relay 2204 is held dependent on this circuit, by reason of its being operated over contact 2216 of relay 2201.

The locking circuit of relay 2211 now extends as follows: battery, winding of relay 2211, conductor 2267, contact 2330, conductor 2270, contact 2233, contact 2256 to earth. Relay 2211 is therefore dependent upon relay 2204 and relay 2204 is dependent upon relay 2201.

2201 which in turn is dependent upon relay 2205, while relay 2205 is held operated as long as battery is to be found on conductor 2132 at the register, that is to say, until the next digit has been dialled by the calling subscriber and the sequence switch SSO has advanced into position 10.

When relay 2204 operated, it also opened the circuit of relay 2209 at contact 2234, thereby stopping further impulses from being delivered to the step-by-step selector. On the operation of relay 2204 a circuit is also closed for the upper winding of relay 2301 as follows: battery, upper winding of relay 2301, contact 2311, contact 2317, contact 2332, conductor 2264, contact 2235, contact 2237 to earth. Relay 2301 operates partially to close contact 2313 only, thereby short-circuiting its lower winding. Relay 2204 also by opening contact 2234, opens the locking circuit of the counting relay set which restores to normal.

Returning now to the operation of selector S2 it will be seen that when the vertical selection has taken place relay 2403 releases and a circuit is completed for magnet 2407 as follows: battery, winding of magnet 2407, contact 2418, contact 2416, contact 2411 to earth. Magnet 2407 energizes and rotates the wipers 2428, 2435 and 2442 into engagement with the first set of contacts in the selected level, and opens its interrupter contact 2419 whereupon the circuit of relay 2404 is opened, and this relay releases to open the circuit of the rotary magnet at contact 2418.

If the trunk line connected to these contacts is busy, earth will be encountered on contact 2436 and relay 2405 is short-circuited whilst a circuit is completed for relay 2404 as follows: earth, bank contact 2436, wiper 2435, contact 2422, off-normal contact 2424, interrupter contact 2419, winding of relay 2404 to battery. Relay 2404 operates and closes a circuit of the rotary magnet as follows: earth, contact 2411, contact 2416, contact 2418, winding of magnet 2407 to battery.

Magnet 2407 thereupon energizes and the wipers are stepped onto the next set of contacts and the circuit of relay 2404 is opened which in turn opens the circuit of the rotary magnet. This interaction between relay 2404 and magnet 2407 continues until a free trunk is encountered, whereupon the short circuit is removed from relay 2405 and this relay operates in the following circuit: earth, contact 2411, winding of relay 2405, off-normal contact 2424, interrupter contact 2419, winding of relay 2404 to battery.

Relay 2405 operates in this circuit, but relay 2404 owing to its comparatively low resistance remains unoperated. At contacts 2420 and 2427, relay 2405 opens the circuit of relay 2401 which releases and prepares a circuit of the release magnet 2408 at contact 2410, this circuit, however, having been

opened at contact 2425 when relay 2405 operated. After a short interval relay 2402 also releases, earth being maintained on conductor 2280 at contact 2411 during that interval.

It will be assumed that the free trunk selected is the one comprising conductors 2430, 2437, 2444, leading to selector S3 which is prepared for operation, in a similar manner; earth being connected to conductor 2437 to guard and hold up the selector S2 before relay 2402 in the selector S2 releases.

When the hundreds digit has been completely registered the sequence switch SSO advances into position 10 battery is removed from conductor 2132, and relay 2205 thereupon releases and opens the circuit of relay 2201. Relay 2201 releases and opens the circuit of relay 2204 which is slow to release and during the interval in which release takes place a circuit is completed for relay 2202, as follows: battery, winding of relay 2202, resistance 2282, contact 2218, conductor 2132, contact 2135, brush 2130, contacts L1 and L2 in position 9 of sequence switch SSP, brush 2121, contact 2122, winding of relay 2109, contact 2133, contact 2123, brush 2120, contacts N3 and N2 in position 9 of sequence switch SSP, brush 2139, contacts 2134, conductor 2131, contact 2212 to earth.

It will be noted that relay 2108 de-energized and closed contact 2133 when the sequence switch SSO passed into position 10 which it does when the hundreds digit has been registered and the thousands digit has been transmitted to the repeater translator. Relay 2202 operates, and completes a circuit for relay 2203 as follows: earth, contact 2222, contact 2249, winding of relay 2203 to battery. Relay 2203 operates and at contact 2226 again closes the circuit of relay 2211 before this relay has had time to release. When relay 2204 releases, earth is removed from the mid-point of the winding of relay 2301 and this relay operates fully in the following circuit: battery, upper and lower windings of relay 2301 in series, contact 2313, contact 2321, contact 2334, conductor 2268, contact 2256 to earth.

Relay 2301 operates and prepares a circuit for the next series of impulses, since in the case of the hundreds digit it is necessary to have eleven operations of the counting relays before the impulse series is stopped. When relay 2202 operates, a circuit is also completed for relay 2209 as follows: battery, winding of relay 2209, contact 2248, contact 2243, contact 2220, contact 2234, contact 2256 to earth.

Relay 2209 closes a circuit for relay 2208 at contact 2246 whereupon this pair of relays operates in the manner previously described and impulses are sent over conductor 2275 to the set of counting relays 2305-2309 inclusive. These impulses are also sent back to the register at contact 2242 of relay 2208 over contact 2219 and contact 2218. When

the register has been completely set, the loop across conductors 2131 and 2132 is opened at contact 2133, relay 2108 being operated as follows: earth, contact 2144, contacts B4 and B1 of sequence switch SSR in position 10, winding of relay 2108 to battery. The sequence switch SSO advances to position 13.

In this position battery is connected to conductor 2132 as follows: battery, resistance 2141, contacts I2 and I1 in position 13 of sequence switch SSO, contacts P4 and P2 in position 6—14 of sequence switch SSI, contact 2122, brush 2121, contacts L2 and L1 in position 9 of sequence switch SSP, brush 2130, contact 2135, conductor 2132; relay 2202 therefore releases, and opens the circuit of relay 2203 at contact 2222. Relay 2303, however, is slow to release, and in the interval a circuit is completed for relay 2201 as follows: earth, contact 2221, contact 2225, winding of relay 2201 to battery. Relay 2201 energizes and closes a locking circuit for itself at contact 2214 as follows: battery, winding of relay 2201, contact 2214, contact 2239, contact 2256 to earth. When relay 2202 released, the circuit of relay 2209 was opened at contact 2220, and the sending of impulses to the counting relays was arrested. Relay 2201 upon operating connects conductor 2131 to the repeater translator over contact 2213 and conductor 2132 in the repeater translator over contact 2217.

A circuit is thereupon completed for relay 2205 as follows: battery, on conductor 2132 as previously described, contact 2217, resistance 2283, winding of relay 2205, conductor 2284, contact 2316, contact 2371, conductor 2265, contact 2236, contact 2213, conductor 2131, contact 2134, brush 2129, contacts N2 and N3 in position 9 of sequence switch SSP, brush 2120, contact 2123, relay 2142, contacts P2 and P1 in position 13 of sequence switch SSO to earth. Relay 2205 operates, and remains operated until the tens digit has been registered, and the sequence switch SSO has advanced into position 14. When relay 2201 operates a circuit is completed for relay 2209 as follows: battery, winding of relay 2209, contact 2248, contact 2243, contact 2227, contact 2215, contact 2234, contact 2256 to earth.

Relays 2209 and 2208 therefore operate alternatively as before and impulses are transmitted to the counting relay set at contact 2247 to relay 2211 at contact 2244, to keep this relay energized and to the step-by-step switches at contact 2245. When relay 2307 has operated for the third time, that is, when eleven impulses have been recorded and the appropriate number of impulses have been transmitted to the step-by-step switches a circuit is completed as follows: battery, winding of relay 2204, conductor 2285, contact 2351, contact 2344, contact 2338, conductor 2261, contact 2231, conductor 2262, contact 2356, contact 2364 to earth.

Relay 2204 thereupon operates and closes a locking circuit for itself at contact 2232 extending over contact 2216 to earth. With the operation of relay 2204 the holding circuit of relay 2201 is transferred to the following circuit: battery, winding of relay 2201, contact 2214, contact 2238, conductor 2266, contact 2327, conductor 2271, contact 2240 to earth, and relay 2211 is now provided with a locking circuit which extends as follows: battery, winding of relay 2211, conductor 2267, contact 2380, conductor 2270, contact 2233, contact 2256 to earth. With the operation of relay 2204 the circuit of relay 2209 is opened at contact 2234, and the sending of impulses to the step-by-step switches is stopped.

At the end of the transmission of this (the hundreds) series of impulses to the step-by-step switches the wipers 2432, 2439, 2446 of selector S3 will be set to rotate over the level of contacts to which they have been raised to select a free trunk as described in connection with selector S2. It will be assumed that a free trunk has been seized, and comprises conductors 2434, 2441 and 2448 leading to the final selector S4 shown in Fig. 22.

Relay 2502 thereupon operates in the following circuit: battery, upper winding of relay 2502, contact 2514, conductor 2434, bank contact 2433, wiper 2432, conductor 2431, conductor 2430, bank contact 2429, wiper 2428, contact 2421, conductor 2281, contact 2255, winding of retard 2206, upper winding of relay 2207, contact 2245, conductor 2279, contact 2426, wiper 2422, bank contact 2443, conductor 2444, conductor 2445, wiper 2446, bank contact 2447, conductor 2448, contact 2515, lower winding of relay 2502 to earth. Relay 2502 upon operating, closes a circuit for relay 2503 at contact 2519. Relay 2503 upon operating connects earth at contact 2522 through the upper winding of relay 2501 to conductor 2441 to provide a holding circuit for selectors S3 and S4, which is independent of contact 2254.

When relay 2204 operated, earth was connected to the mid-point of the winding of relay 2302 as follows: earth, contact 2237, contact 2235, conductor 2264, contact 2332, contact 2317, contact 2312, upper winding of relay 2302 to battery. Relay 2302 operates partially to close contact 2319 only. Relay 2201 in the repeater translator is now locked up dependent upon relay 2205 which is maintained energized by battery connected to conductor 2132 until the tens digit has been recorded at the register and the sequence switch SSO advanced into position 14.

When battery is removed from conductor 2132, relay 2205 releases and is followed by relay 2201 and shortly after by relay 2204 at contact 2216. Relay 2204 releases, and relay 2302 operates completely in the following circuit: battery, upper and lower wind-

ings of relay 2302 in series, contact 2319, contact 2334, conductor 2268, contact 2256 to earth. Relay 2302 upon operating, opens the locking circuit of relay 2301 at contact 2321 and relay 2301 therefore de-energizes.

In position 14 of sequence switch SSO the fundamental circuit is again closed as follows: battery, winding of relay 2202, resistance 2282, conductor 2132, contact 2135, brush 2130, contacts L1 and L2 in position 9 of sequence switch SSP, brush 2121, contact 2122, winding of relay 2109, contact 2133, contacts J1 and J2 in position 14 of sequence switch SSO, contact 2123, brush 2120, contacts N3 and N2 in position 9 of sequence switch SSP, brush 2129, contact 2134, conductor 2131, contact 2122 to earth. Relay 2202 thereupon operates and closes a circuit for relay 2203 as follows: earth, contact 2222, contact 2249, winding of relay 2203 to battery. Relay 2203 operates, and completes a holding circuit for relay 2211 at contact 2226. Relay 2211 being slow to release is maintained operated during the interval between the release of relay 2205 and the operation of relay 2203.

With the operation of relay 2202, a circuit is completed for relay 2209 as follows: battery, winding of relay 2209, contact 2248, contact 2243, contact 2220, contact 2234, contact 2256 to earth. Relays 2209 and 2208 thereupon operate alternately as before and impulses are sent to the counting relay set over conductor 2275 at contact 2247 and to the register over conductor 2132 at contact 2242. Relay 2109 is thereby intermittently short-circuited and at contact 2138 repeats impulses to the tens register over contacts E1 and E3 in position 14 of sequence switch SSO which steps until it reaches its home position.

When this occurs, the following circuit is completed: earth, contact 2146, contacts B3 and B1 in position 14 of sequence switch SSO, winding of relay 2108 to battery; relay 2108 operates and opens the fundamental circuit at contact 2133. Relays 2109 and 2202 thereupon de-energize. Relay 2202 upon de-energizing completes a circuit for relay 2201 as follows: earth, contact 2221, contact 2225, winding of relay 2201 to battery. Relay 2201 accordingly energizes and locks energized in the following circuit: battery, relay 2201, contact 2214, contact 2239, contact 2256 to earth.

Relay 2201 completes a circuit for relay 2209 as follows: earth, contact 2256, contact 2234, contact 2215, contact 2227, contact 2243, contact 2248, winding of relay 2209 to battery; this circuit is completed when relay 2203 de-energizes, which it does shortly after relay 202 releases. The relays 2209 and 2208 thereupon alternately energize and control the transmission of impulses to the final selec-

tor S4 over contact 2255 and to the relay register set over contact 2247.

When eleven impulses have been registered a circuit is completed as follows: earth, contact 2364, contact 2356, conductor 2262, contact 2231, conductor 2261, contact 2338, contact 2344, contact 2351, conductor 2285, winding of relay 2204 to battery. Relay 2204 thereupon energizes and is locked energized in the following circuit: battery, winding of relay 2204, contact 2232, contact 2228, conductor 2258, contact 2314, contact 2320, contact 2334, conductor 2268, contact 2256 to earth. At contact 2239 it opens the locking circuit of relay 2201, relay 2201 thereupon releases and prepares the fundamental circuit. When the register R10 has responded to the required number of revertive impulses and relay 2108 has operated, the sequence switch SSO advances to position 15, and remains in this position until the units digit has been registered. Consequently further operation now depends upon the receipt of the units digit by the register RG.

When the units digit has been registered the sequence switch SSO advances to position 16 and a fundamental circuit is completed as follows: battery, winding of relay 2202, resistance 2282, contact 2218, conductor 2132, bank contact 2135, brush 2130, contacts L1 and L2 in position 9 of sequence switch SSP, brush 2121, bank contact 2122, contacts P2 and P3 in position 6—14 of sequence switch SSI, winding of relay 2109, contact 2133, contacts J1 and J2 in position 16 of sequence switch SSO, bank contact 2123, brush 2120, contacts N3 and N2 in position 9 of sequence switch SSP, brush 2129, bank contact 2134, conductor 2131, contact 2212 to earth.

Relay 2202 accordingly energizes and at contact 2222 completes a circuit for relay 2203. Relay 2203 accordingly energizes and at contact 2228 opens the locking circuit of relay 2204, which relay de-energizes shortly after and completes an energizing circuit for relay 2209 as follows: earth, contact 2256, contact 2234, contact 2220, contact 2243, contact 2248, winding of relay 2209 to battery. The opening of contact 2235 permits relay 2303 to fully operate in the following circuit: battery, upper and lower windings of relay 2303 in series, contact 2324, contact 2334, conductor 2668, contact 2256 to earth.

Relay 2303 upon operating opens contact 2326, and removes the short circuit across resistance 2283, which is a very high resistance. Relays 2209 and 2208 operate alternately and transmit impulses to the register RG at contact 2242 and to the counting relay set at contact 2247. Relay 2109 is intermittently short-circuited and at contact 2138 transmits impulses to the register R1 over contacts E1 and E2 in position 16 of sequence switch SSO.

When contact 2245 is opened for the first time, the loop across conductors 2434 and 2448 is opened, and relay 2502 releases and completes a circuit as follows: earth, contact 2520, contact 2523, contact 2586, winding of relay 2504, winding of vertical magnet 2581 to battery. Relay 2504 and vertical magnet 2581 energize in this circuit, and relay 2504 closes contact 2525 while magnet 2581 raises the wipers 2556, 2559, 2557, 2560, 2555 and 2561 opposite the first level of contacts. When the shaft of the switch moves off-normal, contact 2586 is opened, and the circuit for subsequent impulses is completed over contacts 2585 and 2525, as follows: earth, contact 2520, contact 2523, contact 2525, winding of relay 2504, winding of magnet 2581 to battery. Relays 2503 and 2504 being slow to release are held operated during the series of impulses. The wipers are therefore raised vertically one step for each impulse sent to the counting relay set. At the end of the series of impulses relay 2504 de-energizes.

When the units register has been completely set, contact 2148 is closed and a circuit completed as follows: earth, contact 2148, contacts B2 and B1 in position 16 of sequence switch SSO, relay 2108 to battery; relay 2108 opens contact 2133 so that the fundamental circuit is opened and relay 2202 releases. The sequence switch SSO is now controlled so as to restore to normal and at the same time to control the restoration to normal of the registering equipment. During this process an impulse is sent to the primary selector to cause the sequence switch SSP to advance into position 12. A circuit is then completed for relay 2201 as follows: earth, contact 2221, contact 2225, winding of relay 2201 to battery.

Relay 2201 thereupon energizes and completes a locking circuit for itself as follows: battery, winding of relay 2201, contact 2214, contact 2239, contact 2256 to earth. When relay 2203 releases, the circuit of relay 2209 is completed as follows: battery, winding of relay 2209, contact 2248, contact 2243, contact 2227, contact 2215, contact 2234, contact 2256 to earth.

Relays 2209 and 2208 thereupon operate alternately. Relay 2209 at contact 2247 sends impulses to the counting relay set and relay 2208 at contact 2245 opens the loop to the step-by-step switches and at contact 2244 maintains relay 2211 energized by the intermittent connection of earth to its upper terminal.

Returning now to the operation of the final selector S4, when the loop is first opened at contact 2245, relay 2502 releases and completes a circuit as follows: earth, contact 2520, contact 2523, off-normal contact 2585, contact 2573, contact 2535, contact 2546,

winding of rotary magnet 2582 to battery. A parallel circuit is also completed from contact 2535 through the winding of relay 2508 to battery. This relay is slow to release and is maintained energized during the series of impulses and closes contact 2540 so as to provide a circuit for impulses independent of contact 2535. The wipers are thereupon rotated one step on each impulse transmitted to the counting relay set, and are thereby stepped onto the wanted contact in the selected level.

When the relay set has been completely operated a circuit is completed for relay 2204 as follows: battery, winding of relay 2204, conductor 2285, contact 2351, contact 2344, contact 2338, conductor 2261, contact 2231, contact 2262, contact 2356, contact 2364 to earth. Relay 2204 upon operating closes a circuit for relay 2304 as follows: battery, winding of relay 2304, contact 2323, contact 2318, contact 2332, conductor 2264, contact 2235, contact 2237 to earth.

Relay 2304 operates to close a locking circuit for itself at contact 2335 as follows: battery, winding of relay 2304, contact 2335, conductor 2265, contact 2237 to earth, and opens its initial energizing circuit at contact 2332, contact 2335 being closed, however, before contact 2332 has opened. Relay 2304 also opens contact 2334, thereby releasing relays 2302 and 2303.

At contact 2333 a circuit is now completed for relay 2205 as follows: earth, contact 2150, relay 2151, contacts N1 and N2 in position 12 of sequence switch SSP, brush 2129, contact 2134, conductor 2131, contact 2213, conductor 2269, contact 2333, contact 2284, relay 2205, resistance 2283, contact 2217, conductor 2132, contact 2135, brush 2130, contacts M2 and M1 in position 12 of sequence switch SSP, winding of relay 2152 to battery. In this circuit relay 2205 energizes but owing to the high resistance 2283 relays 2151 and 2152 do not energize at this time. At contact 2234 relay 2204 opens the circuit of relay 2209 and the transmission of impulses to the step-by-step switches is arrested. It will be remembered that relay 2201 was locked energized when the fundamental circuit was opened after the counting relay set had been operated in accordance with the revertive control impulses sent back for the units digit and the circuit of this relay is now transferred to the following circuit: battery, winding of relay 2201, contact 2214, contact 2238, conductor 2266, contact 2331, conductor 2270, contact 2233, contact 2256 to earth; relay 2211 being also operated in the following circuit:

battery, winding of relay 2211, conductor 2267, contact 2328, conductor 2271, contact 2240 to earth.

In this condition contacts 2213, 2217 and 2255 are closed and the speaking leads are connected through the repeater translator so

that conversation can take place. It will be noted that relay 2211 is dependent upon relay 2205 while the step-by-step switches and relays 2201, 2204, 2304 are all ultimately dependent upon contact 2256 of relay 2211. Consequently the calling subscriber by causing relay 2205 to release can cause the whole connection to be restored to normal.

Returning now to the final selector, it will be remembered that relay 2508 was held operated during the series of units impulses and that the wipers are now resting on the line of the wanted subscriber. It will be assumed first of all that the line of the wanted subscriber is idle, and that battery is therefore connected to conductor 2568. When relay 2508 releases at the end of the units series of impulses a circuit is completed as follows: battery, conductor 2568, bank contact 2563, wiper 2557, contact 2550, contact 2537, lower winding of relay 2509, contact 2533, contact 2522 to earth.

Relay 2509 operates and closes a locking circuit for itself as follows: battery, upper winding of relay 2509, contact 2574, contact 2521 to earth. The circuit of the rotary magnet 2582 is thereupon opened at contact 2546 and ring back tone is connected to the upper speaking conductor at contact 2542. Contacts 2541 and 2547 are also closed and ringing current is then fed to the wanted subscriber's line over the following circuit: battery, ringing generator 2591, contact 2588, lower winding of relay 2506, contact 2526, contact 2541, contact 2548, wiper 2556, bank contact 2562, conductor 2568, instrument of wanted subscriber, conductor 2572, bank contact 2567, wiper 2561, contact 2555, contact 2547, contact 2532 to earth.

The connection of ringing current is interrupted at intermittent intervals by the operation of relay 2584 which is intermittently connected and disconnected from battery by interrupter 2592. Contacts 2588 and 2589 are therefore closed alternately, and generator superimposed battery are alternately connected to the upper speaking conductor.

It will be remembered that earth was connected to the release trunk conductor 2441 through the upper winding of relay 2510. The upper winding is now short circuited when relay 2509 operates, and closes contact 2543, direct earth being now connected to the release trunk conductor as follows: earth, contact 2522, contact 2543 to release trunk conductor 2441. Relay 2509 upon operating, also marks the line of the called subscriber engaged by connecting earth to the private normal conductor 2575 over the following circuit: earth, contact 2545, contact 2550, wiper 2557, bank contact 2563, private normal conductor 2575.

When the called subscriber replies by lifting his receiver off the switch hook a loop is completed across conductors 2568 and 2572

and relay 2506 operates in the following circuit: battery, either of contacts 2588 and 2589, lower winding of relay 2506, contact 2526, contact 2541, contact 2548, wiper 2556, contact 2562, conductor 2568, loop at called subscriber's sub-station, conductor 2572, bank contact 2567, wiper 2561, contact 2555, contact 2547, contact 2532 to earth. 70

Relay 2506 upon operating closes a locking circuit for itself as follows: battery, upper winding of relay 2506, contact 2530, contact 2521 to earth. Relay 2506 also disconnects ringing current from the called subscriber's line at contacts 2532 and 2526, ring back tone is disconnected from the calling subscriber's line at contact 2527, and relay 2501 is connected to the loop across conductors 2568 and 2572. Relay 2501 thereupon operates in the following circuit: battery, upper winding of relay 2501, contact 2528, contact 2541, contact 2548, wiper 2556, contact 2562, conductor 2568, loop at called subscriber's sub-station, conductor 2572, contact 2567, wiper 2561, contact 2555, contact 2547, contact 2531, lower winding of relay 80 85 90 95 100

2501 to earth. Relay 2501 then operates and reverses the battery connections to conductor 2434 and 2448, battery being connected to the lower speaking conductor as follows: battery, upper winding of relay 2502, contact 2516 to the lower speaking conductor 2448, and earth being connected to the upper speaking conductor as follows: earth, lower winding of relay 2502, contact 2513 to the upper speaking conductor 2434. 100

Returning now to the repeater translator, it will be remembered that the polarizing winding of relay 2207 was completed at contact 2256 of relay 2211. When the battery connections to the speaking conductors are reversed when the called subscriber responds, relay 2207 operates and short circuits the high resistance 2283 at contact 2241. When the high resistance is now short-circuited, the current flow over conductors 2131 and 2132 is increased sufficiently to cause relay 2152 to energize and thereby control metering or like operations in a manner which is well known in the art and which is therefore not illustrated. The speaking circuit is now completed, and the subscribers may converse. 110 115 120

The calling subscriber is fed with battery from relay 2153 in the following circuit: battery, upper winding of relay 2153, contacts P2 and P1 in position 12 of sequence switch SSP conductor 2112 and thence through the secondary and primary line finders, subscriber's loop, primary and secondary finders, conductor 2113, contacts O2 and O1 in position 12 of sequence switch SSP, lower winding of relay 2153 to earth. 125

When the conversation is finished, the subscribers hang up their receivers, and when the calling subscriber hangs up relay 2153 130

releases and opens contact 2150 so that earth is removed from the upper speaking conductor and the circuit of relay 2151 in the primary selector PS and relay 2205 in the 5 repeater translator RT is opened, and these relays release. At contact 2240 relay 2205 opens the locking circuit of relay 2201 which releases after a short interval and opens the locking circuit of relay 2204 which also releases and opens the circuit of relay 2211. 10

Relay 2304 also releases when its circuit is opened at contact 2237 and the repeater translator is now in its normal position. Relay 2211 opens the loop to selector S4 at 15 contact 2255 and relay 2502 thereupon releases and opens the circuit of relay 2503, relay 2503 accordingly releases and at contact 2521 opens the locking circuits of relays 2506 and 2509 which accordingly 20 energize, and at contact 2522 removes earth from the release trunk conductor 2441. When relay 2506 releases or when the called subscriber hangs up whichever may happen first, relay 2501 releases and a circuit is completed 25 as follows: earth, contact 2520, contact 2524, contact 2518, contact 2587, winding of magnet 2583 to battery, the release magnet operates and releases the shaft of the switch which thereupon restores to normal.

30 In the primary selector relay 2152 upon releasing causes the sequence switch SSP to pass into position 14, whereupon the switch is restored to normal in the well-known manner as well as the finder switches PF and SF.

35 When relay 2211 released earth was removed from conductor 2280 at contact 2257 and when relay 2503 in the final selector releases the remaining earth at contact 2522 was removed whereupon relay 2405 in selector S2 and the 40 corresponding relay in selector S3 releases. When relay 2405 releases a circuit is completed as follows: earth, contact 2425, contact 2410, contact 2413, off-normal contact 2414, winding of release magnet 2408 to battery. Magnet 2408 energizes and causes the 45 selector switch S2 to restore to normal. The release magnet of the selector S3 operates in a similar manner to release the switch S3. If the called subscriber is busy, earth will 50 be encountered on contact 2563, and a circuit completed for relay 2507 before relay 2508 releases as follows: battery, winding of relay 2507, contact 2544, contact 2539, contact 2550, wiper 2557, contact 2563 to earth. Relay 2507 55 operates and when relay 2508 releases is locked up in the following circuit: battery, winding of relay 2507, contact 2544, contact 2538, contact 2534, contact 2522 to earth. Busy tone is connected up at contact 2536, 60 from the busy tone transformer 2590. When the calling subscriber receives the tone he hangs up. The step-by-step switches then release as before while the release of the register controller takes place in known manner.

65 It will be remembered that the holding

circuit for relay 2211 in the repeater translator is provided by relay 2203 prior to and during the time that revertive impulses are being sent back to the register by relay 2208 during the actual transmission of impulses 70 either backwards or forwards and by relay 2204 during the pause which ensues between the termination of one complete operation of the counting relays and the commencement of the next operation, the opening of the circuit for short intervals is ineffective since relay 2211 is slow to release. 75

During the reception and sending of the thousands and hundreds digits relay 2204 is 80 held operated in dependence upon relays 2201 and 2205, consequently means are provided for a preliminary release of the connection before the hundreds digit has been sent back, by a permanently opening the fundamental circuit at the register. The release of the 85 register when the calling subscriber hangs up prematurely may be described briefly. When the calling subscriber hangs up, sequence switch SSI passes into position 17, sequence switch SSR passes into position 1 after the 90 registers have restored to normal and sequence switch SSI then passes into position 1. The permanent opening of the fundamental circuit causes relays 2205 and 2202 and in consequence all the relays dependent upon 95 them, to release. Relay 2211 effects the release of the step-by-step switches by opening contact 2255.

It will be noted that during the release of 100 the register a fundamental circuit is closed over contacts P3 and P2 in positions 6-14 of sequence switch SSI, then opened in positions 15 and 16 and again closed over contacts P2 and P1 in position 17 of sequence switch SSI, before the fundamental circuit 105 is finally permanently opened.

If the hundreds digit has been sent back then when the fundamental circuit is closed relay 2202 operates in the following circuit: 110 battery, winding of relay 2202, resistance 2282, contact 2218, conductor 2132, contact 2135, brush 2130, contacts N2 and N3 in position 9 of sequence switch SSP, brush 2121, contact 2122, contacts P2 and P1 in position 17 of sequence switch SSI, contact 2123, brush 2120, contacts C3 and C2 in position 9 of sequence switch SSP, brush 2129, contact 2134, conductor 2131, contact 2212 to earth. Relay 2202 operates and completes a circuit 115 for relay 2203 over contacts 2222 and 2249. Relay 2203 completes a circuit for relay 2211 at contact 2226. 120

A circuit is also completed for relay 2209, and relays 2209 and 2208 operate alternately as previously described. When the relay set 125 has been completely operated, relay 2204 is operated over the previously traced circuit and completes the following circuit: earth, contact 2237, contact 2235, conductor 2264, contact 2332, contact 2318, contact 2322, up- 130

per winding of relay 2303 to battery. It also opens the locking circuits of the counting relays 2305—2309 and the circuit of relay 2209 at contact 2234. The counting relays restore to normal and impulsing ceases.

6 By this time, the fundamental circuit is opened and relay 2202 releases, which is followed by the release of relay 2203 after a short interval during which relay 2201 operates but only momentarily as there is no locking circuit for it. Relay 2204 is locked up in the following circuit: battery, winding of relay 2204, contact 2202, contact 2208, conductor 2258, contact 2254, contact 2230, contact 2224, conductor 2268, contact 2256 to earth. After a short interval however the fundamental circuit is again closed in position 17 of sequence switch SSI and relays 2203 and 2202 again energize thereby opening the locking circuit of relay 2204. A further series of retractive impulses are then transmitted so that when relay 2204 again energizes relay 2304 energizes, relay 2303 having energized when relay 2204 de-energized. 20 There is now no locking circuit for relay 2204 and consequently this relay can at once release; the fundamental circuit is now permanently open and all the relays de-energized.

25 Relay 2205, it will be recalled, is connected across the speaking conductors after each digit has been completely sent to the step-by-step switches and before a final selector has been seized this relay is maintained operated until the register steps into the next sending position. If the thousands digit has been sent the register steps into its hundreds sending position and relay 2205 thereupon opens the circuit of relay 2204 which releases; relay 2301 then operates completely. Relay 2302 similarly operates completely when the register steps into its tens sending position and relay 2303 operates completely immediately the vertical motion of the final selector has been completed. Relay 2303 upon operating, 30 removes the short circuit across resistance 2283 at contact 2326. Relay 2304 operates immediately the rotary movement of the final selector has been completed, and completes the speaking circuit.

35 It is assumed that the units digit was 6 and the hundreds digit was 8, then referring to the table of impulses it will be seen that five impulses are required to be sent back by the repeater translator before the fundamental circuit is opened, but if the hundreds digit had been odd fifteen impulses would have been required. As the fundamental circuit is still open and relay 2203 is still energized the counting relays will continue to operate until eleven impulses have been sent back, whereupon a circuit is completed as follows: battery, winding of relay 2210, conductor 2263, contact 2343, contact 2350, contact 2337, contact 2260, contact 2230, conductor 2262, contact 2356, contact 2364 to earth.

40 It will be remembered that as soon as relay 2202 is operated, contact 2245 of relay 2208 is short-circuited and hence no impulses are being sent to the step-by-step switches. Relay 2210 upon operating, opens contact 2254 and thereby removes earth from conductor 2280, whereupon relay 2510 in the final selector operates over the following circuit: battery, winding of relay 2404, contact 2419, contact 2424, winding of relay 2405, contact 2423, wiper 2435, contact 2436, conductor 2437. A similar circuit in parallel is at this point connected up in selector S3 over conductor 2438, conductor 2435, contact 2440, conductor 2441, upper winding of relay 2510, 45 contact 2522 to earth.

50 Relay 2510 operates and closes a locking circuit for itself as follows: battery, lower winding of relay 2510, contact 2552, contact 2522, to earth, and short-circuits its upper winding at contact 2553. Relay 2510 also closes contacts 2549, 2551 and 2554 thereby transferring the trunk conductors to the set of wipers connected to the lower banks. Relay 2210 in the repeater translator also opens 55 the locking circuit of the counting relay set at contact 2251, and with the exception of relay 2305 these relays restore to normal.

55 A circuit is maintained, however, for relay 2305 as follows: battery, upper and lower 60 windings of relay 2305 in series, contact 2341, conductor 2276, contact 2252 to earth. A locking circuit for relay 2210 is therefore provided as follows: battery, winding of relay 2210, contact 2229, contact 2250, contact 2234, 65 contact 2256 to earth. Relay 2210 also opens the circuit of relay 2203 at contact 2249 but this relay is slow to release and maintains relay 2210 operated for a short period and relay 2210 also opens the circuit of relay 2209 70 at contact 2248, and the transmission of retractive impulses is arrested.

75 After a short interval, relay 2203 releases and is followed by relay 2210 which transfers the locking circuit for relay 2305 from earth on conductor 2202 to earth on contact 2256 over contact 2254, contact 2251, conductor 2278, contact 2369, contact 2361, contact 2355, contact 2363, contact 2349, contact 2370, conductor 2277, contact 2253, contact 2248 is again closed, and the transmission of the retractive impulses recommences. The locking circuit of the counting relay set is again closed at contact 2251 and impulses are transmitted to the counting relays over conductor 2275. The first impulse operates relay 2306, and the next impulse operates relay 2307 and the operation proceeds until a total of fifteen impulses have been sent back.

80 Since eleven impulses were sent back before relay 2210 operated, a further four impulses will be required and when relay 2309 operates and the fifteenth impulse is sent back the fundamental circuit is opened, relay 2202 releases and opens the circuit of relay 2209.

2203. The further operation takes place as previously described and need not be repeated in this connection.

In Figs. 24 and 24a an alternative arrangement to that shown in Figs. 20 and 20a is provided for the purpose of working with a different type of revertive control system from that described with relation to Fig. 19. The principal difference between these circuits is in connection with the release arrangements and more particularly in that when trunking takes place to another exchange no holding circuit to the switches of the distant exchange is provided from the register. Consequently the switches in the step-by-step exchange while they are in calling position must be controlled locally by a time release arrangement. For the purpose of working in such a system Figs. 20 and 20a have been modified to produce the register translator RT1 as shown in Figs. 24 and 24a by the addition of four relays, namely, 3601, 3602, 3621 and 3622. The first figure in the references to the relays which are common to both arrangements has been altered from 2 to 3, but the other three figures are the same, so that the identity of the various contacts and relays can be readily traced.

In making the statement that no holding circuit to the distant exchange is provided, it should be understood that there is no arrangement for holding up the relay 3205 during the setting of the switches, that is to say, there is no feeding forward of battery in between the various digits. Instead of that the fundamental circuit is opened and remains open until the register is in readiness to respond to the next series of revertive control impulses. It has therefore not been necessary to show a new figure corresponding to Fig. 19.

When the fundamental circuit is first closed a circuit is completed as follows: battery, resistance 3604, contact 3603, conductor 3181, over the fundamental circuit, conductor 3132, contact 3608, winding of relay 3602 to earth. Relay 3602 energizes and at contact 3633 completes a circuit for relay 3601. Relay 3601 accordingly energizes and thereupon by closing contacts 3605 and 3607 establishes a fundamental circuit similar in every respect to the fundamental circuit which was described in connection with Fig. 10. Relay 3602 is of very high resistance and therefore the relay in the register corresponding to relay 2109 does not respond until relay 3202 is connected up.

When relay 3601 operates a circuit is completed for relay 3211 as follows: earth, contact 3606, contact 3609, winding of relay 3211 to earth. Relay 3211 operates and at contact 3610 completes a holding circuit for relay 3601. When contacts 3605 and 3607 close, relay 3202 operates and is followed by the operation of relay 3203.

Relay 3602 has its circuit opened at contacts 3603 and 3608 and after a short interval releases, but without effect since relay 3211 is maintained operated over contact 3226 and relay 3601 is maintained operated over contact 3610. The setting up of a connection is similar to that already described except that because relay 3202 is not energized over the fundamental circuit in between the impulse series, relay 3203 is arranged to control the locking circuit of relay 3204. This locking circuit may be traced as follows: battery, winding of relay 3204, contact 3232, contact 3228, conductor 3258, contact 3334, conductor 3268, contact 3256 to earth.

It will be recollected that this is similar to the locking circuit which was provided after the tens digit had been transmitted by the repeater translator RT. In the present case, however, a locking circuit has also to be established after the thousands digit and after the hundreds digit has been transmitted by the repeater translator so that the holding circuit of relay 3204 is only opened when the fundamental circuit is again closed at the register controller due to the registration of the next digit. This is accomplished by connecting conductor 3258 directly to earth over contacts 3334 and 3256 whereas in the previous case it passed over contacts 2314 and 2320, and in that case the holding circuit over conductor 2258 is held open at contact 2320 until the register translator RT has transmitted the hundreds digit, to the step-by-step switches and the tens digit has been registered by the calling subscriber.

As will be readily seen, in the present arrangement if for any reason the fundamental circuit should not be again closed, then relay 3204 will be maintained locked energized. This might occur due either to the subscriber delaying to complete his dialling, or to the subscriber hanging up prematurely. In either case the relays 3621 and 3622 would control the release as can now be followed.

If the subscriber delays to complete his dialling the repeater translator RT1 continues to operate until all the digits registered by the calling subscriber have been dealt with, relay 3204 then locks operated; in any case the repeater translator stops its operation with relay 3204 locked operated and holds the step-by-step switches operated until relay 3304 operates, since relay 3211 is held operated in the following circuit: battery, winding of relay 3211, conductor 3267, contact 3330, conductor 3270, contact 3233, contact 3256 to earth.

As soon as relay 3211 operates, the time pulse lead 3612 is connected at contact 3611 as follows: conductor 3612, contact 3611, conductor 3613, contact 3630, contact 3623, upper winding of relay 3621 to battery. Earth is momentarily connected to the time pulse lead, say, every thirty seconds, so that after

an interval of up to thirty seconds earth is connected to the upper winding of relay 3621 over this circuit and relay 3621 partially energizes to close contact 3625 only. When 5 earth is removed from conductor 3612, relay 3621 operates completely in the following circuit: battery, upper and lower windings of relay 3621 in series, contact 3625, contact 3629, conductor 3268, contact 3256 to earth. 10 If the connection is not completed within thirty seconds from the energization of relay 3621, earth is again connected to the time pulse lead 3612 and a circuit is completed for the upper winding of relay 3622 in the following 15 circuit: earth, on conductor 3612, contact 3611, conductor 3613, contact 3630, contact 3624, upper winding of relay 3622 to battery. Relay 3622 operates partially to close contact 3627 only and on the removal of 20 earth from the time pulse lead shortly after, relay 3622 operates fully in the following circuit: battery, upper and lower windings of relay 3622 in series, contact 3627, contact 3629, conductor 3628, contact 3256 to earth. 25 Relay 3622 on operating fully closes contacts 3626, 3632 and 3628. At contact 3626 a circuit is completed for relay 3201 as follows: battery, winding of relay 3201, conductor 3631, contact 3626, contact 3629, conductor 3268, contact 3256 to earth. Relay 30 3201 operates in this circuit and connects through the speaking conductors and closes a locking circuit for itself as follows: battery, winding of relay 3201, contact 3214, contact 3239, contact 3256 to earth. At contact 3632 a circuit is completed for relay 3204 as follows: battery, winding of relay 3204, conductor 3285, contact 3632, contact 3629, conductor 3268, contact 3256 to earth. 35 At contact 3628 a circuit is completed for relay 3304 as follows: earth, contact 3256, conductor 3268, contact 3629, contact 3628, winding of relay 3304 to battery. Relay 3304 accordingly energizes and changes the 40 locking circuit of relay 3211 to the following circuit: battery, winding of relay 3211, conductor 3267, contact 3328, conductor 3271, contact 3240 to earth. 45 When relay 3205 releases, or if it has already released, the circuit of relay 3211 will be opened at contact 3240, relay 3211 thereupon releases and opens the loop circuit to the step-by-step switches at contact 3255, and all the step-by-step switches release. 50 Relay 3304 upon operating opens the circuit of relays 3201, 3621 and 3622 at contact 3629, and opens the locking circuit of relay 3204 at contact 3334, the locking circuit of relay 3201 is also opened; relays 3201, 3621 and 55 3622 then release and are followed by the release of relay 3304. When relay 3211 releases the circuit of relay 3601 is opened and this relay releases to reverse the battery connections to the trunk line and thereby mark 60 the trunk line as being idle.

I claim:

1. An automatic or semi-automatic telephone system including a step-by-step exchange and a revertive control exchange characterized in that a translating arrangement is provided in the step-by-step exchange to enable the switches in the step-by-step exchange to be operated by revertive control from the revertive control exchange. 70

2. An automatic or semi-automatic telephone system including a step-by-step exchange and a revertive control exchange characterized in that a translating arrangement is provided in the step-by-step exchange to enable the switches in the revertive control exchange to be operated from the step-by-step exchange. 75 80

3. An automatic or semi-automatic telephone system including a step-by-step exchange and a revertive control exchange characterized in that certain of the switches in the step-by-step exchange are arranged to have a plurality of sets of wipers so as to increase their capacity to that of the corresponding switches in the revertive control exchange, in which a repeater translator adapted to be taken into use and controlled from a register controller in the revertive control exchange is arranged to transmit a plurality of series of impulses to operate switches in the step-by-step exchange, and when controlled in a particular way causes a different set of wipers of one of said step-by-step switches to be selected. 90 95

4. An automatic or semi-automatic telephone system including a step-by-step exchange and a revertive control exchange characterized in that a register controller which is adapted to be associated with a trunk line used for calls from the step-by-step exchange to the revertive control exchange is provided with relay register sets adapted to operate while a calling subscriber is dialling a number to register the digits dialled other than those utilized in selecting the said trunk line and is adapted subsequently to control the setting of the revertive control switches. 100 105 110

5. An automatic or semi-automatic telephone system employing register controllers for controlling the operation of revertive control switches in which a relay is provided in the trunk relay group from which a register controller is adapted to be seized, said relay being adapted to be operated if a subscriber replaces his receiver before completing a call to guard the calling line until the revertive control switches have restored to normal. 115 120

6. An automatic or semi-automatic telephone system employing register controllers for controlling the operation of revertive control switches in which a relay is provided in the trunk relay group from which a register controller is adapted to be seized, said relay being adapted to be operated if a subscriber 125 130

delays to dial after initiating the setting up of a connection to enable the register controlled to be isolated and to prevent any register controller associated with said relay group from being taken into use until the subscriber has replaced his receiver.

7. An automatic or semi-automatic telephone system in which a register controller is adapted to be selected in readiness for a call to be set up over a trunk line and is adapted to be taken into use immediately said trunk line is selected by a group selecting switch.

8. An automatic or semi-automatic telephone system comprising an exchange having switches arranged on a non-decimal basis and an exchange having step-by-step switches arranged on a decimal basis characterized in that the step-by-step switches in the second exchange which are taken into use by subscribers of the first exchange are arranged on similar non-decimal basis to the switches in the first exchange.

9. An automatic or semi-automatic telephone system comprising an exchange having switches arranged on a non-decimal basis and an exchange having step-by-step switches arranged on a decimal basis in which the step-by-step switches in the second exchange are arranged on a similar non-decimal basis to the switches in the first exchange and in which the different controlling effects exerted to determine the operation of the various ranks of switches taken into use in the second exchange through the intermediary of a repeater translator are arranged to be entirely independent of each other in the repeater translator itself.

10. A register controller for controlling the operation of revertive control switches in which a set of counting relays is provided for each digit to be registered, each set of relays after registering the dialled digit being subsequently operated by impulses transmitted back from the revertive control switches characterized in that one of said sets after being operated in the manner described is subsequently operated by a fixed number of impulses transmitted back from the revertive control switches.

11. A register controller for controlling the operation of revertive control switches in which a set of counting relays is provided for each digit to be registered, each set of relays after registering the dialled digit being subsequently operated by impulses transmitted back from the revertive control switches characterized in that the total number of impulses required to operate a relay set is adapted to vary by arranging for the relay sets when nearing the completion of their operation to successively close contacts in different circuits the particular circuit to be closed depending upon the value of the

digit registered and/or upon the value of a previous digit.

12. A register controller for controlling the operation of revertive control switches in which a pair of relays are adapted to respond to each series of impulses which is to be registered and are arranged to take up alternately one position or another as each impulse is received and according to the position they are in when an impulse series terminates are arranged to exert a controlling influence upon the number of revertive control impulses to be received for that particular series and/or for a subsequent series of impulses.

13. A register controller for controlling the operation of revertive control switches in which the series of impulses generated by a calling subscriber and the series of impulses generated by the revertive control switches are received on counting relay sets while the distribution of the various series of impulses to the counting relay sets is also effected by means of relays.

14. A register controller for controlling the operation of revertive control switches comprising a counting relay set for each digit to be registered which receives both the impulses dialled by a calling party and the impulses sent back from the revertive control switches, auxiliary relays which determine the total number of impulses to be received by the various counting relay sets, a pair of relays which respond differently according as to whether the various series of impulses are odd or even and which are adapted to control the operation of the auxiliary relays, and relay sets which control the distribution of the various series of impulses and the operation of the auxiliary relays.

15. A register controller for controlling the operation of revertive control switches including a set of relays which are arranged to be operated in the event of a subscriber delaying to dial or replacing his receiver prematurely so as to control the restoration of all the switches which have moved off-normal by successively opening and closing the fundamental circuit.

16. A register controller for controlling the operation of revertive control switches and adapted to be selected if idle from a trunk relay group individual to a trunk over which a talking connection is set up in which guarding potential is normally provided from the trunk relay group under the direct control of the calling subscriber until the revertive control switches all have been positioned so that the release of the register controller can be brought about on the subscriber replacing his receiver.

17. A register controller for controlling the operation of revertive control switches in which if a subscriber delays to dial after initiating the setting up of a connection a

- set of relays is adapted to be operated the operation of said relays being different according as to whether the delay takes place before or after a certain number of series of revertive impulses have been received.
18. A register controller for controlling the operation of revertive control switches in which a subscriber replaces his receiver prematurely a set of relays is adapted to be operated the operation of said relays being different according as to whether the subscriber replaces his receiver before or after a certain number of series of revertive impulses have been received.
19. A register controller for controlling the operation of revertive control switches over a fundamental circuit in which the relay which opens the fundamental circuit after the completion of a series of revertive impulses is adapted to connect battery to one conductor and earth to the other conductor of the fundamental circuit until everything is in readiness for the transmission of the next series of impulses.
20. A repeater translator for use in telephone systems comprising an impulse sender adapted to generate a plurality of series of impulses each series comprising a predetermined number of impulses, certain of said impulses in each series being transmitted in one direction and the remainder being subsequently transmitted in another direction characterized in that if the number of impulses transmitted in the first direction for one of said series should reach a predetermined number a special control is exerted in the other direction without any impulses being transmitted in that direction and an additional series of impulses is thereupon transmitted, part of which is transmitted in the first direction and the remainder of which is transmitted in the other direction.
21. A repeater translator for use in telephone systems comprising an impulse sender adapted to generate a plurality of series of impulses each series comprising a predetermined number of impulses certain of said impulses in each series as determined by the receiving apparatus being transmitted in one direction and the remainder being subsequently transmitted in another direction characterized in that different circuits are closed after a series of impulses have been generated so that the predetermined number of impulses in the series can be varied.
22. A repeater translator for use in telephone systems and adapted to transmit impulses in one direction to a register controller over a fundamental circuit and to transmit impulses in another direction to step-by-step switches in which a relay in the repeater translator is held operated by current which is fed forward from the register controller after a series of impulses registered on the register controller has effected the operation of a step-by-step switch and until the next series of impulses has been registered, whereupon the relay releases and causes the fundamental circuit to be completed.
23. An impulse sender for use in telephone systems comprising a pair of relays adapted to alternately energize and de-energize and adapted to control, in combination with a set of counting relays, the transmission of impulses over an external circuit; the counting relays being adapted to be operated successively under the control of said pair of relays for a predetermined number of impulses, which is greater than the number of relays in the set, independent means being provided for causing a selected number only of said impulses to be transmitted over the external circuit.
24. A step-by-step switch for use in telephone systems having two sets of wipers in which a winding of a relay which is adapted to select the required set of wipers is connected to the test conductor and is adapted not to be operated when guarding potential is connected to the test conductor at a previous point in the connection and to be operated when said potential is connected to the test conductor through only the winding of the switching relay.
25. An automatic or semi-automatic telephone system as claimed in claim 4 in which the operation of one relay register set is adapted to modify the control of another relay register set which is to be operated subsequently.
26. An automatic or semi-automatic telephone system as claimed in claim 7 in which the trunk line is adapted to be taken into use by a step-by-step group selecting switch and to be normally associated with a revertive control switch.
27. An automatic or semi-automatic telephone system as claimed in claim 8 in which the final selector switches of the first exchange have access to two hundred lines and the final selector switches of the step-by-step exchange have access to one hundred lines over one set of wipers and to another hundred lines over a second set of wipers characterized in that the final selector switches are accessible in common to subscribers of both exchanges as regards the groups of one hundred lines available over one set of wipers and, that as regards the groups of one hundred lines available over the alternative set of wipers, final selector switches are provided available only to subscribers in the step-by-step exchange.
28. A register controller as claimed in claim 16 in which if the calling subscriber replaces his receiver prematurely a guarding potential is adapted to be fed forward from the register controller immediately the application of guarding potential from the trunk relay group ceases said first potential per-

sisting while the revertive control switches are being operated to a position in which they automatically release.

29. A register controller as claimed in claim 5 17 in which the set of relays is adapted to control the opening and closing of the fundamental circuit extending to the revertive control switches.

30. A register controller as claimed in claim 10 19 in which the relay is adapted to be locked energized over two independent circuits one of said circuits being dependent upon the condition of the revertive control switches the other being dependent upon the 15 registration of the next digit.

31. A repeater translator as claimed in claim 20 20 in which a stepping device is successively operated for each series of impulses generated, which stepping device according 25 to its setting determined the predetermined number for the next series of impulses.

32. An impulse sender as claimed in claim 23, characterized in that the first impulse or impulses of a series up to the selected number 25 are transmitted over an external circuit.

33. An impulse sender as claimed in claim 23 in which the last impulse or impulses of a series depending upon the number selected are transmitted over an external circuit.

34. An impulse sender as claimed in claim 23 in which the counting relays are arranged to successively close contacts in different circuits, independent controlling means being provided to cause a particular one of said 25 circuits when closed to be effective to arrest the generation of impulses.

35. A step-by-step switch as claimed in claim 24 in which said winding is of low resistance and is connected in series with the 40 test conductor the relay being adapted to lock operated over a second winding and short circuit said low resistance winding.

36. A register controller as claimed in claim 18 in which the set of relays is adapted 45 to control the opening and closing of the fundamental circuit extending to the revertive control switches.

37. A repeater translator as claimed in claim 21 in which a stepping device is successively operated for each series of impulses generated, which stepping device according 50 to its setting determined the predetermined number for the next series of impulses.

38. An impulse sender as claimed in claim 23, characterized in that the first impulse or impulses of a series up to the selected number 55 are transmitted over an external circuit, and in that the last impulse or impulses of a series depending upon the number selected are transmitted over an external circuit.

39. An automatic or semi-automatic system including a step-by-step exchange and a revertive control exchange with trunk lines 60 comprising only two conductors each extend-

ing from the revertive control exchange to the step-by-step exchange, characterized in that translating apparatus is provided in the step-by-step exchange to cooperate with the senders in the revertive control exchange by revertive control exercised over said two-conductor trunk lines to enable the switches in the step-by-step exchange to be operated from the revertive control exchange.

40. An automatic or semi-automatic system including a step-by-step exchange and a revertive control exchange interconnected with the step-by-step exchange by a plurality of trunk lines extending from the step-by-step exchange to the revertive control exchange and comprising only two conductors each, characterized in that translating apparatus is provided in the step-by-step exchange arranged to be set responsive to the step-by-step impulses and to exercise the revertive control over the switches in the revertive control exchange over said two-conductor trunk lines.

41. In a multi-exchange telephone system, an exchange wherein the connections are set up through automatic switches controlled in a given way, a second exchange wherein the connections are set up through automatic switches controlled in a different way, trunk lines extending from the first-named exchange to the second exchange, means effective when a call is made from a line of the first exchange to a line of the second exchange for taking one of said inter-exchange trunk lines for use in the first exchange, register-senders in the first exchange arranged to respond to control in the manner of the switches in the first exchange and to exercise the different control necessary to set the switches in the second exchange, means effective upon any one of said trunk lines being taken for use in the first exchange for rendering one of said register-senders temporarily individual to such trunk line, and means including a timing device for automatically restoring said register-sender to common use at the end of a predetermined time.

42. In a multi-exchange telephone system, an exchange wherein the connections are set up through automatic switches controlled in a given way, a second exchange wherein the connections are set up through automatic switches controlled in a different way, trunk lines extending from the first-named exchange to the second exchange, means effective when a call is made from a line of the first exchange to a line of the second exchange for taking one of said inter-exchange trunk lines for use in the first exchange, register-senders in the first exchange arranged to respond to control in the manner of the switches in the first exchange and to exercise the different control necessary to set the switches in the second exchange.

second exchange, means effective upon any one of said trunk lines being taken for use in the first exchange for rendering one of said register-senders temporarily individual to such trunk line, means including a timing device for automatically restoring said register-sender to common use at the end of a predetermined time, and means dependent upon said register-sender being controlled from the calling line in accordance with the number of a desired line for disabling the last-named means.

43. An automatic or semi-automatic telephone system employing register controllers for controlling the operation of revertive control switches as claimed in claim 2 in which a relay (164) is provided in the trunk relay group from which a register controller is adapted to be seized, said relay being adapted to be operated if a subscriber replaces his receiver before completing a call to guard the calling line until the revertive control switches have restored to normal.

44. An automatic or semi-automatic telephone system employing register controllers for controlling the operation of revertive control switches as claimed in claim 2 in which a relay (165) is provided in the trunk relay group from which a register controller is adapted to be seized, said relay being adapted to be operated if a subscriber delays to dial after initiating the setting up of a connection to enable the register controller to be disconnected and to ensure that the relay group will be no longer effective to take a register controller into use until the subscriber has replaced his receiver.

45. A register controller for controlling the operation of revertive control switches in telephone systems as claimed in claim 2, and adapted to be selected if idle from a trunk relay group in which guarding potential is normally provided from the trunk relay group under the direct control of the calling subscriber, so that the release of the register controller can be brought about on the subscriber replacing his receiver.

46. A register controller for controlling the operation of revertive control switches in telephone systems as claimed in claim 2, and adapted to be selected if idle from a trunk relay group in which guarding potential is normally provided from the trunk relay group under the direct control of the calling subscriber, so that the release of the register controller can be brought about on the subscriber replacing his receiver, in which if the calling subscriber replaces his receiver prematurely a guarding potential is adapted to be fed forward from the register controller immediately the application of guarding potential from the trunk relay group ceases, said first potential persisting while the revertive control switches are being operated

to a position in which they automatically release.

In witness whereof, I hereunto subscribe my name this second day of August, A. D. 1928.

JOHN WICKS.
